UNITED STATES PATENT OFFICE.

LAURENCE E. TOPHAM, OF SWAMPSCOTT, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SHOE MACHINE.

Application filed April 9, 1917. Serial No. 160,751.

This invention relates to shoe machines, and is herein shown as embodied in a machine for operating upon shoes in which the shoe and the means for operating upon the shoe are moved relatively to transfer the point of operation about the shoe and to change the relative positions of the shoe and the operating means to present the shoe properly to the operating means as the point of operation is transferred about the shoe, and in which the shoe is supported in operating position in the machine, and all of its movements are effected and controlled by automatically acting mechanisms.

Certain features of the invention, however, are not limited to machines for operating upon shoes which are wholly automatic in character, but may be embodied in machines in which certain of the movements of the shoe are imparted by the operator. Certain features of the invention also are not limited to automatic machines for operating on shoes, but may be employed in automatic machines for operating upon the parts of shoes before they are assembled. Certain other features of the invention are not limited to automatic shoe machines, but may be embodied with advantage in machines for operating upon shoes in which the shoe is held and manipulated by the operator.

The primary objects of the invention are to improve the construction and mode of operation of automatic shoe machines of the type in which the relative positions of the shoe and the operating means are changed to cause the shoe to be presented properly to the operating means as the point of operation is transferred about the shoe, and to provide such machines with novel and improved mechanism for automatically changing the relative positions of the shoe and the means for operating upon the shoe as the point of operation is transferred about the shoe which will improve the efficiency and reliability in operation of such automatic machines. With these objects in view, a feature of the invention contemplates the provision of mechanism controlled from the shoe for adjusting the time relations of the mechanism for moving the shoe to transfer the point of operation about the shoe which will be hereinafter termed the feeding mechanism, and the mechanism for changing the relative positions of the operating means

and the shoe to present the shoe properly to the operating means. This feature of the invention has two different embodiments in the machine hereinafter described. In one embodiment of this feature of the invention, means controlled from the shoe is provided for adjusting the time relation of the feeding mechanism and the position changing mechanism, in accordance with the size of the shoe to be sewn, upon the placing of the shoe in the machine. In the preferred form of this embodiment of the invention the relative speeds of the feeding means and the position changing mechanism are adjusted in accordance with the size of the shoe to be sewn upon the placing of the shoe in the machine through a connection with the jack upon which the shoe is supported in the machine during the operation thereon. In the second embodiment of this feature of the invention means controlled from the shoe is provided which is arranged to operate automatically during the operation of the machine to adjust the relative speeds of the feeding mechanism and the position changing mechanism to restore the shoe and the position changing mechanism to their proper time relations when they are out of time.

The provision of means arranged to operate automatically during the operation of the machine to adjust the relative speeds of the feeding and the position changing mechanism to restore the shoe and the position changing mechanism to their proper timed relations when they are out of time is also considered to be a feature of the present invention, whether or not such means is controlled from the shoe. In machines for operating upon shoes such as shoe sewing machines in which the feed movements of the shoe are produced by feeding devices acting directly on the shoe, the shoe is not fed a uniform or predetermined distance during each cycle of operations but indeterminate variations occur in the rate of feed. This feature of invention when embodied in such machines or in other shoe machines in which the feed movements of the shoe are indeterminately variable enables a position changing mechanism to be employed which acts continuously or at regular intervals or during each cycle of operations of the machine so that the relative movements of the shoe and the operating means are rendered

smoother and more uniform than in automatic shoe sewing machines or in other automatic shoe machines having an indeterminately variable feed heretofore produced.

5 In the preferred form of this feature of the invention, the time relations of the feeding mechanism and the position changing mechanism are adjusted during the operation of the machine to restore the shoe and the position changing mechanism to their proper time relations, also through a connection with the shoe supporting jack.

A still further feature of the invention contemplates mounting the shoe supporting jack in the machine so that the end of the jack adjacent the point of operation and the end of the jack remote from the point of operation may each be moved independently of the other or any direction laterally of the jack or, in the present form of the invention, in any horizontal direction. This manner of mounting the jack enables the shoe to be moved in the direction of feed to transfer the point of operation about the shoe and transversely to the direction of feed to maintain the margin of the shoe bottom in its proper location laterally with relation to the operating means and also enables the jack to be tipped about axes extending longitudinally and transversely of the shoe to position the shoe properly with relation to the operating means. In the preferred form of the invention the movements of the shoe in the direction of the line of feed are produced and the location of the shoe in a direction transverse to the line of feed is controlled by devices engaging the shoe at or adjacent the point of operation, and the tipping movements of the shoe are produced and controlled by devices acting on the jack to move the end of the jack remote from the point of operation in directions laterally of the jack. This manner of mounting the jack results in a great improvement in and simplification of the jack supporting mechanism and also enables the jack moving mechanism to be greatly improved and simplified as compared with the corresponding mechanism of prior machines.

50 In addition to the above features, the invention comprises various other novel and improved features hereinafter described and particularly pointed out in the claims, the advantages of which will be understood and appreciated by those skilled in the art.

The features of the invention will be understood from the accompanying drawings illustrating a machine embodying the invention in its preferred form, and the following detailed description of the constructions therein shown.

In the drawings, Figure 1 is a view in front elevation of a machine embodying the invention; Fig. 2 is a view in side elevation of the machine, looking from the right;

Fig. 3 is a plan view of the machine; Fig. 4 is a view in vertical section, taken substantially on the line 4—4 of Fig. 3; Fig. 5 is a view in horizontal section, taken substantially on the line 5—5 of Fig. 1; Fig. 6 is a view in front elevation, partly broken away and partly in section, illustrating particularly certain parts of the driving and stopping mechanism for the machine; Fig. 7 is a view in side elevation illustrating the parts of the sewing mechanism; Fig. 8 is a detail plan view, partly in section, illustrating particularly parts of the sewing mechanism and parts of the driving and stopping mechanisms; Fig. 9 is a detail, 80 plan view illustrating particularly the mechanism for driving the pattern cam shaft; Fig. 10 is a detail view in side elevation, looking from the left-hand side of the machine, illustrating the mechanism for driving the pattern cam shaft and the mechanism for controlling the speed of the shaft; Fig. 11 is a detail plan view illustrating the mechanism for driving the pattern cam shaft and the mechanism for controlling the speed of the shaft; Fig. 12 is a view in front elevation of a portion of the mechanism illustrated in Fig. 11; Fig. 13 is a detail plan view illustrating a portion of the mechanism for supporting the jack and mechanism acting yieldingly on the jack, to hold the shoe in the machine and to eliminate back lash in certain of the parts; Fig. 14 is a detail view in elevation illustrating the jack frame and spindle; Fig. 15 is a view of the jack frame and spindle, looking from the left of Fig. 14; Fig. 16 is a view illustrating a tool for adjusting the parts of the jack in jacking the shoe; Fig. 17 is a detail plan view illustrating certain parts of the mechanism for supporting the jack and for tipping and turning the jack; Fig. 18 is a sectional view taken substantially on the line 18—18 of Fig. 17; Fig. 19 is a view in side elevation illustrating a portion of the mechanism shown in Fig. 13; Fig. 20 is a sectional view taken substantially on the line 20—20 of Fig. 13; Fig. 21 is a detail view in front elevation, partly in section, illustrating a portion of the pattern cam shaft and connections actuated thereby; Fig. 22 is a plan view of the mechanism illustrated in Fig. 21; Fig. 23 is a detail sectional view taken substantially on the line 23—23 of Fig. 22; Fig. 24 is a detail plan view illustrating a portion of the mechanism acting yieldingly on the jack, to hold the shoe in the machine and to eliminate back lash in certain of the parts; Fig. 25 is a detail view in side elevation, partly in section, illustrating a portion of the mechanism shown in Fig. 24 and certain driving connections; Figs. 26 and 27 are views in front elevation of the mechanism illustrated in Fig. 25; Fig. 28 is a sectional view, taken 130

substantially on the line 28—28 of Fig. 24; Fig. 29 is a sectional view taken substantially on the line 29—29 of Fig. 28; Fig. 30 is a sectional view taken substantially on the line 30—30 of Fig. 13; Fig. 31 is a detail view in front elevation illustrating the edge gage mechanism and the feed changing mechanism; Fig. 32 is a view in side elevation of the mechanism illustrated in Fig. 31, looking from the right; Fig. 33 is a sectional view taken substantially on the line 33—33 of Fig. 11; Fig. 34 is a detail plan view, partly in section, illustrating a portion of the mechanism shown in Fig. 11; Fig. 35 is a sectional view taken substantially on the line 35—35 of Fig. 11; Fig. 36 is a sectional view taken substantially on the line 36—36 of Fig. 9; Fig. 37 is a detail view in side elevation, looking from the left-hand side of the machine, illustrating portions of the mechanisms for controlling the speed of the pattern cam shaft and for tipping and turning the jack; Fig. 38 is a detail sectional view illustrating the pattern cam shaft and the cams mounted thereon, and taken substantially on the line 38—38 of Fig. 39; Fig. 39 is a sectional view taken substantially on the line 39—39 of Fig. 38; Fig. 40 is a detail view in front elevation illustrating certain parts of the mechanism for stopping the machine during or at the completion of the sewing of a seam; Fig. 41 is a view in front elevation of the mechanism illustrated in Fig. 40; Fig. 42 is a detail view in rear elevation, partly in section, illustrating certain parts of the mechanism for stopping the machine, and certain parts associated therewith; Fig. 43 is a sectional view taken substantially on the line 43—43 of Fig. 42; Fig. 44 is a plan view illustrating certain parts of the mechanism shown in Fig. 42; Figs. 45, 46, 47 and 48 are detail plan views illustrating in different positions the mechanism for stopping the machine, Figs. 45 and 47 each showing the parts adjusted for the sewing of a right shoe and respectively showing the positions of the parts upon stopping the machine as the pattern cam shaft is brought to starting position, and upon stopping the machine at the completion of the sewing of a seam, and Figs. 46 and 48 each showing the parts adjusted for the sewing of a left shoe, and respectively showing the positions of the parts upon stopping the machine as the pattern cam shaft is brought to starting position, and upon stopping the machine at the completion of the sewing of a seam; Fig. 49 is a detail view in front elevation, partly in section, illustrating certain parts of the mechanism for stopping the machine and for lifting the presser-foot at the completion of the sewing of a seam; Fig. 50 is a sectional view taken substantially on the line 50—50 of Fig. 49; Fig. 51 is a detail view in front elevation, partly in section, illustrating certain parts of the mechanism for stopping the machine; Fig. 52 is a detail view, partly in section, illustrating certain parts of the locking mechanism for locking the speed controlling mechanism for adjusting the speed of the pattern cam shaft for the size of the shoe to be sewn in position when the machine is started; Fig. 53 is a detail sectional view taken substantially on the line 53—53 of Fig. 8; Fig. 54 is a detail plan view illustrating the mechanisms for controlling the speed of the pattern cam shaft with the parts in the positions which they assume during the sewing operation when the shoe is fed faster than the predetermined rate for which the cam shaft is timed; Fig. 55 is a view similar to Fig. 54, with the parts in the positions which they assume when the shoe is fed slower than the predetermined rate; Figs. 56, 57 and 58 are plan views illustrating the mechanisms for controlling the speed of the pattern cam shaft in different positions which they assume during the sewing of a seam, Fig. 56 showing the positions of the parts of these mechanisms at the beginning of the seam, Fig. 57 showing the positions of the parts when the toe of the shoe is reached, and Fig. 58 showing the positions of the parts at the completion of the seam; Fig. 59 is a detail view in side elevation illustrating a portion of the mechanism shown in Fig. 7; and Fig. 60 is a view illustrating further details of the mechanism shown in Fig. 52.

In the form illustrated in the drawings of this application the invention is embodied in a machine the mechanism for operating upon the shoe of which consists of a sewing mechanism constructed and arranged for sewing outsoles to the welts of welted shoes. The broader features of the invention, however, are not limited to shoe sewing machines, but may be embodied with advantage in machines for performing various operations upon shoes or the parts of shoes.

In the illustrated embodiment, the invention comprises in addition to the sewing mechanism a jack upon which the lasted shoe is placed by the operator preparatory to the sewing of a seam, means for supporting the jack constructed and arranged to permit a lateral movement of the jack and shoe in the direction of feed to transfer the point of operation about the shoe and a movement transversely of the direction of feed to maintain the edge of the shoe bottom in the proper lateral relation to the stitch forming, work holding and work feeding devices of the sewing mechanism, mechanism for moving the jack to change the position of the shoe with relation to the devices for operating on the shoe to present the shoe properly to said devices as the point

of operation is transferred about the shoe bottom, means for driving the sewing mechanism and said jack moving mechanism during the sewing of the seam, devices for stopping the machine at the completion of the sewing of a seam, means for driving said jack moving mechanism independently of the sewing mechanism to bring the jack to starting position, and devices for stopping the machine when the jack has been brought to starting position.

The sewing mechanism of the machine illustrated in the drawing, with the exception of certain changes in the pull-off mechanism hereinafter described, is substantially the same in construction, arrangement and mode of operation of parts as that of the Goodyear rapid lockstitch machine for sewing outsoles, illustrated and described in the patent to French & Meyer, No. 473,870, dated April 26, 1892. This mechanism (see Figs. 1 and 7) comprises a curved hook needle 2, a work feeding awl 4, a shuttle 6, a take-up 8, an auxiliary take-up 10, a thread-locking device 12, a pull-off 14, and a tension device 16. The machine is also provided with a work support 18 and a presser-foot 20. The parts of the sewing mechanism are driven from a series of cams mounted upon a cam shaft 22 which for the sake of convenience in the following description will be termed the sewing cam shaft.

For the sake of clearness in the explanation of certain features of the invention, certain parts of the sewing mechanism and the mechanisms for actuating these parts are described in this application. For a full and complete description of the parts not described herein, reference may be had to the French & Meyer patent referred to above. The awl 4 (see Figs. 7, 8, 31 and 32) is mounted upon an awl carrier 24 pivoted upon a stud 26 mounted in a bearing in an upright 28 carried by the feed slide 30. Secured to the feed slide is a bracket 32 carrying a stud 34 upon which is pivoted a lever 36. Pivoted upon the lever 36 is a block 38 engaging in a curved groove 40 in the forwardly projecting arm of the lever 42 pivoted upon the stud 44. The rearwardly projecting arm of this lever carries a cam roll 46 engaging in a cam groove in a cam disk 48 mounted on the sewing cam shaft 22. During the rotation of the sewing cam shaft the lever 42 is oscillated by the action of the cam groove in the cam disk 48 on the cam roll 46, and through the connection of the feed slide with the forwardly projecting arm of the lever 42 the feed slide is reciprocated in its guides in the frame. By adjusting the lever 36 about the stud 34 the distance of the block 38 from the axis of oscillation of the lever 42 may be varied to give the desired length of feed. In order

to enable the operator accurately to position the lever 36 to give a predetermined length of feed a scale plate 50 is mounted on the frame of the machine and is provided with a series of perforations 52 in 70 which stop pins 54 and 56 may be inserted to limit the movements of the lever.

The auxiliary take-up consists of a roll mounted upon a lever 56^a pivoted at 58 on the frame. This lever is acted upon by a 75 spring 58^a which tends to maintain the lever in an elevated position in engagement with an adjustable stop pin 60, but allows the roll to yield to give up thread during the 80 loop drawing stroke of the take-up.

The pull-off comprises a roll mounted upon a forwardly extending arm 60^a fixed to one end of the rock shaft 62 mounted in bearings in the frame. An upwardly extending arm 64 fixed to the other end of the rock shaft 62 carries a pivotally mounted block 66 which engages in a groove 68 in an oscillating lever 70 pivoted at 72 on the vertically movable support 74. The support 74 is pivotally mounted at 76 upon a rearwardly extending arm of the presser-foot lever 78 which is pivoted upon a stud 80 mounted in the frame of the machine. The lower end of the support 74 is formed with guides embracing a block 82 pivoted on the rock shaft 62, the block serving as a guide for the lower end of the support. A spring 84 is arranged to act on the support 74 and normally tends to lift the support to maintain 100 the presser-foot in yielding engagement with the work. The lever 70 is oscillated through certain connections from a cam lever actuated by a cam carried by the sewing cam shaft 22 of the machine, as will be hereinafter described.

The presser-foot 20 is mounted upon the forward end of the lever 78. The presser-foot mechanism also comprises an arm 86 pivoted upon the stud 80, which carries the presser-foot lever and extending rearwardly from its pivotal point above the rearwardly extending arm of the presser-foot lever. A rod 88 is pivotally connected at its lower end to the rearwardly extending arm of the presser-foot lever and passes through a lateral projection 90 on the arm 86. A sleeve 92 is mounted on the rod above the projection 90 and a coiled spring 94 surrounding the rod is interposed between the upper end of the sleeve and a nut 96 threaded on the upper end of the rod. The rear end of the arm 86 is formed with a series of teeth adapted to be engaged by a pawl 98 pivoted at 100 upon a cam lever 102. This lever is pivoted at 104 upon the frame and carries a cam roll 106 for engagement with a cam groove in a cam disk 108 mounted on the sewing cam shaft 22. The pawl 98 is yieldingly engaged with the teeth on the rear 110 120 130

end of the arm 86 by means of a leaf spring 110 mounted on the lever 102. The rear end of the presser-foot lever is formed with a series of teeth which are adapted to be engaged by a locking pawl 112 pivoted at 114 on the frame. This pawl is yieldingly engaged with the teeth on the end of the presser-foot lever by means of a leaf spring 116 mounted on the lever 102. In order to throw out the pawls during each cycle of operations the pawl 98 is formed with a shoulder 118 which engages a pin 120 on the frame, and the lever 102 is formed with a projection 122 for engagement with a projection 124 on the pawl 112. During the feeding of the work the pawls 98 and 112 are disengaged respectively from the teeth on the rear end of the arm 86 and on the rear end of the presser-foot lever 78, the presser-foot then being held lightly in engagement with the work by the tension exerted by the spring 84. After the work has been fed and before the needle retracts from the work, the arm 86 is lifted by the action of the cam lever 102 through the pawl 98, thereby compressing the spring 94 and causing the presser foot to engage the work with considerable pressure, after which the presser-foot is locked in position by the action of the pawl 112 and remains locked during the remainder of the cycle of operations.

The driving mechanism for the machine (see Figs. 2, 3, 4 and 5) comprises a shaft 126 upon which is mounted a fast pulley 128 and a loose pulley 130. This shaft carries a bevel gear 132 which meshes with a bevel gear 134 mounted on the upper end of a vertical countershaft 136. Fixed upon the shaft 136 is a disk 138 carrying the driving member 140 of a friction clutch. The driven member 142 of the clutch is carried by a flange extending outwardly from a sleeve 144 loosely mounted upon the countershaft 136. The sleeve 144 also carries a spiral gear 146 meshing with a spiral gear 148 formed on a sleeve 150 mounted on the sewing cam shaft 22 to rotate therewith. During the sewing operation the members 140 and 142 of the main friction driving clutch are engaged and the sewing cam shaft 22 is driven through the spiral gears 146 and 148 at a speed depending upon the speed of the driving shaft 126.

The jack upon which the lasted shoe is supported during the sewing operation (see Figs. 14, 15 and 16) comprises a spindle 152 and a jack frame secured to the upper end of the spindle. A last pin 154 is mounted upon an arm 156 carried by a slide 158 mounted in a guide 160 in the jack frame and adapted to be clamped in position therein by a friction clamp 162 actuated by a clamping screw 163. The jack frame is also provided with a toe rest 164 carried at the

upper end of an arm 166 on the jack frame and adapted to support the toe of the lasted shoe. The last pin is pivoted at 168 on the arm 156 of the jack frame, and is provided with an arm 170 extending downwardly 70 therefrom into position to be engaged by a plunger 172 slidably mounted in a suitable bore in the slide 158. The plunger 172 is yieldingly engaged with the end of the arm 170 by means of a coiled spring 174 interposed between one end of the plunger and a block secured in the opposite end of the slide. The spring 174 tends to keep the toe of the shoe down in engagement with the toe rest 164. In jacking the lasted shoe 80 the shoe is placed on the jack with the last pin seated in the last pin hole and the toe of the shoe resting on the toe rest, the spring 174 then acting to force the toe of the shoe down upon the toe rest 164. The slide 158 then is adjusted so that the budge at the toe of the shoe is in line with the forward face of the toe rest. This is preferably done by placing a gage against the forward face of the toe rest so that it extends 85 upwardly beyond the toe rest and then adjusting the slide 158 forwardly to bring the toe of the shoe into engagement with the gage. In order to enable the slide 158 to be readily adjusted in the guide 160 in the jack frame gear teeth 176 are formed upon the upper side of the slide, these teeth projecting into an opening 178 in the jack frame. The slide 158 is adjusted in the jack frame by means of a tool 180 provided 90 at one end with a gear 182 adapted to be inserted in the opening 178 in the jack frame and to mesh with the teeth 176 on the slide 158. By turning the tool after it is inserted in the opening in the jack frame 95 the slide 158 may be adjusted in the proper position, after which the slide is held in position by tightening the clamp 162. This adjustment of a shoe always brings the toe 100 of the shoe to the same position with relation to the jack spindle, regardless of the size of the shoe.

After the shoe is jacked, the operator places the shoe in position in the machine with the projecting edges of the outsole and welt between the work support and presser-foot of the machine at the proper point in the margin of the shoe bottom for the starting of a seam, and sets the machine in operation.

The movements which are imparted to the shoe during the sewing operation to place the portion of the shoe at the point of operation in the proper position with relation to the sewing mechanism as the point of operation is transferred about the shoe, consist of lateral tipping movements or tipping movements about axes extending in the general direction of the length of the shoe, longitudinal tipping movements, or 115

tipping movements about axes extending transversely of the shoe to bring the edge of the shoe bottom at the point of operation into the proper plane, and lateral turning movements to bring the marginal line of the shoe bottom at the point of operation into proper position with relation to the line of feed. In addition to these tipping and turning movements the shoe is also given relatively slight vertical movements. To enable the shoe to be moved vertically and to be tipped and turned during the sewing operation to present the different portions of the projecting edge of the sole in proper position to the sewing mechanism, the spindle 152 which carries the jack frame is yieldingly supported vertically so that the spindle can accommodate itself to variations in the vertical position of the shoe, and the supporting devices for the spindle are arranged so that the lower end of the spindle may be moved freely in any direction in a horizontal plane and are provided with suitable bearings in which the spindle is rotatably mounted. In the construction shown (see Figs. 2, 13, 17, 18, 19 and 20) the jack spindle is rotatably mounted in bearing arms 184 and 186 in a supporting frame 188. The spindle is supported vertically in the frame 188 by the engagement of a collar 190 formed on the spindle with the arm 184, and by the engagement of a gear 192 also formed on the spindle with the upper side of the arm 186. The frame 188 carries a horizontal shaft 194 having its ends engaged in the arms of a yoke 196 formed at the forward end of a rod 198. The rear end of the rod 198 is threaded into a bushing or bearing sleeve 200 engaging in a bearing in a shackle block 202. The sleeve 200 is held in the bearing in the shackle block by means of a collar 204 threaded on the forward end of the sleeve. The rod 198 is held in adjusted position in the sleeve 200 by means of a lock nut 206 threaded upon the rod and engaging the end of the sleeve. This construction forms a swivel joint between the rod 198 and the shackle block 202. The shackle block 202 embraces a yoke 208 and is pivotally connected therewith to swing in a vertical plane by means of bearing pins 210 mounted in the arms of the shackle block and engaging in bearing bosses in the yoke. The yoke 208 embraces a link frame 212 and is pivotally connected with the link frame to swing in a horizontal plane by means of bearing pins 214 mounted in the arms of the yoke and engaging in bearing bosses formed on the link frame and centrally located with relation to the frame. The link frame 212 is formed with oppositely extending spaced arms 216 and 218, and is pivotally connected to the end of a supporting arm 220 by bearing pins 222 mounted in the arms 216 and 224 engaging in the end of the arm 220, and is

pivotally connected with the end of a supporting arm 224 by bearing pins 226 mounted in the arms 218 and engaging in the end of the arm 224. The arms 220 and 224 are respectively pivoted upon a shaft 270 and upon a stud 228 mounted in the frame of the machine. These arms are of substantially the same length, and the yoke 208 as above described is pivotally connected with the link frame 212 at substantially the central point of the frame so that the yoke 208 is supported in a substantially horizontal position, but is free to move forwardly and rearwardly and to swing about its pivotal connection with the link frame 212, this connection moving in substantially a straight line perpendicular to the vertical plane of the line of feed of the machine during the forward and rearward movements of the yoke. In order to support the jack spindle, and at the same time to permit it to move vertically in accordance with variations in the vertical position of the shoe, a slide block 228^a is mounted upon the rod 198 and is connected with the yoke 208 by a link 230. Pivotedly connected with the slide block 228^a is a rod 232 extending at its lower end through a sleeve 234 mounted upon trunnions 236 engaging in bearings in an arm 238 on the yoke 208. Surrounding the rod 232 is a coiled spring 240 interposed between a collar 242 fixed to the rod and the upper end of the sleeve 234. By this mechanism the rod 198 and the jack spindle and jack carried at the forward end of the rod are yieldingly supported, while the rod is permitted to swing readily in a vertical plane to accommodate the variations in the vertical position of the jack spindle as the point of operation is transferred about the shoe.

The pivotal connection between the shackle 202 at the rear end of the rod 198 and the yoke 208 permits the jack spindle to move vertically, the pivotal connection between the frame 188 and the yoke 196 at the forward end of the rod 198 allowing a relative angular movement between the frame and the rod during the vertical movements of the jack spindle. The forward and rearward movements of the lower end of the jack spindle are permitted by the mounting of the supporting devices for the spindle upon the swinging arms 220 and 224. The lateral movements of the lower end of the jack spindle are permitted by the pivotal connection between the yoke 208 and the frame 212, the connection between the rear end of the rod 198 and the shackle block 202 allowing the rod to turn in the shackle block during the lateral movements of the lower end of the spindle.

During the sewing operation the jack spindle is acted upon by yieldingly acting devices which tend to swing the spindle

about the pivotal connection between the frame 188 and the yoke 196 at the forward end of the rod 198 toward the rear of the machine, and thus to keep the projecting 5 edge of the sole between the work support and the presser-foot in position to be acted upon by the stitch-forming devices. The shoe is held positively to the machine by the needle and awl, while either the needle or awl is engaged in the projecting edge of the 10 sole, and at other times during a cycle of operations the shoe is held by the grip of the presser-foot and work support exerted upon opposite sides of the sole edge. Slight 15 vertical movements to compensate for the curvature of the surface of the shoe bottom are imparted to the shoe by the engagement of the work support and presser-foot with the sole edge, these parts acting as guides on the shoe. The tipping movements are imparted to the shoe by devices acting directly 20 on the jack supporting spindle to move the lower end of the spindle forwardly and rearwardly and laterally in horizontal directions, and the turning movements are imparted to the shoe by devices acting on the 25 spindle to rotate the spindle. Because of the fact that the shoe is held at all times at the point of operation by the needle and awl and by the work support and presser-foot, the tipping and turning movements are caused to take place about the point of operation, the shoe being tipped and turned about these work engaging devices as a 30 fulcrum.

The tipping and turning movements are imparted to the jack through suitable connections from a cam shaft which, for the sake of convenience, will be hereinafter 40 termed the pattern cam shaft. This cam shaft is rotated through less than a complete revolution during the sewing of a shoe and then its rotation is completed while the sewing mechanism remains at rest to bring the shaft to the proper position for the 45 start of the next operation upon another shoe. To permit the same cams to be used in sewing both right and left shoes, the machine has provision whereby the cam shaft 50 may be rotated in either direction. The same set of connections is employed for imparting the lateral tipping movements to the shoe in sewing either a right or a left shoe. On account of the reversal in the 55 direction of rotation of the cams, however, two sets of connections are provided for imparting the longitudinal tipping movements to the shoe and two sets of connections for imparting the turning movements to the 60 shoe, one set of connections being used in sewing a right shoe and the other set being used in sewing a left shoe.

In the present construction the lateral tipping movements of the shoe are produced by the forward and rearward swinging move-

ments of the arm 220 which, through the connections described between the lever and the lower end of the jack spindle, impart forward and rearward movements to the lower end of the spindle. The swinging 70 movements of this lever are produced by means of a cam roll 244 (Figs. 9, 21 and 22) mounted on the lever and engaging a cam groove in a cam disk 246 mounted upon the pattern cam shaft 248.

The mechanism for imparting the longitudinal tipping movements to the shoe employed in sewing a right shoe (see Figs. 1, 2, 3, 17, 18, 21 and 22) comprises a connection block 250 pivoted upon the lower end of the jack spindle 152 and carrying a stud 252, the ends of which engage in bearings in the arms of a yoke 254 formed at the end of a rod 256. The opposite end of this rod is connected by a swivel joint with a shackle 258 pivotally connected by bearing pins 260 with a shackle 262 which in turn is pivotally connected by bearing pins 264 with the arm 266 of a lever 268 pivoted upon the vertical shaft 270. This lever is formed with arms 272 upon which is mounted a segment plate 274. This segment plate is formed with a notch adapted to be engaged by the upper end of a latch 276 pivoted upon a stud 278 mounted in the end of one arm of a lever 280 pivoted upon the shaft 270, the latch serving as a connection between the lever 268 and the latter lever. The other arm of the lever 280 carries a cam roll 282 engaging in a cam groove in the cam disk 246. The oscillation of the cam lever 280 through the connections described will move the lower end of the jack spindle laterally and thereby impart longitudinal tipping movements to the shoe.

The mechanism for imparting the turning movements to the jack spindle to turn the shoe laterally employed in sewing a right shoe (see Figs. 1, 2, 3, 17, 18, 21 and 22) comprises the gear 192 hereinbefore mentioned, and a circular rack or internal gear segment 282 meshing with said gear. The gear segment 282 is secured to the outer ends of the arms 284 of a hanger 286 pivotally connected with the frame 188 by a shaft 288 secured in the hanger 286 and having its ends engaged in bearings in arms 290 and 292 on the frame 188, as shown in Fig. 18. The gear segment 282 is formed with a forwardly projecting arm 292 pivotally connected by a stud 294 with the arms of a connecting bracket 296. This bracket carries a stud 298 having its ends engaged in the arms of a yoke 300 formed at one end of a rod 302. The opposite end of this rod is connected by a swivel joint with a shackle 304 which is pivotally connected by bearing pins 306 with a shackle 308. The shackle 308 in turn is pivotally connected by bearing pins 310 with one arm of a bell crank 312 pivoted at 130

314 upon the lever 268. In the construction shown the central portion of the bell crank is formed to embrace the lever 268 and is pivotally connected with the lever by a stud carried by and projecting upwardly from a block 316. The other arm of the bell crank 312 is pivotally connected at 318 to one end of a link 320. The other end of this link is pivotally connected at 322 with a link 324 10 pivoted to swing about a pivot 326. In the construction shown the link 324 is provided with oppositely extending arms 328 (Fig. 2), the ends of which are formed with bearings to receive bearing studs mounted in the frame of the machine. The other end of the link 324 is pivotally connected at 330 with one end of a link 332, the other end of which is pivotally connected at 334 with the arm 336 of a lever 338 pivoted upon the shaft 270. The lever 338 is formed with arms 340 to which is attached a segment plate 342 having a notch adapted to be engaged by the upper end of a connecting latch 344 pivoted upon a stud 346 mounted in one arm of a lever 348 pivoted on the shaft 270. The other arm of this lever carries a cam roll 350 engaging in a cam groove in a cam disk 352 mounted on the cam shaft 248. With this construction the bell crank lever 312 through which turning movements are imparted to the jack spindle moves with the lever 268 as the lever is oscillated to impart the lateral movements to the lower end of the spindle, and there is substantially no angular movement of the bell crank 312 produced by the movements of the lever 268, the link 320 during the swinging movement of the latter lever swinging about its pivotal connection 322 with the link 324, the center of which lies substantially in or adjacent to a line through the center of the pivotal connection 318 and through the center of the shaft 270 upon which the lever 348 is pivoted. The result 40 of this construction is that there is substantially no tendency to produce rotary movement of the jack spindle by the lateral movements of the lower end of the spindle. In order to support the forward end of the lever 268 and the bell crank 312 mounted thereon, a roll 354 is mounted on the block 316 and engages in a guide groove 356 in an arc-shaped bracket 358 secured to the frame of the machine.

50 In the construction shown the mechanism employed for imparting the longitudinal tipping movements to the shoe when a left shoe is being sewn (see Figs. 1, 3, 17, 18, 21 and 22) comprises a connection block 360 pivoted on the lower end of the jack spindle and carrying a stud 362 having its ends engaged in the arms of a yoke 364 formed at one end of a rod 366. The opposite end of the rod is connected by a swivel joint with a shackle 368 pivotally connected by bearing

pins 370 with a shackle 372. This shackle in turn is pivotally connected by bearing pins 374 with the forwardly extending arm 376 of a lever 378 pivoted upon the vertical stud 228. The rearwardly extending arm of this lever is pivotally connected at 382 with one end of a link 384, the other end of which is pivotally connected at 386 with the arm 388 of a lever 390 pivoted upon the vertical shaft 270. The lever 390 is formed with 75 arms 392 upon which is mounted a segment plate 394 having a notch adapted to be engaged by the lower end of the latch 276. When a left shoe is to be sewn the latch 276 is turned by the operator to disengage its upper end from the notch in the segment plate 274, thereby disconnecting the lever 268 from the cam lever 280 and the lower end of the latch is engaged in the notch in the segment plate 394, thereby connecting the lever 80 85 390 with the cam lever.

The mechanism for imparting the turning movements to the jack spindle to turn the shoe laterally when a left shoe is being sewn (see Figs. 1, 3, 17, 18, 21 and 22) comprises 90 a connecting bracket 396 pivoted on the stud 294. This bracket carries a stud 398 having its ends engaged in bearings in the arms of a yoke 400 formed at one end of a rod 402. The opposite end of this rod is connected by a swivel joint with a shackle 404 which is pivotally connected by bearing pins 406 with a shackle 408, which in turn is pivotally connected by bearing pins 410 with one arm of a bell crank lever 412 pivoted at 414 upon the arm 376 of the lever 378. The bell crank 412 is constructed to embrace the arm 376 of the lever 378 and is pivotally connected therewith by means of a stud carried by a block 416. The other arm of the bell crank 105 412 is pivotally connected at 418 with the forward end of a link 420, the rear end of which is pivotally connected at 422 with one arm of a second bell crank 424 pivoted at 426 on the frame. The other arm of the latter bell crank is pivotally connected at 428 with one end of a link 430, the other end of which is pivotally connected at 432 with the arm 434 of a lever 436 pivoted upon the shaft 270. This lever is formed with arms 438 on which is mounted a segment plate 440 having a notch adapted to be engaged by the lower end of the latch 344. When a left shoe is to be sewn, the upper end of the latch 344 is disengaged from the notch in the segment plate 342 to disconnect the lever 336 from the cam lever 348, and the lower end of the latch is engaged in the notch in the segment plate 440 to connect the lever 436 with the cam lever 348.

110 The parts of the mechanism for imparting the longitudinal tipping movements to the shoe when a right shoe is being sewn, and the parts of the mechanism for imparting the longitudinal tipping movements to the 115 120 125 130

jack when a left shoe is being sewn, are arranged in substantially symmetrical relations, as will be seen from an inspection of Fig. 3. These mechanisms operate to move 5 the lower end of the spindle in paths having a substantially symmetrical relation to each other with reference to a plane perpendicular to the line of feed and passing through the point of operation. The parts of the 10 mechanism for imparting the turning movements to the jack when a right shoe is being sewn, and the parts of the mechanism for imparting the turning movements to the jack when a left shoe is being sewn, also have a 15 relatively symmetrical arrangement.

The mechanism acting on the jack spindle and tending yieldingly to swing the jack toward the rear of the machine and thus to keep the edge of the shoe sole between the 20 work support and the presser-foot of the sewing mechanism (see Figs. 1, 2, 13, 19, 24, 25, 26, 27, 28 and 29) comprises a pulley or disk 396^a fixed to the jack spindle intermediate the lower end thereof and the jack and 25 a pair of cables 398^a and 400^a, each attached at one end to the pulley 396^a the cables passing in opposite directions about the pulley. These cables extend rearwardly from the disk 396^a respectively over pulleys 402^a and 30 404^a and then forwardly, and are respectively connected at their other ends to tension springs 406^a and 408^a, which springs are attached at their forward ends to pins 410^a and 412^a mounted in the frame of the machine. These springs acting yieldingly on 35 the jack spindle tend to keep the edge of the shoe sole between the work support and presser-foot of the sewing mechanism. These springs also, because of their connection through the cables 398^a and 400^a with the disk 396^a fixed to the jack spindle, tend to rotate the jack spindle. Mechanism is provided for controlling the tension exerted by each of these springs which will operate 40 to vary the tension at different points in the sewing operation. The springs are arranged to exert a turning effect on the jack spindle so as to take up any lost motion or play resulting from looseness in the parts of the 45 jack turning mechanism. The effective force resultant from the tensions of the two springs tending to turn the jack spindle is, of course, equal to the difference between the tensions exerted by the springs. The springs 50 also act to take up lost motion in the mechanisms for tipping the jack. The springs tend to swing the spindle and jack toward the rear of the machine with a force equal to the sum of the tensions exerted by the springs. On account of the curvature of the 55 shoe bottom, and on account of the correcting movements which are imparted to the shoe during the sewing operation, the edge of the shoe sole tends to be thrown out from 60 between the presser-foot and work support

at certain points in the sewing operation, and this tendency varies in degree at different points. To counteract this tendency, the mechanism for controlling the tension of the springs 406^a and 408^a acts to vary the tension exerted by the springs to cause said springs to exert a comparatively heavy total tension at such points differing in amounts at different points as found to be required. At other points there is no particular tendency for the edge of the sole to be thrown out from between the presser-foot and work support, and there may even be a tendency for the edge of the sole to be drawn farther in between the presser-foot and work support. 70 At such points, the mechanism for controlling the tension exerted by the springs causes the springs to exert a comparatively light total tension sufficient to keep the edge of the sole in proper position between the presser-foot and work support without causing the work support or edge gage to exert an undue resistance to the feeding of the work. The tension of one of the springs is always greater than that of the other, so that there 75 is always a resultant tension tending to turn the jack spindle to take up lost motion in the jack turning mechanism. The mechanism for controlling the tension exerted by the springs 406^a and 408^a is arranged to act on the pulleys 402^a and 404^a over which the cables 398^a and 400^a pass. In the construction shown the pulley 402^a is mounted in a yoke 414^a pivoted at 416^a on a swivel block 418^a, the stud 420^a of which is mounted in a bearing in the end 80 of an arm 420^b of a lever 422^a mounted upon a shaft 424^a. The pulley 404^a is mounted in a yoke 426^a pivoted at 428^a upon a swivel block 430^a, the stud 432^a of which is mounted in a bearing in the arm 432^b of a lever 434^a also mounted upon the shaft 424^a. In 85 order to control the position of the pulley 402^a, a spiral gear segment 436^a is carried by the arms 438^a of the lever 422^a, and is engaged by a spiral gear 440^a fixed to a shaft 442. A ratchet wheel 444 is carried by and 90 preferably formed integral with the spiral gear, and a pair of actuating pawls 446 and 448 mounted upon an eccentric 450 carried by a shaft 452 are arranged to engage the ratchet wheel. The shaft 452 is journaled at its lower end in a bearing block 454 and at its upper end in a bearing 456 formed in the housing 458. The shaft 452 is actuated 95 by means of a bevel gear 460 fixed to the driving shaft 126 and meshing with a bevel gear 462 fixed to the upper end of the shaft 452. The pawls 446 and 448 are connected by a tension spring 464 which tends to move the acting ends of the pawls into engagement with the teeth of the ratchet wheel 444. The pawls are reciprocated in the same direction by the eccentric 450, and on account 100 of the arrangement of the pawls upon the opposite sides of the ratchet wheel, they are 105 110 115 120 125 130

adapted to rotate the ratchet wheel in opposite directions. The pawls are so controlled that only one of the pawls can engage the teeth of the ratchet wheel at a time. The engagement of the pawls with the teeth of the ratchet wheel is controlled by a shield 466 rotatably mounted on the shaft 442 just below the ratchet wheel 444 and arranged to engage the acting ends of the pawls.

10 As shown in Figure 29, substantially half of the shield extends beyond the ends of the teeth on the ratchet wheel 444, so that when the shield is in central position, as shown in this figure, the ends of the pawls 446 and 448 will be held from contact with the teeth on the ratchet wheel by their engagement with the arcuate edge 468 of this half of the shield. The circumferential portion of the other half of the shield, however, is cut 20 away so that its edge, indicated at 470, lies within the teeth of the ratchet wheel. When the shield is rotated in one direction or the other from the position shown in the drawings, bringing any portion of this half of 25 the shield into a position opposite the acting end of either of the pawls, that pawl will be swung inwardly by the spring 464 into engagement with the teeth on the ratchet wheel. To the shield is secured a 30 gear segment 472 which meshes with a gear segment 474 formed on the end of a lever 476 pivoted at 478 on one end of a link 480. The opposite end of the lever 476 carries a cam roll 482 which engages a cam 484 mounted on the cam shaft 248. The lever 476 is acted upon by a tension spring 486 which tends to keep the cam roll 482 in engagement with the cam 484. By the action 35 of the lever 476 the shield 466 is normally maintained in a central position with the acting ends of both of the pawls in engagement with the portion 468 of the edge of the shield so that both of the pawls are held out of engagement with the ratchet wheel. 40 With the parts in this condition, a constant predetermined tension will be exerted by the spring 406^a upon the cable 398^a. When, 45 during the progress of the shoe through the machine, the shoe reaches a point where the tension exerted by the spring 406^a is to be increased to a predetermined amount, the lever 476 will be actuated by the cam 484 to rotate the shield 466 in a right-hand direction, Figs. 24 and 29, to bring the portion 470 of the edge of the shield into a position 50 opposite the pawl 446. This will allow the pawl 446 to engage the ratchet wheel 444, and the ratchet wheel will be turned in a left-hand direction, thereby rotating the spiral gear 440^a in a direction to elevate the gear segment 436^a and to actuate the lever 422^a to swing the pulley 402^a toward the rear of the machine, thereby exerting a pull 55 on the cable 398^a and increasing the tension of the spring 406^a. When the shoe arrives

at a point at which the tension of the spring 406^a is to be lessened, the cam 484 allows the lever 476 to be actuated by the spring 486 to rotate the shield 466 in a left-hand direction to permit the acting end of the pawl 448 to engage the ratchet wheel 444. The pawl 448 will then act to rotate the ratchet wheel and the spiral gear 440^a in a right-hand direction and the lever 422^a will be actuated in a direction to swing the pulley 402^a forwardly to lessen the tension exerted by the spring 406^a upon the cable 398^a. In order that after the spring reaches the required tension the acting end of the pawl may be thrown out of engagement with the teeth of the ratchet wheel, mechanism is provided for restoring the shield 466 to its central position when the required tension is reached. In the construction shown the forward end of the link 480 is pivotally connected at 488 with one arm of a bell crank lever 490 pivoted upon a stud 492 upon the frame of the machine. To the other arm of this bell crank is connected by a universal joint 494 the rear end of a link 496. The forward end of this link is connected by a universal joint 498 with a clamp 500 secured to the cable 398^a. This mechanism, through its connection with the lever 476, will act to shift said lever about the point of contact of the roll 482 with the cam 484 as a centre in one direction or the other to restore the shield 466 to central position when the required tension of the spring 406^a is reached. For example, assume that the pawl 446 is acting upon the ratchet wheel 444 to turn the ratchet wheel in a direction to increase the tension of the spring 406^a. The pull exerted by the pulley 402^a upon the cable 398^a will move the clamp 500 connected with the forward end of the link 496 toward the rear of the machine. When the spring 406^a reaches the required tension, the lever 476 will have been actuated through the link 496, the bell crank 490 and the link 480 to turn the shield 466 back to central position. A corresponding action is produced also when the tension exerted by the spring 406^a has been lessened through the action of the pawl 448 upon the ratchet wheel 444. It will, therefore, be seen that the cam 484 will act to cause a predetermined tension to be exerted by the spring 406^a at each point in the progress of the shoe 110 through the machine.

In order to maintain the ratchet wheel 444 and the spiral pinion 440^a in any position into which they are moved by the action of either of the pawls 446 and 448 on the ratchet wheel 444, a friction clutch is provided comprising a friction clutch member 502 secured to a flange 504 on the shaft 442 which is adapted to engage a co-operating friction clutch member 506 rotatably mounted on the shaft 442. On the periphery of the clutch 125

member 506 are formed a series of ratchet teeth 508 which are adapted to be engaged by the end of a retaining pawl 510 slidably mounted in a bracket 512 secured to the frame of the machine and acted upon by a coiled spring 514 which tends to keep the end of the pawl in engagement with the teeth 508. The engagement of the pawl 510 with the teeth 508 on the clutch member 506 prevents the rotation of the spiral pinion 440^a under the action of the spring 406^a. When the pawl 446 acts to rotate the ratchet wheel 444 the clutch member 506 will be allowed to rotate by the retaining pawl 510, the teeth 508 on the clutch member facing in a direction to prevent rotation of the clutch member in a right-hand direction only, Fig. 24. When the pawl 448 acts to rotate the ratchet wheel 444, the clutch faces of the clutch member 502 and the clutch member 506 will slip during the rotation of the ratchet wheel, the friction between these faces, however, being sufficient to prevent the rotation of the spiral pinion 440^a under the action of the spring 406^a.

The mechanism for controlling the tension exerted by the spring 408^a is substantially the same in construction, arrangement and mode of operation as the mechanism for controlling the tension of the spring 406^a. For the sake of clearness, however, the parts of the latter mechanism will be briefly pointed out in the present description.

The lever 434^a upon which the pulley 404^a is mounted is provided with arms 518 which carry a spiral gear segment 520 which meshes with a spiral pinion 522 fixed to a shaft 524. This spiral pinion carries a ratchet wheel 526 which is adapted to be engaged by the acting ends of either of the pawls 528 and 530 mounted upon the eccentric 450 carried by the shaft 452. The pawls 528 and 530 are connected by a spring 532 which tends to move the acting ends of the pawls into engagement with the ratchet wheel. The engagement of the pawls with the ratchet wheel is controlled by a shield 534 rotatably mounted on the shaft 524 and having substantially the same construction as the shield 466. To the shield 534 is secured a gear segment 536 which meshes with a gear segment 538 formed at the end of a lever 540 pivoted at 542 upon the end of a link 544. The opposite end of the lever 540 carries a cam roll 546 engaging a cam 548 fixed to the correcting cam shaft 248. The spiral pinion 522 is held in the position into which it is moved by either of the pawls 528 or 530 by a friction clutch comprising a clutch member 550 secured to the shaft 524 and a cooperating clutch member 552 rotatably mounted on the shaft 524 and having peripheral ratchet teeth 554 adapted to be engaged by a retaining pawl 556. The retaining pawl 556 is slidably mounted in a bracket 558 and is

held in engagement with the ratchet teeth 554 on the clutch member 552 by means of a coiled spring 560. The mechanism for restoring the shield 534 to its central position when the spring 408^a reaches the required tension comprises a bell crank 562 pivoted upon the stud 564 on the frame of the machine and having one arm pivotally connected at 566 with the forward end of the link 544, a clamp 568 secured to the cable 400^a, and a link 570 connected at one end by a universal joint 572 with the other arm of the bell crank 562, and at its other end by a universal joint 574 with the clamp 568.

It will be readily seen that the forward and rearward and lateral movements of the lower end of the jack spindle, and the turning movements of the spindle imparted thereto in tipping and turning the jack, will take up and let out on the cables 398^a and 400^a, and will thus tend to cause the tension exerted by the springs 406^a and 408^a to vary from the predetermined tensions determined by the cams 484 and 548. The actuating connections between the pulleys 402^a and 404^a controlling the tension of the springs 406^a and 408^a and the levers 476 and 540, however, will cause the predetermined tension to be exerted by each of the springs, regardless of the horizontal position of the lower end of the jack spindle, or of the position into which the spindle is turned. For example, assume that the lower end of the jack spindle is moved horizontally, or that

the spindle is turned so as to exert a pull or to take up on the cable 398^a, thereby causing the tension exerted by the spring 406^a to become temporarily greater than the predetermined tension determined by the cam 484. This pull exerted on the cable through the connections between the cable and the lever 476 will swing the lever rearwardly about the point of contact of the cam roll 482 with the cam 484. This movement of the lever will turn the shield 466 in a direction to permit the pawl 448 to engage the ratchet wheel 444. The pawl will then act on the ratchet wheel to turn the ratchet wheel in a direction to swing the pulley 402^a forwardly and thereby relieve the tension exerted on the cable by the spring 406^a.

When the tension exerted by the spring reaches the predetermined amount determined by the cam 484, the pawl 448 will be thrown out of operation in the manner hereinbefore described. If the jack spindle is positioned so as to cause the tension exerted by the spring 406^a upon the cable to fall below the predetermined tension, the lever 476 will be swung forwardly and will rotate the shield 466 in a direction to throw the pawl 446 into operation, and through the operation of the pawl on the ratchet wheel 444 the pulley 402^a will be swung rearwardly to increase the tension exerted by the spring 406^a on the

cable 398^a. The mechanism for controlling the tension of the spring 408^a will act in a similar manner. It will also be seen that the mechanisms for controlling the tension 5 exerted by the springs 406^a and 408^a will operate in a reliable manner to produce the required tension of the springs whatever the size of the shoe which is being sewn.

When sewing along the shank of a shoe, 10 the shoe is tilted about an axis substantially parallel with, or extending in the general direction of the longitudinal axis of the shoe bottom to an extent such that the plane of the portion of the projecting edge of 15 the sole at the point of operation does not lie parallel with the work engaging faces of the presser foot and work support. The result of this tilting of the shoe, when operating along the shank, is that the presser 20 foot and work support do not correctly measure the thickness of the work, but the presser foot is separated from the work support by a distance greater than the thickness 25 of the work. If this error in the work measuring operation of the work support and presser foot were uncorrected, or if the throw of the pull-off, when operating along 30 the shank, were determined in the usual manner by the distance between the presser foot and work support, the pull-off would draw off from the supply during each cycle 35 of operations a length of thread in excess of that required for the formation of the succeeding stitch, and this would result in a looseness in the stitches. To correct or compensate for this error in the work measuring 40 action of the work support and presser foot, the present machine is provided with mechanism for diminishing the throw of the pull-off from that determined by the relative positions of the presser foot and work support 45 when operating along the shank of the shoe. In the construction shown (see Figs. 1, 7, 8 and 9) the cam lever for actuating the oscillating lever 70 of the pull-off mechanism is indicated at 578. The cam lever is pivoted upon the shaft 580, and is provided 50 with an arm 582 carrying a cam roll 584 engaging in a cam groove in the cam disk 58. The cam lever is provided with a second 55 arm 588 upon which is pivoted at 590 a bell crank 592, one arm of which is connected by a link 594 with the oscillating lever 70. The other arm of the bell crank 592 is connected 60 by a link 596 with an arm 598 fixed to a rock shaft 600, mounted at one end in a bearing in a bracket 602 on the frame, and at the other end in a bearing in an arm 604 formed on the bracket 606 secured to the frame.

The parts are shown in Fig. 7 of the drawing substantially in the positions which they assume during each cycle of operations when the pull-off is at the beginning of its 65 acting stroke except that the presser foot is

lifted, the lifting of the presser foot having caused the pull-off to assume a position somewhat below its normal starting position. When operating along the shank of a shoe the rock shaft 600 is adjusted so as to 70 locate the arm 598 substantially in the position shown in Fig. 7. With this adjustment of the rock shaft the full throw is not imparted to the pull-off as determined by the 75 position of the presser foot, but its throw has been diminished by the adjustment of the arm 598 to compensate for the error in the work measuring function of the work support and presser foot when operating 80 along the shank. In passing from the shank to the forepart of the shoe the rock shaft 600 is turned in a direction to swing the arm 598 toward the front of the machine. As will be obvious from an inspection of 85 Fig. 7, this adjustment of the arm 598 through the link 596, the bell crank 592, the link 594 and the lever 70 will adjust the pull-off lever, consisting of arm 64, rock shaft 62 and arm 60^a, so that the pull-off roll 14 will start from a lower position at 90 the beginning of the acting stroke of the pull-off lever. The parts are constructed and arranged so that at the end of the acting stroke of the pull-off lever the link 596 is swung substantially into line with the 95 arm 598. This adjustment of the arm 598, therefore, will produce substantially no variation in the position of the pull-off at the end of its acting stroke. Since the limit of 100 the acting stroke of the pull-off is substantially the same with either position of the arm 598, the length of the acting stroke of the pull-off will be increased by the adjustment of the arm, as described. In passing 105 from the shank of the shoe to the forepart upon the opposite side of the shoe the rock shaft 600 is turned to swing the arm 598 rearwardly to its initial position. This adjustment of the arm will again reduce the 110 stroke of the pull-off for the sewing of the stitches along the shank. The mechanism provided for effecting the adjustment of the rock shaft 600 in timed relation to the movements of the shoe in the manner described is operated from the correcting cam 115 shaft 248. In the construction shown a bevel gear 608 is mounted on the rock shaft 600 and meshes with the bevel gear 610 mounted upon the upper end of a shaft 612 having a bearing at its upper end in an arm 614 on the bracket 606 and at its lower end in an arm 616 on the bracket 618. To the lower end of the shaft 612 is attached an arm 620, carrying at its end a cam roll 622, arranged to engage a peripheral cam on the cam disk 624, mounted on the correcting cam shaft 248. In order to maintain the cam roll in engagement with the periphery of the cam disk 624, a spring 626 is coiled about the shaft 612 and has the end of one 120 125 130

arm engaged with the arm 620, and the end of its other arm engaged behind the bracket 618.

The machine is provided with an edge gage 628, movably mounted above the upper surface of the work support 18 to engage the edge of the sole. The edge gage is automatically actuated to advance the edge gage into predetermined operating position in engagement with the sole edge and to retract the same out of operating position at predetermined points in the sewing operation or in timed relation to the passage of the shoe through the machine. The edge gage is retracted from engagement with the edge of the sole of the shoe when sewing along the shank. The distance of the line of stitches from the edge of the sole is then determined by the engagement of the forward edge of the work support with the upper, and the line of stitches is formed relatively remote from the sole edge or close to the upper. When passing from the shank to the forepart of the shoe, the edge gage is moved forward into engagement with the sole edge so as to cause the line of stitches to be formed relatively close to the sole edge or relatively remote from the upper as compared with the stitches along the shank. When passing from the forepart to the shank, the edge gage is withdrawn from engagement with the sole edge. In connection with the edge gage mechanism, automatically operating feed changing mechanism is employed, which acts to shorten the length of stitch in passing from the shank to the forepart of the shoe, and to increase the length of stitch in passing from the forepart to the shank. In the construction shown, (see Figs. 1, 2, 8, 31 and 32) the edge gage 628 is mounted upon the upper end of a shaft 630, journaled in bearings in the upright 28 on the feed slide 30. This manner of mounting the edge gage 628 enables the edge gage to swing over the upper surface of the work support into and out of acting position. Upon the lower end of the shaft 630 is formed a series of spiral gear teeth meshing with the teeth of the spiral gear 632, fixed to one end of a shaft 634, journaled in bearings in the dove tailed portion of the feed slide. Upon the other end of the shaft 634 is secured a disk 636, upon which is formed a series of gear teeth 638, meshing with the teeth of the gear segment 640 carried by the upper end of an arm 642, fixed to one end of the shaft 644, mounted in bearings in a bracket 646, secured to the frame of the machine. On the other end of the shaft 644 is secured an arm 648, carrying at its outer end a roll 650, engaged by an arm 652, fixed to the upper end of a rock shaft 654. A second arm 656 is fixed to the shaft 654 and carries at its outer end a cam roll 658, arranged to engage a peripheral cam on the cam disk 246. The arm 642 is acted upon by a coiled spring 660, attached at one end of the arm, and at the other to a point on the frame of the machine, which spring tends to swing the arm toward the rear of the machine, and thus to hold the edge gage in retracted position and also to maintain the cam roll 658 in engagement with the periphery of the cam disk 246. Through the action of the peripheral cam on the cam disk 246 on the cam roll 658, and the action of the spring 660 on the arm 642, the said arm is swung in opposite directions in timed relation to the other parts of the machine to advance the edge gage into operating position in passing from the shank of the shoe to the forepart, and to retract the edge gage from operating position in passing from the forepart to the shank. In passing from the shank of the shoe to the forepart the arm 642 is swung forwardly and through the disk 636, the shaft 634 and the shaft 630 this movement of the arm swings the edge gage 628 forwardly into operative position. In a corresponding manner, in passing from the forepart to the shank of the shoe the arm 642 is swung rearwardly, thereby through the connections described swinging the edge gage 628 rearwardly out of operating position. When starting a seam along the shank of the shoe, the lever 36, the angular position of which determines the length of the stitch, rests against the rear side of the pin 54, placed in one of the perforations in the gage plate 50, the position of this pin determining the length of the stitches to be formed along the shank. The rearward movement of the lever is limited by means of the pin 56 placed in one of the perforations in the gage plate 50 to the rear of the lever. In sewing about the forepart of the shoe the lever 36 is adjusted so that it engages the forward side of the pin 56, the position of which determines the length of the stitches formed about the forepart. When sewing along the shank on the side of the shoe last sewn the lever 36 is again adjusted so that it engages the rear side of the pin 54. In the present machine the feed regulating lever 36 is automatically swung from its forward position in engagement with the pin 54 to its rearward position in engagement with the pin 56 in passing from the shank to the forepart of the shoe, and is swung back to its forward position in passing from the forepart to the shank through connections with the edge gage mechanism. In the construction shown, a plate 662 is adjustably secured to the lever by means of a screw 664 passing through a slot 666 in the plate and threaded into the lever. The forward end of the plate is formed with a down-turned projection 668 adapted to be engaged upon its rear side by a shoulder 670 formed on the disk 636. Secured upon the

outer end of the shaft and preferably formed integral with the disk 636 is a block 672, upon which is adjustably mounted a segmental plate 674, secured to the block by means of a screw 676, passing through a slot 678 in the plate and threaded into the block. The upper or forward end of the segmental plate 674 is adapted to engage the forward side of the projection 668 on the plate 662. When the seam is started along the shank of the shoe, the shoulder 670 on the disk 636 is engaged with the rear side of the projection 668 on the plate 662. In passing from the shank of the shoe to the forepart, the disk 636 is turned in a right hand or clockwise direction (Fig. 32) by the action of the arm 642, to advance the edge gage 628 into operating position. During this movement of the disk 636, the end of the segmental plate 674 engages the forward side of the projection 668 on the plate 662 and moves the latter plate and the lever 36 to which it is attached, toward the rear of the machine until the lever brings up against the forward side of the pin 56. The lever 36 is thus positioned to shorten the stitch length for sewing about the forepart of the shoe. In passing from the forepart of the shoe to the shank upon the opposite side of the shoe, the disk 636 is turned in a left hand or counter-clockwise direction, Fig. 32, by the action of the arm 642, to retract the edge gage from operating position. During this movement of the disk the shoulder 670 is engaged with the rear side of the projection 668 on the plate 662 and moves said plate and the lever 36 forwardly until the lever engages the rear side of the pin 54, thus restoring the lever to its initial position for sewing along the shank of the shoe. The provision for adjustment of the plate 662 on the lever 36 and of the segmental plate 674 on the block 672 enables the action of the feed changing mechanism to be regulated to compensate for variations in the limiting positions of the lever 36, as determined by the pins 54 and 56. These pins, of course, may be placed in different perforations in the gage plate 50 to give any desired length of stitch along the shank, or about the forepart of the shoe.

The mounting of the edge gage on the feed slide, so that it moves with the awl during the feed, is of considerable advantage. In machines employing an edge gage which is fixed in the direction of feed, the awl is often thrown out of line with the needle during the feeding of the work so that the needle, as it advances through the work, does not enter the perforation made in the work by the awl. This difficulty is due chiefly to the leading on of the work by the operator, or to the crowding of the work in advance of the point of operation to the rear to ensure the positioning of the edge of the sole firmly against the edge gage.

This crowding of the work rearwardly in advance of the point of operation often causes the edge of the sole in advance of the point of operation to lie in a direction oblique to the line of feed, extending from 70 the point of operation toward the rear of the machine. When this inclined edge of the work engages a fixed edge gage during the advancing movement of the feed slide, through the action of the edge gage upon 75 the edge of the work, the point in the work engaged by the awl is crowded forwardly, thereby throwing the awl out of line with the needle. This difficulty is obviously corrected by mounting the edge gage upon the 80 feed slide so that it moves with the awl.

The pattern cam shaft 248 is driven in timed relation to the sewing cam shaft 22 or to the shoe feeding mechanism so as to impart the tipping and turning movements 85 to the shoe in proper timed relation to the movements imparted to the shoe by the shoe feeding mechanism and to operate the mechanism tending to swing the jack rearwardly, the pull-off mechanism, the edge 90 gage mechanism and the feed changing mechanism at the proper times during the progress of the shoe through the machine. The mechanism for driving the pattern cam shaft is timed for a predetermined relative 95 rate of feed of the shoe before the sewing operation is started, and will operate to drive the pattern cam shaft at a predetermined speed as long as the predetermined relative rate of feed of the shoe is 100 maintained. The shoe is fed by the lateral movement of the awl while the awl is projected through the welt and outsole of the shoe and the shoe is not always advanced either a uniform or a predetermined distance during each cycle of operations of the machine but variations occur in the rate of feed of the shoe from the predetermined rate of feed. These variations may be due to the character of the stock which is being 110 sewn or to the resistance offered by the work-engaging parts of the machine to the feeding of the shoe, or they may be due to other causes. In order that the pattern cam shaft may be driven in proper timed relation to the movements of the shoe as the shoe progresses through the machine, automatically acting mechanism is provided for restoring the pattern cam shaft and the shoe to their proper timed relation upon the occurrence of a variation in the predetermined 120 rate of feed of the shoe which destroys the proper timed relation of the pattern cam shaft and the shoe. The shoe and the pattern cam shaft may be restored to their proper timed relation either by increasing or decreasing the rate of feed of the shoe relative to the speed of the cam shaft or by increasing or decreasing the speed of the 125 cam shaft relative to the rate of feed of the 130

shoe. In the present embodiment of the invention the shoe and the cam shaft are restored to their proper timed relation by varying the speed of the cam shaft relative 5 to the rate of feed of the shoe. In the operation of the machine upon different sizes of shoes the cam shaft must be driven at a higher rate of speed relative to the rate of feed of the shoe when a small size shoe 10 is being sewn than when a large size shoe is being sewn. This will be evident from a consideration of the fact that substantially the same movements must be imparted to a small shoe as to a large shoe in sewing a 15 seam about the marginal portion of a shoe, and the various parts operated from the pattern cam shaft must be given substantially the same movements in sewing a small shoe as when a large shoe is sewn. The 20 number of stitches, however, made in sewing about a small size shoe is considerably less than the number made in sewing a large size shoe. The pattern cam shaft must therefore be given substantially the same 25 predetermined number of degrees of rotation in the sewing of a small size shoe in which the number of cycles of operations is relatively small as in the sewing of a large size shoe which requires a relatively large 30 number of cycles of operations. To enable the same mechanism to be employed in sewing different sizes of shoes means is provided for relatively timing the pattern cam shaft and the shoe feeding means for the 35 size of the shoe which is to be sewn before the sewing operation is started. In the present embodiment of the invention the pattern cam shaft and shoe feeding means are relatively timed for different sizes of 40 shoes by adjusting the speed of the pattern cam shaft. The mechanism for regulating the speed of the pattern cam shaft in accordance with the size of the shoe to be sewn is set by the placing of the shoe in position in the machine to start the sewing operation through a connection between the 45 jack and said mechanism and is locked in position when the machine is started so that the adjustment of said mechanism is maintained until the seam is completed. 50

With a normally substantially uniform speed of the pattern cam shaft certain of the motions produced by the cams on the pattern cam shaft would be especially hard 55 motions resulting in excessive strain on the parts and would tend to be jerky in character. This is particularly true of the motions imparted by the cams on the pattern cam shaft to the mechanisms for tipping and 60 turning the shoe. In order to lessen the strain upon the parts at the points where these motions occur the acting portions of the cams producing these motions are extended respectively over a considerably 65 greater angle on the cam disks upon which

they are formed than would otherwise be the case and the speed of the pattern cam shaft at these points is increased so that these motions are produced in substantially the same time as with a uniform speed of 70 the cam shaft.

In the construction illustrated, the pattern cam shaft driving mechanism (see Figs. 1, 2, 3, 9, 10, 11, 12 and 36) comprises a gear 682 attached to the pattern cam shaft 75 and a spiral gear 680 meshing with the gear 682. The spiral gear 680 is journaled on and held from movement longitudinally of a shaft 684 which is slidably mounted in bearings in sleeves 686 and 688, which sleeves are respectively journaled in bearings 690 and 692 in the frame of the machine. The sleeve 686 carries at one end a bevel gear 694 and the sleeve 688 carries at one end a bevel gear 696, these gears each 80 meshing with an intermediate bevel gear 698 secured to the lower end of a vertical shaft 700 arranged in alignment with the counter shaft 136 but capable of being rotated independently of said shaft. When 85 rotary movement is imparted to either the sleeve 688 or the intermediate bevel gear 698 the bevel gears 694 and 696 will be rotated in opposite directions. The spiral gear 680 is provided with a series of clutch projections 90 95 formed on one end of the gear for engagement with the clutch projections 704 formed on the bevel gear 694 and upon its opposite end the spiral gear 680 is provided with a second series of clutch projections 706 for engagement with the clutch projections 708 formed on the bevel gear 696. When the spiral gear 680 is clutched to the bevel gear 694 the pattern cam shaft will be driven in a right hand or clockwise direction (Fig. 9), 100 which is the direction of rotation imparted to the cam shaft when a right shoe is being sewn. When the spiral gear 680 is clutched to the bevel gear 696 the cam shaft will be driven in a left hand or counter clockwise direction which is the direction proper for sewing a left shoe. In order that the spiral gear 680 may be shifted longitudinally to clutch the same either to the bevel gear 694 105 or to the bevel gear 696 the shaft 684, upon which the spiral gear is mounted, is arranged for longitudinal movement in its bearings in the sleeves 686 and 688. When changing from a right shoe to a left, or from a left shoe to a right, the operator shifts the 110 shaft 684 longitudinally to reverse the direction in which the pattern cam shaft 248 is driven before the machine is started. The mechanism provided for shifting the shaft 115 comprises a block 710 secured to the end of the shaft 684, a rod 712 threaded into the block and having a pair of spaced projections 714 extending laterally therefrom, a lever 716 pivoted on the shaft 718 and having an arm 720 carrying a pin 722 engaging 120

125

130

between the projections 714 and a second arm 724, and an operating lever 726 pivotally mounted in a recess in the arm 724 by means of a pin or stud 728. The lever 716 is held in position by means of a sliding latch pin 730 (see Figs. 9 and 51) mounted in guides in the arm 724 of said lever and passing at its upper end loosely through the operating lever 726, a nut 732 being threaded upon the upper end of the pin to engage the lever 726. The latch pin is actuated to project the lower end thereof below the arm 724 of the lever 716 by means of a coiled spring 734 surrounding the latch pin within a suitable chamber in the arm 724, said spring being interposed between a collar 736 threaded into the arm 724 at the upper end of the chamber and a collar 738 mounted on the latch pin. The arm 724 of the lever 716 moves over a gage plate 740 formed on the frame, said plate having two openings or recesses 742 and 744 adapted to receive the lower end of the latch pin 730 to lock the lever 716 in position. The openings in the gage plate are so located that, when the latch pin 730 is engaged in the opening 742, the spiral gear 680 will be clutched to the bevel gear 694 and that when the latch pin is engaged in the other opening 744 the spiral gear 680 will be clutched to the bevel gear 696. In shifting the spiral gear 680 from clutching relation to one bevel gear into clutching relation to the other bevel gear, the operator swings the hand lever 726 upwardly about the stud 728 to disengage the lower end of the latch pin from the hole in the gage plate 740, and then swings the lever 716 about the stud 718 until the lower end of the latch pin snaps into the other hole in the gage plate. This movement of the lever 716 will shift the shaft 684 and the spiral gear 680 longitudinally to disengage the clutch projections at one end of the spiral gear from the clutch projections on one of the bevel gears and to engage the clutch projections at the other end of the spiral gear with the clutch projections on the other bevel gear. During the sewing operation the bevel gears 694 and 696 are driven by the rotary movement of the sleeve 688. The mechanism for driving the sleeve 688 comprises a ratchet wheel 746 secured to the outer end of the sleeve and a pair of pawls 748 and 750 pivoted, respectively, at 752 and 754 upon an arm 756 of an oscillating pawl carrier 758 pivoted upon a stud 759 threaded at one end into the bore in the outer end of the sleeve 688. The pawls 748 and 750 are connected by a tension spring 760 which maintains the acting ends of the pawls in engagement with the teeth on the periphery of the ratchet wheel 746. The acting ends or tooth engaging projections on the pawls face in the same direction and the pawls co-operate to impart rotary move-
ment to the ratchet wheel during the oscillation of the pawl carrier 758. As shown in Fig. 10, the acting ends of the pawls are not spaced an integral number of teeth apart but the acting end of the pawl 748 is arranged an integral number and a half teeth in advance of the acting end of the pawl 750. The mechanism for oscillating the pawl carrier 758 comprises an actuating lever 762 having its forward end engaged between and pivotally connected by a stud 764 with the spaced arms 766 on the pawl carrier. The lever 762 is pivotally mounted at 768 upon the upper end of the link 770, which is pivoted at 772 upon a pivoted support 774 adjustably mounted to swing upon an axis substantially parallel with the pivotal connection between the upper end of the link 770 and the lever 762. In the construction shown the support 774 comprises the substantially parallel side arms or plates 776 and 778 between which the lever 762 and the link 770 move, the support being mounted upon trunnions 780 and 782 extending laterally from the side plates 776 and 778 and engaging in bearings in the frame of the machine, as shown in Fig. 12. The rear end of the lever 762 is pivotally connected to the lower end of a link 784, the upper end of which carries a sleeve 786 adjustably mounted thereon and pivotally connected at 788 to the rear end of the cam lever 790. The cam lever is mounted upon the shaft 580 and carries at its forward end a cam roll 792 engaging in a cam groove in a cam disk or wheel 794 mounted on the sewing cam shaft. During the sewing operation the lever 762 is oscillated about its connections with the support 774 to oscillate the pawl carrier 758 upon the shaft 684 to cause the pawls to advance the ratchet wheel 746, a back and forth movement being imparted to the pawl carrier and pawls during each cycle of operations.
The speed at which the sleeve 688 and the bevel gears 696 and 694 are driven is regulated by the angular adjustment of the pivoted support 774. The parts of the mechanism described are so arranged that, at the end of the stroke of the lever 762 in a direction to retract the pawls 748 and 750, the center of the pivotal connection between the link 770 and the lever 762 is in alignment with the axis of the pivoted support 774. When the lever 762 is actuated in a direction to advance the pawls, the lever will have a compound movement, the pivotal connection 764 between the lever and the pawl carrier 756 swinging about the axis of the shaft 759 and the pivotal connection between the upper end of the link 770 and the lever swinging about the pivotal connection between the lower end of the link and the support 774. It will thus be seen that with this construction and arrangement of parts, 130

an angular adjustment of the pivoted support 774 in a left-hand or counter-clockwise direction (Fig. 10) will cause a greater amount of the movement of the left-hand 5 end of the lever 762 to be absorbed in the angular movement of the link 770 about its pivotal connection with the support, and this will result in a lessening of the movement imparted to the right-hand end of the 10 lever and to the pawl carrier, and that an adjustment of the pivoted support in a right-hand or clockwise direction will correspondingly increase the amount of movement imparted to the right-hand end of the lever and 15 to the pawl carrier.

The movement imparted by the lever 762 to the pawl carrier 758, and to the pawls 748 and 750, is an accelerated movement, the pawl carrier and pawls increasing in the 20 speed of their movement as the rear end of the lever 762 swings upwardly. It is to be noted that whatever the amplitude of movement of the pawls, or the speed of the pattern cam shaft, the pawls are advanced to 25 drive the cam shaft throughout substantially the same part of a rotation of the sewing cam shaft, or throughout substantially the same period in each cycle of operation. The cam shaft is preferably driven 30 during a part of a cycle of operations, including the period in which the shoe is fed. This driving mechanism for the cam shaft has the advantage that it drives the cam shaft smoothly at either high or low speed.

To enable the adjustment of the support 774 to be effected, a gear segment 796 is 35 formed on the support, this gear segment meshing with a gear segment 798 mounted upon the end of a shaft 800 (Fig. 33) journaled in a bushing 802 secured in the frame 40 of the machine. Fixed upon a reduced portion of the shaft 800 is a disk 804 upon which is formed a series of teeth 806. The teeth on the disk are adapted to be engaged by 45 the acting ends of either of the pawls 808 and 810 mounted to oscillate about the axis of the disk. In the illustrated construction, the pawl 808 is pivoted at 812 upon a pawl carrier 814 pivoted upon the bushing 802. The pawl 808 is pivotally connected at 816 with one end of the link 818, the opposite end of which is pivotally connected at 820 with an arm 822 on the rock shaft 824. The swinging of the arm 822 in one direction advances the pawl and tends to engage the pawl with the teeth 806 on the disk 804, while the swinging of the arm 822 in the opposite direction retracts the pawl and tends to release the pawl from engagement with the teeth 806. The movement 55 of the pawl about its pivotal connection with the carrier 814 in a direction to disengage its acting end from the teeth 806 is limited by the engagement of an adjustable abutment screw 826 threaded into the pawl car-

rier with the pawl. The pawl 810 is mounted and actuated in a similar manner. The pawl 810 is pivotally mounted at 828 upon a pawl carrier 830 pivoted upon the bushing 802. The pawl 810 is pivotally connected 70 at 832 with one end of the link 834, the opposite end of which is pivotally connected at 836 with a second arm 838 on the rock shaft 824. The movement of the pawl 810 about the pivotal connection 828 in a direction to disengage its acting end from the teeth 806 is limited by the engagement of an adjustable abutment screw 840 with the pawl. The rock shaft 824 is operated by means of a gear 842 secured to the rock shaft and a gear segment 844 (see Fig. 3) formed at the end of one arm of a bell crank lever 846 meshing with the gear. The bell crank lever 846 is pivoted at 848 on the frame of the machine, and carries at the end 85 of its other arm a cam roll 850 engaging a cam groove in the cam wheel 794. A fiber block 852 is mounted in a cylindrical chamber in the pawl carrier 830, and is acted upon by a coiled spring 854 interposed between 90 the block and the end wall of the chamber which forces the block yieldingly against the pawl carrier 814, as shown in Fig. 33. The block acts as a brake upon the pawl carriers, and causes the pawls to swing on their pivotal connections with the pawl carriers to carry their acting ends toward and from the disk 804 respectively before they are advanced and retracted about the axis of the disk. The acting ends of the pawls face 95 in opposite directions, and are therefore adapted to rotate the disk in opposite directions.

The engagement of the pawls 808 and 810 with the teeth 806 on the disk 804 is controlled by a shield 856 mounted to rotate upon a bushing formed on the disk 804 and located adjacent one side of the disk in position to engage the lateral projections 858 and 860 formed on the pawls. The shield 105 110 is formed with arc shaped edges or faces 862 and 864 located slightly beyond the teeth on the disk 804 for engagement, respectively, with the lateral projections 858 and 860 on the pawls to prevent the pawls from engaging the teeth on the disk. Between the faces 862 and 864 the shield is cut away as at 866 (Fig. 11) to enable either of the pawls to engage the teeth on the disk when the shield is turned to bring the cut-away 115 into a position opposite the acting end of the pawl. The width of the cut-away 866 in the shield, however, is such that, when the shield is in central or normal position, as shown in Fig. 11, the projections 858 and 860 on the pawls will be respectively engaged with the arc shaped faces 862 and 864 of the shield and both the pawls will be held out of engagement with the teeth on the disk 804. When the speed of the bevel gears 694 and 120 125 130

696 and of the pattern cam shaft is to be increased the shield 856 is turned in a direction to disengage the arc shaped face 862 of the shield from the projection 858 and to 5 place the cut-away 866 in the shield opposite the acting end of the pawl 808 to permit the pawl to engage the teeth 806 on the disk 804. With the acting end of the pawl engaged with the teeth on the disk during the advancing 10 movement of the pawl the disk will be turned in a left hand or counter-clockwise direction (Fig. 11), thereby causing an adjustment of the pivoted support 774 to increase the speed at which the bevel gears 694 and 696 and the pattern cam shaft are 15 driven. In a corresponding manner, when the speed of the bevel gears 694 and 696 and of the pattern cam shaft is to be reduced the shield 856 is turned in a direction to disengage 20 the arc shaped face 864 of the shield from the projection 860 and to place the cut-away 25 in the shield opposite the acting end of the pawl 810 to permit this pawl to engage the teeth 806 on the disk 804. Then, during the advancing movement of the pawl 810 the disk will be turned in a direction to adjust 30 the pivoted support 774 to diminish the speed of the bevel gears and of the pattern cam shaft.

30 The shield 856 is shifted about the axis of the disk 804 in one direction or the other to throw one of the pawls 808 and 810 into operation by the movement of a lever 864^a, having one end pivotally connected at 866^a 35 with the shield. Intermediate its ends the lever 864^a is pivoted at 868 to the longitudinally movable rod 870 the longitudinal position of which is determined by mechanism controlled by the timed relation of the shoe 40 and the cam shaft. The other end of the lever 864^a is pivotally connected at 872 with one end of the rod 874 upon which is mounted a hollow cylinder or sleeve 876. The sleeve is pivotally connected at 878 with 45 the forwardly extending arm of a bell crank 880 pivoted at 882 upon the rearwardly extending arm of a bell crank 884. A yielding connection is provided between the sleeve 876 and the rod 874 which will permit the 50 rod and the sleeve to move relatively in either direction longitudinally of the rod. In the construction shown (see Fig. 35) the left hand end portion of the rod which is somewhat larger than the remainder of the 55 rod is fitted in a suitable opening in a cap 886 threaded upon one end of the sleeve 876, and a bushing 888 is threaded upon the opposite end of the rod and is fitted in a suitable opening in the opposite end of the 60 sleeve. Mounted upon the rod at the left hand end of the chamber in the sleeve is a collar 890 arranged to engage the shoulder 892^a at the juncture of the enlarged portion of the rod and the reduced portion of the 65 rod and the inner face of the cap 886, and

mounted upon the rod at the opposite end of the chamber in the sleeve 876 is a corresponding collar 892 arranged to engage the inner end of the bushing 888 and the end wall of the chamber in the sleeve. A coiled spring 70 75 894 surrounds the rod within the chamber in the sleeve and acts against the collars 890 and 892 at its opposite ends. With this construction it will be noted that a movement of the rod 874 relative to the sleeve 876 or a movement of the sleeve relative to the rod in either direction will compress the spring 894. The bell crank 884 which carries the bell crank 880 at the end of its rearwardly extending arm is pivoted upon a stud 896 80 carried by a bracket 898, and its other arm is pivotally connected at 899 with the link 900, constituting one member of a toggle, the other member of which consists of a link 902 pivotally connected with the link 900 at 85 904. The link 902 of the toggle is pivotally connected at 906 with one arm of a lever 908 pivoted upon the stud 896. The other arm of this lever carries a cam roll 910 engaging in a cam groove 912 in a cam disk 914 loosely 90 mounted upon the upper end of the pattern cam shaft 248. The cam disk 914 is journaled upon the hub of a disk 916 (see Fig. 36) secured to the cam shaft 248 and is 95 driven from the gear 682 at the same speed as said gear through connections presently to be described.

The disk 804 is held stationary except during the forward strokes of the pawls 808 and 810 by means of a brake shoe 918 (see 100 Fig. 34) formed on the arm 920 of a lever 922 pivoted upon the stud 924, said brake shoe being arranged to engage frictionally the periphery of the disk. The lever 922 is actuated to engage the brake shoe 918 with the periphery of the disk 804 by the movement of a lever 926 pivoted at 928 on the frame and carrying an abutment screw 930 for engagement with the forward face of the arm 932 of the lever 922. The required 105 movements are imparted to the lever 926 by means of an arm 934 on the pull-off actuating lever 578, having a cam face 936 engaging a roll 938 mounted on the end of the lever 926.

The angular position of the bell crank 880 is controlled by a link 940 pivotally connected at its rear end to the laterally extending arm of the bell crank 880 and at its forward end to an arm of a lever 942 pivoted 110 upon the stud 924 above the lever 922. A gear segment 944 is carried by the lever 942 and meshes with a gear segment 946 secured to the upper side of the disk 804.

The position of the central joint 904 of the toggle consisting of the toggle links 900 and 902 is controlled through a link 948 pivotally connected at one end to the link 902 at a point intermediate the ends of the latter link and at the other to one arm of a 115 120 125 130

bell crank 950 pivoted upon the stud 952 carried by an arm on the bracket 898. The other arm of the bell crank 950 is connected by a link 954 with the arm 956 of an adjustable lever 958 pivoted upon bearing pins 960. The angular position of the lever 958 is determined by the size of the shoe to be sewn upon by the machine, the lever being positioned before the machine is started by the placing of the shoe in proper position in the machine for the starting of the seam through connections with the jack herein-after described.

For the purpose of eliminating as far as possible hard motions between the cams and the cam levers or actuating the jack, the speed of the cam shaft is controlled by the action of the cam groove 912 in the cam disk 914 on the cam roll 910. After a shoe is placed in operating position in the machine, the lever 958 is locked in position so that the bell crank lever 950 has no movement during the sewing operation. Through the action of this cam groove on the cam roll 910 the lever 908 is swung about the stud 896. The swinging of the lever 908 through the toggle links 902 and 900 will swing the bell crank 884 about the stud 896. When the pattern cam shaft in its rotation approaches a point where the speed of the cam shaft is to be increased to relieve a hard motion between one of the pattern cams and the lever for actuating the jack therefrom, the cam roll carrying arm of the cam lever 908 is swung to the left (Fig. 11) by the action of the cam groove 912 on the cam roll 910. As the cam roll carrying arm of the cam lever 908 is swung to the left, the movement of the cam lever will swing the bell crank 884 to the left about the stud 896. This movement of the bell crank 884 will carry the pivot of the bell crank 880 mounted thereon to the left. During the lateral movement of the pivot of the latter bell crank, the lever 942 to which the forward end of the link 940 is connected is held in a substantially stationary position, and because of the connection of the laterally extending arm of the bell crank 880 with the rear end of the link, said arm will be maintained very nearly in an unvaried angular position. The lateral movement of the pivot of the bell crank 880, will, therefore, result in a substantially bodily lateral movement of the bell crank. As the bell crank 880 is moved bodily to the left the sleeve 876, to which the forwardly extending arm of the bell crank is connected and the rod 874 connected with the sleeve will be moved to the left and the lever 864^a will be swung upon its pivotal connection with the rod 870 in a direction to carry the pivotal connection 866^a between the forward end of the lever and the shield 856 to the right, the rod 870 then being held in position by the mecha-

nism controlled by the time relation of the shoe and the pattern cam shaft. This movement of the lever 864^a will turn the shield 856 in a clockwise direction until the arc-shaped face 862 of the shield is disengaged from the projection 858 on the pawl 808, and the projection engages in the cutaway 866 in the shield so that the pawl can engage the teeth on the disk 804. The pawl 808 acting on the teeth on the disk 804 during its advancing stroke will turn the disk in a left-hand or counter clockwise direction, (Fig. 11), and through the connections described between the disk and the pivoted support 774 will turn the support in a right hand or clockwise direction (Fig. 10) which will result in increasing the amount of movement imparted by the pawl carrier 758 and the pawls 748 and 750 to the toothed disk 746, or in increasing the speed of rotation of the pattern cam shaft through the connections hereinbefore described. In the same manner when the speed of the pattern cam shaft, after having been increased, is to be reduced to normal again, the cam roll carrying arm of the cam lever 908 is swung to the right (Fig. 11). This movement of the cam lever will cause the shield 856 to be turned in the opposite or in a counter clockwise direction until the face 864 of the shield is disengaged from the projection 860 on the pawl 810, and the projection engages in the cutaway 866 in the shield so that the latter pawl can engage the teeth on the disk 804. Through the action of the pawl 810 on the disk the disk will be turned in a clockwise direction, and the pivoted support will be swung upon its axis in a left hand or counter clockwise direction (Fig. 10) to diminish the speed at which the toothed disk 746 is driven by the pawls 748 and 750, and to diminish the speed of the pattern cam shaft.

The shifting of the angular position of the lever 958, when a shoe is placed in operating position in the machine through the connections between said lever and the toggle consisting of the toggle links 900 and 902, will shift the position of the toggle. The shifting of the toggle through the connection between the toggle and the bell crank 884, will swing this bell crank about the stud 896 in one direction or the other depending upon the direction in which the lever 958 is shifted. The swinging movements of the bell crank 884 produced by the shifting of the lever 958 will cause either an increase or a decrease in the speed of the pattern cam shaft in the same manner that the swinging movements of the bell crank produced by the cam lever 908 causes the change in the speed of said shaft, as hereinbefore described. When changing from a certain size shoe to a smaller size, the lever 958 is swung forwardly thereby through the connections be-

115

120

125

130

tween the arm 956 of the lever and the toggle, the central joint of the toggle is shifted to the left (Fig. 11). This will result in swinging the bell crank lever 884 to the left 5 on its axis and in increasing the speed of the cam shaft in the manner explained above. In changing from a certain size shoe to a larger size, the lever 958 will be swung rearwardly, the central joint of the toggle will 10 be shifted to the right (Fig. 11), the bell crank lever 884 will be swung to the right, and the speed of the pattern cam shaft will be reduced.

The longitudinal movement of the rod 870 15 in either direction will swing the lever 864^a about its pivotal connection with the end of the rod 874. The shifting of the rod to the right (Fig. 11) will actuate the lever 864^a to turn the shield in a clockwise direction, 20 thereby throwing the pawl 808 into operation, and will therefore produce an increase in the speed of the pattern cam shaft. In a corresponding manner the shifting of the rod to the left (Fig. 11) will actuate the 25 lever 864^a to turn the shield in a counter clockwise direction, thereby throwing the pawl 810 into operation and producing a decrease in the speed of the pattern cam shaft. The longitudinal position of the rod 870 30 is determined by the time relation of the shoe and the pattern cam shaft. As long as a predetermined time relation is maintained between the shoe and the pattern cam shaft, or as long as the shoe is fed at the predetermined rate for which the cam shaft is timed 35 when the operation is started, the longitudinal position of the rod 870 will be substantially unchanged. In case the shoe lags behind the cam shaft, thereby disturbing the 40 proper time relation of the shoe and the shaft, the rod 870 will be shifted longitudinally to the left to produce a decrease in the speed of the cam shaft. In case the shoe gets ahead of the cam shaft the rod 870 will be 45 shifted to the right to increase the speed of the cam shaft.

After one of the pawls 808 and 810 has 50 acted to adjust angularly the disk 804, thereby producing a change in the speed of the cam shaft 248, the shield 856 is turned back to its central or normal position to throw the active pawl out of operation.

The manner in which the shield 856 is restored to its central or normal position is as 55 follows: when the lever 864^a has been actuated to turn the shield 856 in a direction to throw the pawl 808 into operation or in a clockwise direction, the turning of the disk 804 produced by the action of the pawl 808 60 through the gear segments 946 and 944 swings the lever 942 on its pivot in a direction to move the link 940 endwise toward the front of the machine. The movement of the link 940 swings the bell crank 880 upon its pivot and through the connection of the bell 65

crank with the lever 864^a the latter lever will be swung upon its pivotal connection with the rod 870 to turn the shield in a counter clockwise direction to its central position, as shown in Fig. 11. In a similar manner when the lever 864^a has been actuated to turn the shield 856 in a counter clockwise direction to throw the pawl 810 into operation, the turning of the disk 804 by the pawl 810 through the connections described will 70 swing the lever 864^a on its pivotal connection with the rod 870 to turn the shield 856 in a clockwise direction to its central position. 75

The cam disk 914 is driven from the spiral gear 680 by the following driving connections (see Figs. 9 and 36). A pinion 962 is journaled upon a stud 964 secured in the arm 966 of a pivoted carrier 968, and meshes with the peripheral teeth 970 on the cam disk 914. The carrier 968 has the construction shown in Fig. 36 and is pivoted upon a hollow stud 972 projecting upwardly from the frame and upon a collar or bushing 974 held in place by a screw 976 passing through the stud and threaded into the frame. Journaled upon the stud 972 is a pinion 978 meshing with the pinion 962 and also meshing with a third pinion 980 journaled upon a stud 982 secured in the frame of the machine. The pinion 980 is also in mesh with the peripheral teeth of the gear 682. The pivoted carrier 968 is held stationary during the operation of the machine. The pinions 962 and 980 are substantially identical in size and in number of teeth so that the cam disk 914 is driven at the same speed as the gear 682. 90

The parts are so constructed and arranged that when a right shoe is being sewn, 105 the cam groove 912 acting on the cam roll 910 will actuate the lever 908, and the parts connected therewith to produce a change in the speed of the pattern cam shaft at least one stitch in advance of the point or time at which the change in the speed of the shaft is to be produced. In order that the actuation of the cam lever 908 may occur at least one stitch in advance of the point or 110 time at which the change in the speed of the pattern cam shaft is to be produced when the cam shaft is reversed for the sewing of a left shoe, the cam disk 914 is shifted angularly about the pattern cam shaft upon reversing the driving connections to reverse the direction of rotation of the cam shaft a distance corresponding to two stitches or to two cycles of operation of the sewing mechanism. This shifting of the cam disk 914 is 115 effected by swinging the carrier 968 on its pivot through connections with lever 716. In the construction shown these connections comprise an arm 984 (see Fig. 9) formed on the lever 716, an arm 986 formed on the pivoted carrier 968, and a bolt 988 secured in a 120 125 130

slot 990 in the arm 984 and operating in a slot 992 in the arm 986. When the lever 716 is adjusted by the operator to reverse the direction of rotation of the pattern cam 5 shaft, the swinging of the lever through the above described connections between the lever and the pivoted carrier 968 will swing the carrier upon its axis. During the swinging movement of the carrier, the pinions 980 10 and 978 then being held from turning movement through the meshing of the teeth of the pinion 980 with the teeth of the gear 682, the gear 962 will be turned upon the stud 964 in a clockwise direction, thereby turning the disk 914 on the cam shaft 248 in a counter clockwise direction. The extent of the swinging movement of the carrier 968 may be regulated to regulate the angular adjustment of the disk 914 by adjusting the bolt 20 988 in the slot 990 in the arm 984. The forward end of the link 940 is connected with the lever 942 by a pin or bolt 990^a secured in a slot 992^a in the lever 942. By adjusting the bolt 990^a in the slot 992^a the speed 25 of the pattern cam shaft may be regulated to correspond with different adjustments of the shoe feeding mechanism for different lengths of feed.

The mechanism controlled by the time relation of the shoe and the pattern cam shaft 248 for determining the longitudinal position of the rod 870, and for shifting the same (see Figs. 1, 3, 37 and 54 to 58) comprises a lever 994 pivoted by means of a 30 stud 996 between the arms of a U-shaped hanger 998, which is pivoted upon trunnion pins 3 mounted in the spaced arms 5 of a bracket 7 secured to the frame of the machine. The rear end of the lever 994 is pivotally connected at 9 to the rod 870. The 35 distance between the axis of the stud 996 connecting the hanger 998 and the lever 994 and the center of the pivotal connection 9 connecting the lever with the rod 870 is substantially the same as the distance between the axis of the stud 996 and the axis of the trunnion pins 3, upon which the hanger is pivoted, so that the center of the pivotal connection 9 may be brought into alignment 40 with the axis of the hanger. The forward end of the lever 994 is connected by a universal joint 11 with one end of the rod 13, the other end of which is connected by a universal joint 15 with the toe support 164 of 45 the jack frame. The rod 13 is made in three sections connected by swivel joints indicated at 17 and 19 which enable the parts of the rod to turn relatively. The connection between the lever 994 and the jack frame causes 50 the forward end of the lever to move with the shoe as the shoe is moved to present the different portions of the margin of the shoe bottom to the action of the stitch forming devices. During the movement of the forward end of the lever 994 the lever can swing 55

with the hanger 998 about an axis coincident with the axis of the hanger, or there can be a relative swinging movement between the hanger and the lever about the stud 996. As long as the lever moves only about an axis substantially coincident with the axis of the hanger, or as long as there is no relative swinging movement between the lever and the hanger, the pivotal connection 9 between the rod 870 and the lever will be held 70 substantially in alignment with the axis of the hanger, the rod will be held stationary, and the pattern cam shaft will be driven at a predetermined speed relative to the feeding devices or to the shoe. When, however, any relative swinging movement occurs between the lever 994 and the hanger 998 about the stud 996 in one direction or the other, the rod 870 will be moved longitudinally, thereby producing a variation in the speed 75 of the cam shaft, the relative movement of the lever and hanger in one direction causing a movement of the rod 870 to increase the speed of the cam shaft, and the relative movement of the lever and hanger in 80 the other direction causing a movement of the rod 870 to diminish the speed of the cam shaft. It is to be noted that the forward end of the lever 994 is controlled by and moves with the shoe at all times during the 85 sewing operation, so that the position of the forward end of the lever at any point in the sewing operation is determined by the position of the shoe.

Mechanism is provided for moving the 100 lever 994 from the correcting cam shaft so that when the shoe is fed at a predetermined rate relative to the rotation of the pattern cam shaft the pivotal connection 9 will be maintained in alignment with the axis of 105 the hanger 998, and that when the rate of feed of the shoe varies from the predetermined rate of feed the lever 994 will be swung relatively to the hanger 998 in one direction or the other to vary the longitudinal 110 position of the rod 870. This mechanism comprises a lever 21, the construction and arrangement of which are best shown in Figs. 3, 37, and 54 to 58. This lever is pivoted at 23 between the spaced arms 25 of 115 the hanger 27 which in turn is pivoted at 29 between the spaced arms 31 of the lever 958. This manner of mounting the lever 21 gives the lever a virtual or effective pivot at 29 about which it can be swung. At its forward end the lever 21 is pivotally connected at 33 with the lever 994, the lever 21 engaging between the body of the lever 994 and an arm 35 on the latter lever, and being connected by a stud with the latter lever. It 120 will be seen that for every position of the forward end of the lever 994 there is a position of the pivotal connection 33 requisite to maintain the pivotal connection 9 in alignment with the axis of the hanger 998. The 130

lever 21 controls the position of the pivotal connection 33 during the sewing operation, and is actuated from the pattern cam shaft so that when the shoe is fed at a predetermined rate relative to the rotation of the pattern cam shaft it will move the pivotal connection 33 so as to maintain the pivotal connection 9 in alignment with the axis of the hanger 998. The lever 21 is connected by a link frame 37 with the upper arm 39 of a lever 41 pivoted upon trunnion pins 43 carried by the spaced arms of a bracket 45. Different connections are employed to actuate the lever 21 from the pattern cam shaft respectively when sewing right and left shoes. The mechanism employed in sewing a right shoe comprises a lever 47 pivoted upon the shaft 270, and a link 49 connecting the lower arm 51 of the lever 41 with the rearwardly extending arm 53 of the lever 47. The lever 47 is formed with arms 55 carrying a segment plate 57 having a notch adapted to receive the upper end of a latch 59. The latch 59 is pivoted upon a stud 61 mounted in one arm of a cam lever 63 pivoted on the shaft 270. Upon the other arm of the cam lever is mounted a cam roll 65, engaging a cam groove in the cam disk 352. The mechanism for actuating the lever 41, when a left shoe is being sewn, comprises a lever 67 pivoted on the shaft 270 and a link 69 connecting the lower arm 51 of the lever 41 with the forwardly extending arm 69^a of the lever 67. The lever 67 is formed with arms 71 carrying a segment plate 73 having a notch adapted to receive the lower end of the latch 59 to connect the lever 67 with the cam lever 63. In order to take up lost motion in the connections between the cam lever 63 and the lever 41, a coiled spring 75 is attached at one end to the link 49, and at the other end to the frame. The lever 958 which controls the position of the fulcrum 29 of the lever 21 as stated above is locked in position during the sewing of a shoe. The cam groove in the cam disk 352 in which the cam roll 65 engages, acting through the connections described on the lever 21, moves the lever 21 about its fulcrum 29 during the sewing operation. The cam groove is so formed that when a shoe is placed upon the jack and fed at a predetermined rate relative to the rotation of the pattern cam shaft, the lever 21 will be actuated to move the pivotal connection 33 so that the center of the pivotal connection 9 will always lie in alignment with the axis of the hanger 998, as shown in Figs. 56, 57 and 58. As long as the shoe is fed at the predetermined rate relative to the rotation of the pattern cam shaft, the lever 994 will swing about the pivotal connection 9 as the forward end of the lever is actuated by the movements of the jack, and there will be no swinging movement of the lever 994 relative to the hanger 998.

While the predetermined feed of the shoe is maintained, the longitudinal position of the rod 870 will, therefore, be unchanged. When, however, the shoe is fed at a rate which is faster or slower than the predetermined rate of feed, the lever 994 will swing relatively to the hanger 998, and the pivotal connection 9 will be thrown out of alignment with the axis of the hanger. This swinging movement of the lever 994 relative to the hanger will thus move the rod 870 longitudinally to vary the speed of the pattern cam shaft. The manner in which the mechanism for controlling the speed of the pattern cam shaft operates is illustrated in Figs. 54 and 55. When the shoe is fed at a rate which is faster than the predetermined rate, the lever 994 will be swung about the pivotal connection 996 relatively to the hanger 998 into a position such as that shown in Fig. 54. This movement of the lever will move the rod 870 to the right, thereby producing an increase in the speed of the cam shaft to restore its proper timed relation to the shoe. In a corresponding manner, when the shoe is fed at a rate relative to the cam shaft, which is slower than the predetermined rate, the lever 994 will be swung relatively to the hanger into a position such as that shown in Fig. 55. This swinging movement of the lever will move the rod 870 to the left, thereby producing a reduction in the speed of the cam shaft to restore the cam shaft and the shoe to their proper timed relation. The cam shaft thus is timed for a predetermined rate of feed of the shoe and is driven at a predetermined rate of speed as long as the predetermined rate of feed of the shoe is maintained. When, however, the rate of feed of the shoe varies from the predetermined rate, the speed of rotation of the cam shaft is varied automatically to restore the proper time relation of the cam shaft and the shoe.

It has been found that in actual practice the variation in the rate of feed of the shoe from the predetermined rate of feed will not exceed twenty five per cent. For this reason a twenty five per cent variation in the speed of rotation of the pattern cam shaft will be sufficient to restore the cam shaft and the shoe to their proper timed relations with the greatest variation in the rate of feed of the shoe from the predetermined rate that will occur, and if the pattern cam shaft speed controlling mechanism is arranged to produce a greater variation than this, an uneven and jerky motion of the jack during the sewing will result. In order to limit the amount of variation in the speed of the pattern cam shaft which can be produced by the speed controlling mechanism, the longitudinal movement of the rod 870 is limited by suitable devices. The devices for limiting the

longitudinal movement of the rod 870 are constructed and arranged so that whether the pattern cam shaft is rotating at a relatively high or at a relatively low rate, a variation of substantially twenty five per cent can be produced in the speed thereof to restore the cam shaft and the shoe to their proper timed relations. To this end the devices for limiting the movement of the rod are adjusted so that the rod can have a greater longitudinal movement when the pattern cam shaft is rotating at a relatively high rate than when the speed of rotation of the cam shaft is relatively slow. 10 In the construction illustrated the mechanism for limiting the movement of the rod 870, (see Figs. 11, 12, and 34), comprises a block 77 secured to the rod and having spaced projections 79 and a cam shaped stop member 81 located between the projections and adapted to limit the longitudinal movement of the rod in either direction through the engagement of one or the other of said projections with said member. The stop member 81, is mounted on one end of a shaft 83 journaled in one arm of the lever 922. To the shaft 83 is attached a gear segment 85 meshing with the gear segment 944. The stop member 81 has the irregular or cam shape shown clearly in Fig. 34. It will be noted that with a stop member of the shape shown in this figure, when said member is turned in a clockwise direction from the position shown in said figure, its 20 contact faces will approach the adjacent faces of the stop projections 79, and thus reduce the distance which the rod 870 can move longitudinally in either direction, and that when said member is turned in a counter-clockwise direction, its contact faces will recede from the adjacent faces of the projections 79 and increase the distance which the rod can move. Through the connections between the stop member 81 and the disk 804 the stop member will be turned in a clockwise direction through the rotary adjustment of the disk to reduce the speed of the cam shaft, and will be turned in a counter-clockwise direction through the adjustment of said disk to increase the speed of the cam shaft. 30

The fulcrum 29 of the lever 21, as above described, is carried at the end of arms 31 of the lever 958, so that the fulcrum may be shifted forwardly or rearwardly to vary relatively the lengths of the arms of the lever 21 in changing from one size of shoe to another. In changing from one size to a smaller size, the fulcrum of the lever 21 is shifted forwardly to shorten the length of the forward arm of the lever and to increase the length of the rear arm thereof, while in changing to a larger size the fulcrum of the lever is shifted rearwardly to increase the length of the forward arm of the lever and

to shorten the length of its rear arm. The mounting of the lever 21 on a fulcrum which is movable to vary the relative lengths of the arms of the lever enables the same cam to be employed for actuating the lever for all sizes 70 of shoes. The fulcrum of the lever 21 is located in the proper position for the size of shoe which is to be sewn by the placing of the shoe in the machine in correct position for starting the seam. At the time when the shoe 75 is placed in the machine the rod 870 is positioned so that the center of the pivotal connection 9 lies in alignment with the axis of the hanger 998 and is locked in such position. The lever 958 is at that time unlocked so that it can move freely about its axis. When the shoe is placed in the machine in correct position for the starting of the seam, the position of the forward end 80 of the lever 994 will depend upon the size 85 of the shoe. The larger the shoe which is placed in the machine, the farther the forward end of the lever will be located to the right, and the smaller the shoe the farther to the left will be the position of the forward end of the lever. With the connection between the lever 994 and the rod 870 located in alignment with the axis of the hanger 998, any change in the position of the forward end of the lever 994 will cause the lever 95 to swing about the pivotal connection 9. This movement of the lever 994, through its connection with the lever 21, will actuate the latter lever, the hanger 27 and the lever 958 to shift the fulcrum of the lever 21. The 100 movement of the forward end of the lever 994 to the right, which would be produced by a change in the size of the shoe to be sewn from a certain size to a larger size, will cause the fulcrum 29 to be shifted rearwardly of the lever 21, and in the same way the movement of the forward end of the lever 994 to the left, which would be produced by a change from a certain size to a smaller size, will cause the fulcrum 29 to be 105 shifted forwardly of the lever 21. 110

The position of the lever 958 is thus determined by the size of the shoe placed in the machine, and through the connections between the arm 956 of said lever and the mechanism for controlling the speed of the pattern cam shaft hereinbefore described the cam shaft driving mechanism is set to drive the cam shaft at the proper speed for the size of the shoe to be sewn, or is timed for a 120 predetermined rate of feed of the shoe. The change in the position of the lever 958 in a direction to shift the arms 31 of the lever toward the rear of the machine, which is produced by the placing of a shoe in the machine to be sewn of a larger size than that previously sewn, through the link 954, the bell crank 950, the link 948, and the toggle links 902 and 900, will shift the bell crank 884 to the right, (Fig. 11), and will thus cause 125 130

the pattern cam shaft speed controlling devices to be set to rotate the cam shaft at a slower speed than before, while the change in the position of the lever 958 in a direction 5 to shift the arms 31 of said lever forwardly which is produced by the placing of a shoe in the machine of a smaller size will shift the bell crank 884 to the left and cause said devices to be set to rotate the cam shaft at 10 a faster speed. When the machine is started, the lever 958 is locked in position and remains locked during the entire sewing operation, while the rod 870 is then unlocked. When the machine has been stopped at the 15 completion of the sewing operation, and the jack turned back to starting position ready for another shoe to be placed thereon, the rod 870 is locked in position while the lever 958 is then unlocked, so that the fulcrum 20 for the lever 21 can be located and the cam shaft speed controlling devices can be set for the size of the shoe to be sewn when the shoe is placed in position in the machine for the starting of the seam. The mechanism for locking and unlocking the lever 958, and for locking and unlocking the rod, 25 will be presently described.

Figs. 56, 57 and 58 illustrate the mechanisms for controlling the speed of the pattern cam shaft in the positions which they assume at different points in the operation of sewing a shoe. In each of these figures the parts are illustrated in full lines in the positions which they assume at certain points in the sewing of a large size shoe, and in dotted lines in the positions which they assume at corresponding points in the sewing of a small size shoe. Fig. 56 illustrates the positions of the parts of this mechanism at the beginning of the sewing of a seam, Fig. 57 the positions of the parts during the sewing of the toe of the shoe, and Fig. 58 the positions of the parts at the end of the sewing of the seam. The manner in which the fulcrum of the lever 21 is adjusted for the size of the shoe to be sewn, as described above will be readily understood from an inspection of Fig. 56. The swivel or pivotal connection 19 is preferably located relatively to the jack so that its axis is adjacent to or passes through the center of the toe curve of the shoe, whatever size of shoe is placed on the jack. It will be understood that the limiting positions of the pivotal connection 19 or the positions of this connection at the beginning and at the end of the sewing of the seam will be in symmetrical relation to or upon opposite sides of and at equal distances from the position of this connection when the toe of the shoe is being sewn. The positions of the lever 21 at the beginning and at the end of the sewing of a seam, as shown respectively in Figs. 56 and 58, are symmetrical relatively to its position when the toe of the shoe is reached,

as shown in Fig. 57, to correspond with the limiting positions of the pivotal connection 19. The pivotal connection 23 is brought substantially into line with the pivot 960 of the lever 958 when the toe of the shoe is 70 reached. The fulcrum 29 of the lever 21 is adjusted about the pivot 960 for different sizes of shoes. Changes in the sizes of the shoes placed in the machine therefore do not affect the position of the lever 21 when the 75 toe is being sewn, but this position is the same for all sizes. It will be seen that the movement of the pivotal connection 19 during the sewing of a shoe, or during the sewing between any two points on a shoe, varies with shoes of different sizes and is directly proportional to the size of the shoe placed on the jack. The parts are constructed and arranged so that the fulcrum 29 of the lever 21 is adjusted to cause the movement of the forward portion of the lever to correspond with the movement of the pivotal connection 19. That is, the fulcrum 29 of the lever 21 is adjusted so that the movement of the forward portion of the lever 80 produced during the sewing of a shoe or during the sewing between any two points on a shoe is directly proportional to the size of the shoe.

After the lasted shoe has been secured by 95 the operator in position on the jack and has been positioned to place the projecting edge of the outsole and the welt between the work support and presser-foot of the machine at the proper point in the margin of the shoe 100 bottom for the starting of a seam, the main driving clutch of the machine is engaged by mechanism under control of the operator. During the sewing operation the members 140 and 142 of the main friction 105 driving clutch are held in engagement, and the machine is driven at a speed depending upon the speed of the driving shaft 126. When the sewing operation is completed, the members of the main driving clutch are 110 disengaged and the machine is stopped through the action of automatically acting devices. To enable the members of the main driving clutch to be engaged and disengaged, the sleeve 144 which carries the 115 driven member of the clutch is arranged to slide longitudinally of the shaft 136 upon which it is mounted to engage and disengage the clutch. The spiral gear 146 is formed with a cylindrical recess, as shown in Fig. 4, the upper face of which is engaged by a ball thrust bearing 87 interposed between said face and the upper end of a sleeve 89 mounted on the shaft 136, and in a bearing on the frame to slide longitudinally of the shaft. The upper end of the sleeve 89 is formed with a flange 91 which is adapted to engage an inwardly projecting flange 93 on a collar 95 threaded into the recess in the spiral gear 146. The sleeve 120

89 is moved upwardly by the operator upon starting the machine to lift the sleeve 144 to engage the members of the main driving clutch, and is automatically moved downwardly upon stopping the machine. During the downward movements of the sleeve the flange 91 on the sleeve engages the flange 93 on the collar 95, and moves the sleeve 144 downwardly to disengage the members of the main driving clutch. The collar 95 provides an adjustable connection between the sleeve 89 and the sleeve 144. To enable the collar to be turned readily to adjust the same in the recess in the spiral gear 146 the collar is formed with a series of openings 97 in which may be inserted any suitable tool for turning the collar. The collar when adjusted is held in adjusted position by means of a pin 99 mounted in the spiral gear, the lower end of which is adapted to engage in any one of a series of recesses 101 in the collar. The pin is acted upon by a spring 103 attached to the spiral gear and bearing upon the head of the pin which holds the lower end of the pin in engagement with the recess in the collar.

The mechanism by which the sleeve 89 is actuated to cause the engagement and disengagement of the main driving clutch, (see Figs. 4, 5, 6, 40, 41, 42 and 43), comprises a disk 105 carried at one end of, and preferably formed integral with a sleeve 107 mounted in a bearing 109 in the frame of the machine, said disk having a series of teeth 111 meshing with a series of teeth 113 formed on the exterior of the sleeve 89. To the opposite end of the sleeve 107 is clamped an arm 115 to the outer end of which is connected by means of a stud 117 a hollow cylinder 119. Through this cylinder passes a rod 121 pivotally connected at one end by a stud 123 to the arm 125 of a lever 127 keyed to one end of a shaft 129 mounted to turn in the sleeve 107. Surrounding the rod 121 within the cylinder 119 is a coiled spring 131 which at its lower end engages the lower end wall of the cylinder and at its upper end acts against a collar 133 held by a stop nut 135 upon the rod, the collar being arranged to slide in the upper end of the cylinder. This spring furnishes a yielding connection between the arm 115 and the lever 127. Upon the opposite end of the shaft 129 is mounted a carrier 137 formed with a dove-tailed guide in which is mounted a dove-tailed slide 139. The slide is yieldingly held in elevated position in the carrier 137 by a coiled spring 141 attached at its upper end to a pin 143 secured in the carrier and at its lower end to a pin 145 secured in the slide. Projecting forwardly from the slide 139 is a stud 147 carrying a roll 149 which engages in an irregularly shaped inclined slot 151 formed in a bracket 153 secured to the frame of the machine. This roll also engages in an irregularly shaped slot 155 formed in an arm 157 pivoted upon a stud 159 projecting from a lever 161. The lever 161 is provided with a pivot stud or shaft 163 mounted in bearings in the frame of the machine, and is normally held in elevated position by means of a coiled spring 165 attached at its lower end to a pin projecting from a stud 159^a formed integral with the lever 161, and at its upper end to a pin 167 mounted on the frame of the machine. The lever 161 is provided with an operating arm 169 terminating in a handle. In starting the machine, the operator seizes the handle of the operating arm 169 and swings the lever 161 downwardly from the position shown in Fig. 6 to that shown in Fig. 40. The arm 157, through its engagement with the roll 149, depresses the roll and the slide 139 upon which it is carried, the roll moving downwardly through the slot 151 in the bracket 153, which acts as a guide for the roll. The lower end of the carrier 137 will thus be swung to the left, Figs. 6 and 40, in starting the machine, and through the connection between the carrier and the disk 105 the disk will be turned in a direction to elevate the sleeve 89 to engage the members of the main driving clutch. When the sleeve 89 has been elevated by the movement of the carrier sufficiently to engage the members of the clutch, the spring 131 will yield during the continued movement of the carrier, and the members of the clutch will be held yieldingly in engagement through the action of the spring. In order to retain the members of the main driving clutch in engagement until the sewing of the shoe is completed, a latch 171 is fixed to a stud 173 mounted to turn in a bearing in the lower end of the carrier 137, and is arranged to be engaged with the end of a holding catch 175 fixed to a stud 177 mounted to turn in a bearing in the frame of the machine. The catch is held in acting position by means of a coiled spring 179. As the lower end of the carrier 137 is swung to the left upon starting the machine, the acting end of the catch 175 snaps in front of the end of the latch 171 into position to hold the end of the carrier from moving back to the right. When the carrier is thus latched in position, the handle of the arm 169 is released by the operator, and the lever 161 is elevated by the action of the spring 165 to its initial position. When the sewing operation is completed, the latch 171 is automatically thrown out of engagement with the catch 175, allowing the lower end of the carrier to be returned to its right-hand position. Also the latch 171 may be disengaged from the catch 175 to stop the machine at any time that the operator may desire by a manual manipulation of the catch 175 which is

provided with a handle for this purpose. As the carrier is released, the spring 141 elevates the slide 139, and through the engagement of the roll 149 with the edge of the slot 151, the lower end of the carrier is swung back to the right. By this movement of the carrier the sleeve 89 is depressed. There is a certain amount of lost motion between the sleeve 89 and the collar 95, and the movement of the sleeve, caused by the swinging movement of the carrier under the action of the coiled spring 141, is not sufficient to disengage the members of the main driving clutch which are subsequently disengaged 15 at a predetermined point in the rotation of the shaft 22 by mechanism hereinafter described.

The machine is provided with devices which act when the main driving clutch is 20 disengaged to slow down the speed of the sewing cam shaft 22, and to cause the cam shaft to stop in a predetermined position. The mechanism for slowing down and finally stopping the cam shaft 22 of the machine 25 comprises a slow speed friction clutch which is disengaged while the machine is driven through the main driving clutch, and is engaged when the main driving clutch is disengaged. This slow speed clutch when engaged first acts as a friction brake to slow 30 down the speed of the sewing cam shaft to the speed of the driving member of the slow speed clutch, and then as a driving clutch to drive the cam shaft forward to stopping position. The slow speed clutch comprises the 35 driving and driven friction clutch members 181 and 183 mounted on the sewing cam shaft 22. The driving member 181 of the clutch is journaled upon a sleeve 185 secured 40 by means of a washer 187 and a bolt 189 to a reduced portion of the shaft 22 to rotate with the shaft. The clutch member 181 is driven by means of a bevel gear 191 meshing 45 with a bevel gear 193 formed on the clutch member. The gear 191 is mounted upon the lower end of a sleeve 195 journaled upon a shaft 197 secured at its upper end in the frame. Mounted upon the upper end of the sleeve 195 is a gear 199 which meshes with a 50 gear 201 formed on the disk 138 which carries the driving member 140 of the main driving clutch. The gears 193 and 191, and 199 and 201, are so proportioned that the clutch member 181 is rotated at slow speed 55 as compared with the speed of rotation of the driving member of the main driving clutch. The driven clutch member 183 of the slow speed clutch is secured to the sleeve 150 which is mounted upon the shaft 22 to 60 rotate with the shaft, but is movable longitudinally of the shaft to carry the driven member of the clutch into and out of engagement with the driving clutch member. The sleeve is secured to rotate with the shaft by 65 means of a bolt 203 threaded into the sleeve,

and engaging in a slot 205 in a flange 207 on the sleeve 185. The clutch members are normally held out of engagement by means of a coiled spring 209 seated at one end in a recess in the flange 207 on the sleeve 185, and at its other end in a recess in the sleeve 150. The movement of the sleeve 150 under the action of the spring is limited by the engagement of the stop nut 211 mounted on the end of the bolt 203 with the flange 207. 75

The mechanism for controlling the engagement and disengagement of the slow speed clutch comprises a cam groove 213 formed in the sleeve 150, in which engages a cam roll 215 mounted on the upper end of an arm 217 secured to one end of a shaft 219 mounted to turn in a sleeve 221 engaging in a bearing 223 on the frame of the machine. During the sewing operation, or while the main driving clutch of the machine is engaged to drive the machine, the arm 217 is oscillated idly by the cam 213. When the main driving clutch is disengaged, the carrier 137 is locked to the arm 217. To this end the upper end of the slide 139 is formed 90 with a locking projection or bolt 225 which is adapted to engage in a recess 227 formed in a lateral projection 229 on the arm 217 to lock the arm to the lock bolt carrier 137. When the main driving clutch is engaged, 95 the slide 139 is held in lowered position with the locking projection 225 disengaged from the recess 227 by the engagement of the roll 149 with the edge of the slot 151. When the latch 171 is disengaged from the catch 175 the slide 139 is elevated by the action of the coiled spring 141, and as the arm 217 reaches the proper point in its oscillating movements, the locking projection 225 engages in the recess 227 to lock the carrier 100 137 to the arm. The lower end of the carrier is adapted to be engaged by a spring-pressed plunger 231 mounted to slide in a suitable guideway in the bracket 153. The plunger is attached to one end of a rod 233, and is 105 acted upon by a coiled spring 235 surrounding the rod 233 and interposed between the plunger and one end of the guideway in which the plunger is mounted. The movement of the plunger under the action of the 110 coiled spring 235 is limited by the engagement with the end of the bracket 153 of a stop nut 237 threaded on the end of the rod. When the lock bolt carrier 137 is released 115 the slide 139 rises under the influence of the spring 141 until the locking bolt 225 engages in the recess 227 and the carrier swings on its axis in a direction to carry the lower end thereof to the right until the movement of the carrier is yieldingly limited by the engagement thereof with the plunger 231, the roll 147 then engaging in a recess 237^a forming part of the slot 151. The projection 225 engages in the recess 227 to lock the arm 217 125 to the carrier 137 when the cam roll 215 is 130

located in the right hand idle portion of the cam groove 213, as shown in Fig. 6. The continued rotation of the sleeve 150 brings the inclined portion of a cam groove 213 leading from the right hand idle portion of the groove to the left hand idle portion thereof into engagement with the roll 215. Through the co-operative action of the cam groove and cam roll during the engagement 10 of the roll in this inclined portion of the cam groove, the sleeve 150 is shifted longitudinally of the shaft 22 to the right Fig. 5, to engage the members of the slow speed clutch, and the carrier 137 is swung on its 15 axis in a direction to carry the lower end thereof farther to the right from the position shown in Fig. 6. By this movement of the carrier the sleeve 89 is depressed to disengage the members of the main driving 20 clutch. This movement of the carrier occurs against the tension exerted by the spring 235 on the plunger 231, and after the cam roll leaves the inclined portion of the cam groove, and is engaged in the right-hand portion 25 thereof, the members of the slow speed clutch are held in engagement with a pressure depending on the tension of this spring. After the members of the slow speed clutch are engaged, the driving member of the clutch which is then rotating at slow speed as compared with that of the driven member of the clutch will first act upon the driven member as a brake to reduce the speed of said member and of the sewing cam shaft upon which 30 it is mounted until these parts are rotating at the speed of the driving member of the clutch. The driving member of the clutch will then act to drive the driven member of the clutch and the sewing cam shaft in a forward direction to stopping position. As the shaft reaches stopping position the members of the slow speed clutch are disengaged, and the rotation of the shaft is arrested by a suitable brake. The sleeve 150 is shifted in 35 the opposite direction, or to the left, Fig. 5, to disengage the members of the slow speed clutch, when the shaft arrives substantially at the predetermined stopping position through the co-operative action of the cam groove 213 and the cam roll 215, during the engagement of the roll in the inclined portion of the cam groove leading from the left hand portion to the right hand portion thereof, and the carrier 137 is at this time 40 swung in a direction to carry the lower end thereof back to the left (Figs. 6 and 40), the swinging movement of the carrier then actuating the devices for engaging the brake. The brake actuating devices (see Figs. 4, 5, 45 6, 40, 49 and 50) comprise a lever 239 secured to one end of the sleeve 221, and having an arm 241 in which is mounted a pin or stud 243, to the lower end of which is secured an arm 245. The arm 245 is swung 50 toward the forward face of the carrier 137 by means of a spring 247 coiled about the stud 243, and having its upper end secured in a collar 249 fixed to the upper end of the stud, and its lower end secured in the arm 241. The acting or right hand end of the 55 arm 245 is adapted to engage the left side of a projection 251 on a pin 253 projecting forwardly from the slide 139. During the sewing operation, or while the main driving clutch is engaged, the lower end of the carrier 137 is held in the position shown in Fig. 40, through the engagement of the latch 171 with the catch 175, so that the lower end of the slide 139 and the pin 253 occupy substantially the positions shown in Figs. 49 60 and 50, the slide being held in depressed position by the engagement of the roll 149 with the edge of the slot 151. The pin 253 is located on the slide so that it then lies below the arm 245. As the latch 171 is released from the catch 175 at the end of the sewing operation, and the slide 139 rises under the influence of the coiled spring 141, the lower end of the carrier 137 does not swing 65 to the right sufficiently to enable the end of the arm 245 to swing toward the carrier into position to engage the left side of the projection 251 on the pin 253, but the end of the pin engages an inclined face 255 formed on the rear side of the end of the arm, and 70 moves the arm forwardly away from the carrier. As the lower end of the carrier is swung to the right immediately after the engagement of the members of the slow speed clutch through the action of the cam 75 groove 213 on the cam roll 215, the movement of the carrier carries the projection 251 beyond the end of the arm 245 and the arm is then swung rearwardly into position 80 to engage the left side of the projection. As 85 the lower end of the carrier 137 is swung back to the left the lever 239 will be swung to the left through the engagement of the projection 251 with the end of the arm 245. This movement of the lever effects the setting of the brake. The central portion or hub of the arm 245 is provided with an abutment face 257 for engagement with an arm 259 carried by a brake actuating ring 261 surrounding the sewing cam shaft 22. The 90 ring is pivoted upon an eccentric pin 263, and is formed with oppositely projecting lugs 265 which engage in recesses 267 in a brake disk 269 carried by a sleeve 271 mounted on the sewing cam shaft to slide longitudinally of the shaft but held from rotation with the shaft. The brake disk and the sleeve are held from rotation with the sewing cam shaft by the engagement of the lugs 265 on the ring 261 in the recesses 267 95 in the brake disk. The lugs 265 are formed with curved abutment faces 273 for engagement with the inner faces 275 of the recesses in the brake disk. The brake disk 269 is provided with a facing of friction mate- 100 105 110 115 120 125 130

rial 277 for engagement with a brake surface 279 formed on the cam disk 48. The sleeve 271 is normally held in position on the shaft 22 to maintain the brake disk 269 out of engagement with the brake surface 279 of the cam disk 48, by means of an annular leaf spring 281 interposed between one end of the bearing 275^a and a ring or collar 283 threaded upon the end of the sleeve. As the lever 239 is swung to the left at the time of the disengagement of the slow speed clutch in the manner above described, the abutment face 257 on the arm 241 engages the arm 259 on the brake actuating ring 261, and turns said ring about the eccentric pin 263 upon which it is pivoted, thereby causing the ring to move the brake disk 269 into engagement with the brake surface 279 of the cam disk 48 to arrest the rotation of the sewing cam shaft. By the adjustment of the eccentric pin 263 upon which the brake actuating ring is pivoted, the position of said ring may be regulated so as to produce the required action between the members of the brake to stop the rotation of the sewing cam shaft quickly and efficiently at the predetermined point in the rotation of the shaft.

The mechanism for disengaging the latch 171 from the catch 175 upon the completion 30 of the sewing of the shoe will now be described (see Figs. 4, 8, 45, 46, 47, 48 and 51). The latch 171 is formed with an arm 285 having at its end a socket 287 which is adapted to receive the spherical end 289 of a rod 291 mounted in a hollow cylinder 293. Surrounding the rod 291 within the cylinder 293 is a coiled spring 295 interposed between the end wall of the cylinder and a shoulder 297 on the rod. The movement 35 of the rod 291 under the influence of the coiled spring 295 is limited by the engagement of a washer 299 held by a nut 301 threaded on the outer end of the rod with the end of the cylinder 293. Pivottally connected with the cylinder 293, by means of a pin 303, is a block 305 formed with an upwardly projecting stud 307 by which the block is pivottally connected with the outer end of an arm 309 pivoted to turn loosely 40 on a rock shaft 311 mounted in a bearing in the frame of the machine. An arm 313 is fixed to the upper end of the rock shaft 311 and is adapted to engage a boss 311^a on the arm 309. To the lower end of the rock shaft 311 is secured an arm 315, the outer end of which is pivottally connected at 317 with one end of a link 319. The other end of the link 319 is pivottally connected at 321 with one end of a link 323, the other end of which is pivottally connected at 325 with the outer end of an arm 327, secured to the rock shaft 329, mounted in a bearing 331 in the frame. To the lower end of the rock shaft 329 are secured two actuating arms 333 and 335. The arm 333 is arranged above the arm 335

and carries a cam roll 337 for engagement with a cam rise 347 formed on the upper half of the periphery of the cam disk 352, and the arm 335 carries a cam roll 339 for engagement with another cam rise 345 formed on the lower half of the periphery of the cam disk 352. The position of the pivotally connected links 319 and 323 is controlled by means of a link 341 pivotally connected at one end with the link 323, and at its other end with an arm 343 on the lever 716, which is actuated by the operator in changing from a right shoe to a left, or from a left to a right to shift the position of the cam disk 914 and to reverse the direction of rotation of the pattern cam shaft. When a right shoe is being sewn, the arm 343, the link 341, and the pivotally connected links 323 and 319 controlled thereby are located substantially in the positions shown in Figs. 8, 45 and 47. With the parts adjusted as shown in these figures, the latch 171 is disengaged from the catch 175 by the movement of the arm 335 produced by the action of the peripheral cam rise 345 on the cam disk 352 on the cam roll 339. Fig. 47 shows the positions of the parts after the actuation of the arm 335 by the cam rise 345. By the action of this rise on the cam roll 339, the arm 335 is swung forwardly, and the arm 327 is swung to the right. By this movement of the arm 327 through the links 323 and 319, the arm 315 attached to the lower end of the rock shaft 311, and the arm 313 attached to the upper end of said rock shaft, are swung forwardly. During the forward swinging movement of the arm 313, said arm engages the boss 311^a on the arm 309 and swings the latter arm forwardly, and through the connection between the arm 309 and the latch 171, the latch 171 is actuated to disengage its acting end from the catch 175. When a left shoe is being sewn, the arm 343, link 341, and pivotally connected links 323 and 319 are located in the positions shown in Figs. 46 and 48. With these parts adjusted as shown in these figures, the latch 171 is disengaged from the catch 175 by the movement of the arm 333 produced by the action of the peripheral cam rise 347 on the cam disk 352 on the cam roll 337. By the action of this cam rise on the cam roll 337, the arm 333 is swung forwardly, and the arm 327 is swung to the left. Fig. 48 shows the positions of the parts after the actuation of the arm 333 by the cam rise 347. The movement of the arm 327 to the left through the links 323 and 319 on account of the positions of these links will swing the arm 315 and the arm 313 forwardly as before, to actuate the arm 309, to disengage the acting end of the latch on the catch. The shifting of the links 319 and 323 from one position to the other in changing from a right to a left shoe; or from a

left shoe to a right, is produced by the movement of the arm 343 when the lever 716 is actuated to shift the cam disk 914, and to reverse the direction of rotation of the pattern cam shaft.

Through the mechanism described, the machine is stopped at the predetermined point in the sewing of the seam chosen for the completion of the seam. This point is 10 obviously determined by the position of the rise 345 on the cam disk 352 when a right shoe is being sewn, or by the position of the rise 347 on the cam disk when a left shoe is being sewn.

15 When the sewing operation is completed, and the action of the machine is thus arrested, the operator unjacks the shoe, severs the needle and shuttle threads, and removes the shoe from the machine. Before another 20 shoe can be sewn on the machine, the jack, which during the sewing operation has been turned upon its axis substantially half a revolution, and lies with its toe rest to the left of the sewing point, must be turned to 25 its initial starting position. This is done by throwing into action a driving mechanism which drives the pattern cam shaft independently of the sewing cam shaft until the pattern cam shaft has described substantially a complete revolution from the point at which it started at the beginning 30 of the sewing of the seam. In the construction shown (see Figs. 4, 5 and 8) this mechanism comprises a roll clutch, the driving member of which, indicated at 349, is keyed to a reduced portion of the shaft 136, as is shown clearly in Fig. 4. This member is formed with a circular flange 351 within 35 which projects the upper end of the driven member 353 of the clutch. The driven member 40 of the clutch consists of a sleeve journaled upon a bushing 355 fixed to the reduced lower end of the shaft 136. The driven member of the clutch is formed at 45 its upper end with a series of flat faces indicated at 357, between which and the inner face of the flange 351 on the driving member of the clutch are located a series 50 of clutch rolls 359. The position of the clutch rolls 359 relative to the flat faces 357 on the driven member of the clutch is controlled by a clutch controlling sleeve 361 mounted to turn upon the exterior of the driven member of the clutch, and having a 55 series of spaced projections 363 between which the clutch rolls 359 are placed. The clutch controlling sleeve 361 is acted upon by a coiled spring 365, attached at one end to a pin 367 mounted in the driven clutch member, and at the other to a pin 369 mounted in the clutch controlling sleeve 361. This spring tends to turn the clutch controlling sleeve in a right hand direction (Figs. 5 and 8) relative to the driven member 60 of the clutch to cause the clutch rolls 359 to wedge between the flat faces 357 on the driven clutch member and the inner surface of the flange 351 on the driving member of the clutch to clutch the driven member to the driving member. When the 70 clutch controlling sleeve is free to turn under the action of the spring, it will cause the engagement of the clutch. The devices for controlling the position of the clutch controlling sleeve 361 relative to the driven 75 member of the clutch comprise a lever 371 pivoted at 373 upon a ring 375 mounted upon the exterior of the clutch controlling member and of the driven member of the clutch. The ring 375 has a projection 377 formed thereon, which is engaged on one side by a plunger 379 mounted in a suitable bore in the frame, and actuated by a spring 381, and on the other by a set screw 383 threaded into the frame. The ring is thus 80 held in position on the clutch, but is permitted to yield slightly in one direction. The lever 371 is formed with a cam-shaped inner end adapted to engage the exterior of the clutch controlling sleeve 361, as shown 85 in Fig. 8, to hold said sleeve from turning movement. In throwing the clutch into operation, the lever 371 is swung about its connection with the ring 375 to disengage 90 its inner end from the exterior of the sleeve 361, allowing the latter sleeve to turn relatively to the driven member of the clutch under the action of the coiled spring 365. The clutch will thus be engaged, and the member 353 of the clutch will be driven in 95 the direction indicated by the arrows in Figs. 5 and 8, by the driving member 349 of the clutch. To cause the disengagement of the clutch, the lever 371 is swung in the opposite direction about its connection with the ring 375 to re-engage the cam-shaped inner end of the lever with the exterior of the clutch-controlling sleeve. The engagement of the inner end of the lever 371 with the sleeve 361 will arrest the rotation of 100 the clutch controlling sleeve, while the rotation of the driven member of the clutch will continue until the rolls 359 are released from wedging engagement between the flat faces 357 on the driven member 353 of the 105 clutch and the inner face of the flange 351 on the driving member 349, thus causing the disengagement of the clutch. This rotary movement of the driven member of the clutch while the clutch controlling sleeve 110 361 is held from rotation, stretches the spring 365, and in order to prevent the driven member of the clutch from turning backwardly under the influence of the spring after its rotation in a forward direction ceases, a recoil dog is provided. This dog 115 consists of a ball 387 mounted in an inclined bore 389 in the ring 375 leading to the outer surface of the driven clutch member.

120 The inclination of the bore 389 relative to 130

the outer surface of the driven clutch member is such that when the ball is located in the forward end of the bore it will bind between the outer face of the bore and the outer surface of the driven clutch member. The ball is acted upon by a coiled spring 391 interposed between the ball and a screw 393 threaded into the outer end of the bore, which spring tends to force the ball into the forward end of the bore or into clutching engagement with the outer surface of the driven clutch member. This arrangement of the recoil dog will thus prevent any reverse rotation of the driven clutch member under the action of the spring 365. The lower end of the driven member 353 of the roll clutch is formed with a series of inclined clutch teeth 395 facing in the direction of rotation of the clutch. The clutch teeth are adapted to be engaged by one end of a clutch pawl 397 arranged diametrically of the clutch member 353, and having a spherical bearing end 399 having a bearing in a bore 401 in a flange 403 formed on the upper end of the shaft 700. The pawl 397 is engaged by the upper end of a pin 405 mounted in a bore in the shaft 700, and acted upon by a coiled spring 407 which tends to hold the acting end of the pawl in engagement with the ratchet teeth 395. To the lower end of the shaft 700 is secured the bevel gear 698 which forms the driving connection between the gears 694 and 696, as hereinbefore described. During the sewing operation, the roll clutch then being disengaged, the end of the pawl 397 passes idly over the teeth on the lower end of the clutch member 353, as the gear 698 and the shaft 700 to which it is secured are rotated. After the machine has been stopped at the completion of the sewing operation, and the shoe has been removed from the jack, the operator throws the roll clutch into operation. The member 353 of the clutch is then driven in the direction of the arrow, (Figs. 5 and 8), and through the engagement of the end of the pawl 397 with the teeth 395 on the lower end of the clutch member 353, the shaft 700 and the gear 698 are driven in the same direction as they are driven during the sewing operation, but at a very much higher speed; since they are clutched directly to the counter shaft, 136. The pattern cam shaft, through the operative connections between said gear 698 and the shaft, will be driven at a relatively high speed in the same direction as during the sewing operation, until the jack is located again in its initial or starting position. When the jack has been returned to its initial position, the roll clutch is automatically disengaged to arrest the rotation of the pattern cam shaft. The lever 371 is actuated and controlled to cause the engagement and disengagement of the roll clutch as above described by the following

mechanism. Pivotedly connected at 409 to the outer end of the lever 371, and arranged to operate in a guide 409^a, Fig. 40, is an arm 411, the forward end of which is adapted to engage the rear side of an arm 413 fixed to a stud 415 mounted in turn in a bearing in the frame of the machine. With the forward end of the arm 411 engaged with the arm 413, the lever 371 is held in position with the inner cam shaped end of the lever 75 engaged with the flange 385 on the sleeve 361. To the stud 415 which carries the arm 413 is secured an operating handle 417, by which the arm 413 may be turned to disengage it from the end of the arm 411. The arm 413 is yieldingly held in position in front of the end of the arm 411 by means of a coiled spring 419. The arm 411 is formed with a projection 421 which is engaged by the forward end of a plunger 423 mounted in a suitable bore in the frame of the machine, and acted upon by a coiled spring 425. To throw the roll clutch into operation, the operator turns the operating handle 417 to swing the arm 413 out of engagement with the end of the arm 411. After the arm 411 is thus released it is moved forwardly by the action of the plunger 423, and the lever 371 is swung forwardly about its pivotal connection with the ring 375 to disengage its 95 inner end from the flange on the sleeve 361. This causes the roll clutch to be thrown into operation in the manner previously described. In order to actuate the lever 371 to engage its inner end with the flange on the 100 clutch controlling sleeve 361, and thus throw the roll clutch out of operation when the cam shaft has been turned to starting position, the arm 313 fixed to the upper end of the shaft 311 is arranged to engage a 105 shoulder 429 formed on the arm 411. As the pattern cam shaft arrives at its initial or starting position, the arm 313 is swung rearwardly, and through its engagement with the shoulder 429 it actuates the arm 411 and the 110 lever 371 to cause the inner end of the lever to engage the flange on the clutch controlling sleeve 361 to throw the roll clutch out of operation. With the parts adjusted for sewing a right shoe, as shown in Figs. 8, 45, 115 and 47, this movement of the arm 313 is produced by the engagement of the rise 347 on the periphery of the cam disk 352 upon the cam roll 337 carried by the arm 333. With the parts adjusted as shown in these 120 figures, the forward movement of the arm 333 produced by the action of the cam rise 347 on the roll 337, through the connections described between the arm 333 and the arm 315, swings the latter arm rearwardly and 125 turns the rock shaft 311 to swing the arm 313 rearwardly to throw out the roll clutch. Fig. 45 shows the positions of certain of the parts after the actuation of the arm 333 by the cam rise 347. 130

With the parts adjusted for sewing a left shoe, as shown in Figs. 46 and 48, this movement of the arm 313 is produced by the action of the cam rise 345 on the periphery 5 of the cam disk 352 upon the cam roll 339 carried by the arm 335. With the parts adjusted as shown in these figures, the forward movement of the arm 335 produced by the action of the rise 345 on the roll 339 10 swings the arm 315 rearwardly and turns the rock shaft 311 to swing the arm 313 rearwardly to throw out the roll clutch. Fig. 46 shows the positions of certain of the parts after the actuation of the arm 335 by 15 the cam rise 345. As the arm 411 is moved rearwardly by the action of the arm 313 thereon, the latch arm 413 is swung in front of the forward end of the arm 411 to retain said arm and the lever 371 in position.

20 While the pattern cam shaft is being rotated to turn the jack back to starting position, the retaining pawls 510 and 556 are thrown out of engagement respectively with the teeth on the peripheries of the clutch members 506 and 552, allowing the clutch members to turn and the pulleys 402^a and 404^a to move to give up slack to the cables 398^a and 400^a, so that the cables will not interfere with the turning of the jack spindle. 25 The retaining pawls are thrown out (see Fig. 24) by means of a lever 431 pivoted at 433, and having an arm 435 formed with a lateral projection 437 arranged to engage the projections or shoulders 439 formed on the pawls. The other arm 441 of the lever carries a roll 443 for engagement with the side of the lever 540. The cam 548 is so formed as to actuate the lever 540 and thereby the lever 431 to throw out the retaining pawls 510 and 556 while the pattern cam shaft is rotating to turn the jack back to starting position, and to allow the springs 514 and 560 to throw in the pawls when the jack is restored to starting position. In order to retard the rotation of the clutch members 506 and 552 when the retaining pawls are thrown out, spring-pressed brake plungers 445 and 447 are arranged to engage respectively smooth portions of the peripheries 30 of the clutch members.

The locking mechanism for locking the lever 958 in position during the sewing of a seam, and for unlocking the same so as to permit the lever to be adjusted for the size 35 of the shoe to be sewn when the shoe is placed in position in the machine to start the seam, is constructed and arranged to hold the lever locked in position, after the machine is stopped by the disengagement 40 of the latch 171 from the catch 175 during or at the completion of the sewing operation, and to unlock the lever as the roll clutch is thrown into operation to rotate the pattern cam shaft to turn the jack to starting position. The lever is in this man-

ner maintained in locked condition so that it cannot be displaced when the machine is stopped at any point intermediate the beginning and the end of the seam. The locking mechanism for the lever (see Figs. 3, 8, 42, 43 and 52) comprises a rod 449 pivotally connected at 451 with the lever 958, and arranged to slide through a sleeve 453 pivoted upon a stud 455 upon the frame of the machine. The sleeve 453 carries a pair of locking levers 457 pivoted upon the sleeve by means of pivot studs 459 and having eccentric or cam-shaped inner ends arranged to engage the rod 449, as shown in Fig. 52. Pins 461 are fixed in the outer ends respectively of the locking levers, and engage in slots in the opposite ends of a cross bar 463. The cross bar 463 is connected by a link 465 with the arm 467 of a lever 469 pivoted upon a boss formed on the hub of the lever 127, 45 as shown in Fig. 43. The lever 469 is provided with a second arm 471 arranged to be engaged by the boss 471^a at the end of the arm 125 during the swinging movement of the carrier 137 imparted thereto in starting 50 the machine. The link 465 has a yielding connection with the cross-bar 463. To this end the end of the link adjacent the cross-bar has a sliding engagement in a sleeve 471^b (see Fig. 60) pivotally connected with 55 the cross-bar, and a spring 471^c coiled about the link within a chamber in the sleeve is interposed between the end wall of the chamber and a nut 471^d is threaded on the link. As the machine is started, the lever 127 60 will thus be swung with the lever 127 in a direction to carry the arm 467 of the lever 469 to the left, Fig. 42. This movement of the arm 467 of the lever 469, through the link 465 and the cross-bar 463, 65 will actuate the locking levers 457 to cause them to engage the rod 449 and lock the same from longitudinal movement in the sleeve 453, thereby locking the lever 958 in 70 position. In order to hold the lever 469 from swinging in the opposite direction and unlocking the lever 958 when the machine is stopped upon the disengagement of the latch 171 from the catch 175, a latch pin 473 75 is mounted in the frame in position to engage the inturned end portion of the arm 471 of the lever. A collar 475 is secured to the rear end of the latch pin, and the forward end of the latch pin passes through a sleeve 477 arranged to slide in the bore in 80 the frame in which the pin is mounted. Interposed between the collar 475 and the sleeve 477 is a coiled spring 479 for actuating the latch pin. The movement of the latch pin under the action of the coiled 85 spring 479 is limited by the engagement of a head 481 formed on the forward end of the pin with the forward end of the sleeve 477. The position of the sleeve in the bore 90 in which it is mounted is controlled by the 95

plunger 423, and to this end the sleeve is formed with a flange 483 engaging in a groove 485 in the plunger. When the machine is at rest with the parts in position 5 for starting the sewing of a shoe, the end of the arm 471 of the lever 469 engages the end of the latch pin 473, as shown in Figs. 8 and 42. The plunger 423 is then retracted through its engagement with the projection 10 421, as shown in Fig. 8, and the sleeve 477 is retracted out of engagement with the head 481 of the latch pin.

As the carrier 137 is swung upon its axis in starting the machine, the arm 471 of the 15 lever 569, through the engagement of the boss 471^a on the arm 125 therewith, is swung to the right, Fig. 42, a distance sufficient to carry its end beyond the end of the latch pin 473. The latch pin then is actuated by 20 the spring 479 to project the pin beyond the end of the arm 471 upon the left side of the arm (Fig. 42). Through the engagement of the latch pin with the side of the arm 471, the lever 469 is held from return 25 movement as the carrier 137 swings back to its initial position, when the machine is stopped upon the disengagement of the latch 171 from the catch 175. As the arm 413 is released from engagement with the forward 30 end of the arm 411 by the operator to throw the roll clutch into operation, the advance of the plunger 423 carries forward the sleeve 477, and after the sleeve engages the head of the latch pin 473 the latch pin is moved forwardly, thereby withdrawing the rear end of 35 the latch pin from engagement with the arm 471 and allowing the lever 469 to swing back to its starting position. This movement of the lever 469 releases the locking levers 457 from engagement with the rod 449, thereby 40 unlocking the rod and the lever 958. As the arm 411 is moved rearwardly by the arm 313 to throw the roll clutch out of operation, the plunger 423 is retracted and carries the sleeve 477 rearwardly therewith. The end of the arm 471 then lies immediately 45 behind the rear end of the latch pin 473, so that the movement of the sleeve merely compresses the coiled spring 479.

50 The locking mechanism for locking the rod 870 from longitudinal movement while the machine is at rest (see Figs. 42 and 44) comprises a lever 487 secured to one end of a rock shaft 489, and a link 491 connecting the upper end of the lever with an arm 493 on the lever 127. The lever 487 is formed with a laterally extending arm 495 provided adjacent its end with spaced flanges or ribs 497 adapted to receive between them a pin 499 mounted on a plate 501 clamped to the rod 870 by means of a clamping plate 503 and a series of clamping screws 505. The lower portions of the ribs 497 are inclined to each other so as to form an enlarged flaring 55 entrance to the passage or guideway between

the ribs, while the upper portions of the ribs are substantially parallel and spaced apart a distance substantially the same as the diameter of the pin 499. During the sewing operation the position of the lever 70 487 is such that the end of the arm lies above the pin 499, the pin then being disengaged from between the ribs 497 so that the rod 870 is free to move longitudinally. As the machine is stopped at the end of the sewing 75 operation, the movement of the carrier 137 swings the lever 487 substantially into the position shown in Fig. 42. During this movement of the lever 487, the pin 499 is engaged between the upper portions of the 80 ribs 497. The upper portions of the ribs are located so that when the pin is engaged between them the rod 870 will lie substantially in its central or neutral position, with the center of the pivotal connection substantially in line with the axis of the hanger 998. In case the rod is not in neutral position when the lever 487 is actuated, it will be moved to such position through the engagement of the pin 499 with the inclined 85 portion of one or the other of the ribs 497 at the entrance to the passage between the ribs during the downward movement of the arm 495. When the machine is started, the swinging of the carrier will actuate the 90 lever 487 to restore the arm 495 to its normal position, thereby disengaging the pin 499 from between the ribs 497 and unlocking the rod 870.

The tension mechanism of the machine 100 (see Fig. 42) comprises a tension wheel about which the thread passes on its way from the supply to the sewing point, and devices to control the rotation of the tension wheel to place the thread under a substantially constant tension during the sewing operation, and to relieve the thread of tension when the machine is stopped at the completion of a seam so that the thread may be drawn freely from the supply as the shoe 110 is removed from the machine. The tension wheel consists of two sheet metal disks 507 placed side by side and having oppositely bent interengaging peripheral projections for engaging the thread. These disks are 115 clamped between the disks 509 fixed upon a sleeve 511 journaled upon an enlargement 513 formed on a shaft 515 secured at one end in the machine frame. The disks 509 are recessed to receive the friction washers 517. The friction washers are engaged by friction disks 519 and 521 mounted on the shaft 515, and held from rotation on the shaft by means of a pin 523 passing through the enlargement 513 and having its ends engaged in the disks. The friction disk 521 is formed upon one end of a sleeve 525, upon which is mounted a collar 527 having a threaded engagement with the sleeve and a second sleeve 529 free to slide longitudi- 125 130

nally of the sleeve 525. Interposed between a flange on the collar 527 and a flange on the sleeve 529 is a coiled spring 531. The movement of the sleeve 529 on the sleeve 525 is limited by the engagement of a ring 533 embedded in a groove in the sleeve 525, with a shoulder 535 on the sleeve 529. The outer end of the sleeve 529 is engaged by a flange 537 on a sleeve 539 mounted to slide 10 on the end of the shaft 515. A rod 541 is slidably engaged at one end in the outer end of the bore in the sleeve 539 and at its opposite end is threaded into a block 543, pivoted by means of a stud 543^a to an arm 15 545 secured to the forward end of the rock shaft 489. The rod 541 is formed with an enlargement 547 arranged to engage the outer end of the sleeve 539. Interposed between a collar 549 on the rod 541 and the 20 flange 537 on the sleeve 539 is a coiled spring 551, the strength of which is very slight as compared with that of the coiled spring 531. The parts are shown in the drawings in the positions which they assume when the 25 tension is released. It will be noted that the enlargement 547 is disengaged from the outer end of the sleeve 539, and that the shoulder 535 on the sleeve 529 rests against the ring 533. The coiled spring 531 is, 30 therefore, inactive and the friction disks 519 and 521 are held together or are engaged with the friction washers 517 only by the force of the spring 551. This spring is preferably so light that the force exerted 35 thereby is only sufficient to hold the parts in position, so that the friction disks 519 and 521 furnish very little frictional resistance to the turning of the tension wheel. When the lever 487 is swung upon its axis 40 upon starting the machine, the light spring 551 is first compressed and the enlargement 547 is engaged with the end of the sleeve 539, after which the sleeve 539 and the sleeve 529 engaged thereby are moved longitudinally of the shaft 515. This movement of 45 the sleeve 529 compresses the coiled spring 531 which, acting on the sleeve 525, tends to force the friction disk 521 toward the friction disk 519. Thus during the sewing 50 operation the rotation of the tension wheel is resisted by the frictional action of the friction disks 519 and 521 on the friction washers 517, produced by the action of the coiled spring 531. The force exerted by the 55 coiled spring 531 may be regulated by adjusting the collar 527 on the sleeve 525. When the lever 487 is swung back to the position shown in the drawings upon the 60 stopping of the machine at the completion of the sewing of a seam, the spring 531 moves the sleeve 529 outwardly on the sleeve 525 until the shoulder 535 on the sleeve 529 engages the ring 533, rendering the coiled spring 531 inactive, after which 65 the enlargement 547 is disengaged from the end of the sleeve 539.

The present machine is also provided with mechanism for automatically unlocking and lifting the presser foot upon stopping the machine at the completion of the 70 seam, so that the work may be readily removed from the machine (see Figs. 4, 6, 7, 49 and 59). The machine is stopped at a point in a cycle of operations when the 75 needle and awl are both retracted out of engagement with the work, and the thread is released or unlocked by the thread locking device so that it can be drawn freely from the supply. At this point in a cycle the 80 presser foot is locked in work engaging position by the engagement of the pawls 98 and 112 with the teeth on the rear end of the arm 86 and on the rear end of the presser foot lever. The pawls 98 and 112 are disengaged from the teeth on the rear end of the arm 86 and on the rear end of the presser foot lever to unlock the presser foot to permit the presser foot to be lifted by means of a pawl disengaging lever 553 pivoted upon the stud 80 and provided with rearwardly extending projections 555 and 557 adapted to engage pins 559 and 561 mounted respectively on the pawls 98 and 112. The 85 projections 555 and 557 are formed respectively with inclined faces 563 and 565 for engaging the pins to throw out the pawls during the pawl disengaging movement of the lever 553, and with stop faces 563^a and 565^a for engaging the pins to limit the movement of the lever. The lever 553 is provided 90 with an operating arm 567, and a lifting arm 569 is rigidly mounted upon the presser foot lever immediately in front of the arm 567. A lever 571 is pivoted upon a stud 573 upon the arm 567 of the pawl disengaging or unlocking lever 553, and is formed with a forwardly extending curved arm 575, the rear side of the forward end of which is arranged to engage a pin 577 mounted upon the lifting arm 569 secured to the presser foot lever. The lever 571 is formed with a downwardly extending arm 579, connected by a link 581 with an arm 583 fixed to one end of the rock shaft 585. To the opposite end of the rock shaft is secured an arm 587 having at its outer end a socket to receive one end of a ball-ended link 589. The other end of the link is received in a socket in the arm 591 on the lever 239. As 100 the lever 239 is swung to the left, Figs. 6 and 49, by the action of the carrier 137 upon the stopping of the machine, through the connection of the said lever with the rock shaft 585, the rock shaft is turned in a direction to swing the arm 583 forwardly. During the first part of the forward swinging movement of the arm 583, the arm 567 of 105 the unlocking lever 553 is swung forward- 110

115

120

125

ly by the forward thrust of the link 581, the swinging of the lever 571 upon the stud 573 being limited by the engagement of the arm 575 of the lever with the pin 577. The unlocking lever is thus actuated to disengage the pawls 98 and 112 from the teeth on the rear ends of the arm 86 and of the presser foot lever. When the movement of the unlocking lever is stopped by the engagement 10 of the faces 563^a and 565^a formed on the projections 555 and 557 on the lever with the pins 559 and 561, the lever 571 is swung about the stud 573, and through the engagement 15 of the curved upper side of the arm 575 with the pin 577 the presser foot is lifted from the work.

The present machine is also provided with mechanism for stopping the machine automatically when the needle thread breaks. In 20 the present construction (see Figs. 7 and 8) the auxiliary takeup arm or lever 56^a is formed with a downwardly extending arm 593 upon which is mounted a laterally extending pin 595 passing through a slot 597 in the frame of the machine. The pin 595 is arranged to be engaged by the forwardly facing end of one arm of the lever 599, pivoted on the stud 601. Upon the other arm of the lever 599 is mounted a pin 603 25 adapted to be engaged by the end of an arm 605 secured to the forwardly extending arm on the feed slide actuating lever 42. During the stitch setting stroke of the takeup, the auxiliary takeup lever 56^a is swung downwardly by the pull on the thread, and the pin 595 engages the lever 599 and swings the lever substantially into the position shown in Fig. 8. As the lever 42 is actuated to advance 30 the feed slide, the end of the arm 605 engages the pin 603 and swings the lever 599 in the opposite direction into position to be again engaged by the pin 595. In order to hold the lever 599 either in the position in which it is placed by the action of the pin 595 thereon, or in the position in which it is placed by the action of the arm 605 on the pin 603, a retaining pin 607, actuated by a spring 609, is mounted in the frame of the machine beneath the lever 599, and is 35 provided with a pointed upper end adapted to engage in either of the recesses 611 and 613 formed in the lever. The arm 605 is formed with a projection 615 arranged to engage a shoulder 617 upon an arm 619 pivoted at 621 to the outer end of an arm 623 loosely pivoted on the shaft 311, and having its hub secured to and preferably integral with the hub of the arm 309. The arm 619 is acted upon by a coiled spring 625 40 attached at one end to a pin 627 secured in the arm, and at the other to the frame of the machine, which tends to swing the arm 619 about its pivotal connection with the arm 623 in a direction to carry the shoulder 617

in front of the projection 615. Upon the 65 end of the arm 619 is mounted a pin 629 adapted to engage the lever 599 to limit the movement of the arm 619 under the action of the coiled spring 625. The parts are so constructed and arranged that with the lever 70 599 in the position shown in Fig. 8, the arm 619 is prevented from swinging rearwardly far enough to carry the shoulder 617 into position to be engaged by the forward side of the projection 615 by the engagement of the 75 end of the pin 629 with the lever.

The parts are shown in Fig. 8 in the position which they assume at a point in a cycle of operation just before the feed slide has completed its retracting stroke. It will be 80 noted that the projection 615 has not cleared the shoulder 617, and that the arm 619 is held out of contact with the end of the projection by the engagement of the end of the pin 629 with the lever 599. Starting with the parts 85 in the positions shown in this figure, the parts have the following mode of operation during each cycle while the needle thread is unbroken. As the forward arm of the lever 42 swings to the right to complete the 90 retracting stroke of the feed slide, the projection 615 clears the shoulder 617. During this movement of the lever 42, and as the forward arm of the lever swings to the left to advance the feed slide, the lever 599 remains in the position shown in this figure, and through its engagement with the end 95 of the pin 629, prevents the arm 619 from being swung rearwardly to carry the shoulder 617 in front of the forward side of the 100 projection 615. After the forward side of the projection has passed the shoulder, the arm 605 engages the pin 603 and swings the lever 599 into position to be engaged by the pin 595. The arm 619 then rests against the 105 end of the projection 615. As the forward arm of the lever 42 swings back to the right, the lever 599 is swung back into the position shown in Fig. 8 by the action of the auxiliary 110 takeup before the projection 615 clears the shoulder 617. In case the needle thread is broken at any point in the sewing of the seam, during the next succeeding stroke of the takeup the lever 599 is not engaged and moved by the pin 595, but is held by the retaining pin 607 in the position into which it is moved by the action of the arm 605 on the pin 603. With the lever 599 in this position, when the forward arm of the lever 42 swings to the right, after the projection 615 clears the shoulder 617, the arm 619 is swung rearwardly by the spring 625, carrying the shoulder in front of the forward side of the 115 projection. Then as the forward arm of the lever 42 swings to the left, the forward side of the projection 615 engages the shoulder 617, and the arm 619 is actuated to swing the arm 623 upon which it is pivoted, and 120 125

to swing the arm 309 to which the arm 623 is connected, in a direction to disengage the latch 171 from the catch 175.

Before again starting the sewing operation on a shoe the operator may, if he wishes, disengage the shoe from the sewing mechanism and cause a reverse rotation of the pattern cam shaft to any desired extent so as to permit starting the operation on the shoe back of the point at which the miss-stitch occurred or at the end of the last completed stitch. To do this he moves the jack manually towards the front of the machine to remove the shoe from the sewing mechanism, shifts the shaft 684 longitudinally to reverse the direction of rotation of the pattern cam shaft 248, throws the driving mechanism into operation and after one or more revolutions of the sewing cam shaft 20 operates the catch 175 to stop the machine.

It is found to be impracticable to sew shoes having wide variations in style with a single set of the cams on the pattern cam shaft, although shoes having a slight variation in style may be sewn. To enable different styles of shoes to be sewn upon the machine, the cams are mounted on the pattern cam shaft so that they can be removed and other cams substituted therefor in changing from one style of shoe to another. In the construction shown (see Figs. 36, 38 and 39) the pattern cam shaft is formed in three sections indicated at 631, 633 and 635. The uppermost section 631 is mounted in a bearing 637 in the frame, and is held from longitudinal movement therein by means of a flange 639 formed on the lower end of the shaft section, and engaging the lower end of the bearing and a nut 641 threaded upon the upper end of the shaft section and engaging the disk 916. The gear 682 is keyed to this shaft section. The lowermost section 635 is mounted in a step bearing 643. The shaft section 635 carries the cam disks 484 and 548. These disks are formed upon a sleeve 645 mounted upon the cylindrical upper end of the shaft section 635, and held between a shoulder 647a on the shaft section and the cam disk 246. The central shaft section 633 is held in place between the shaft sections 631 and 635 by means of a rod 647 passing centrally through the shaft sections. This rod has a collar 649 mounted thereon adjacent its upper end for engagement with the upper end of the shaft section 631 to limit the downward movement of the rod. The shaft section 633 carries the cam disks 352 and 246 which are removably mounted thereon, and the cam disk 624 which is formed integral therewith.

The cam disk 352 is removably mounted on the cylindrical upper end of the shaft section 633, and is held between a shoulder 651 on the shaft section and the flange 639 on the shaft section 631. The cam disk

352 is held from turning movement relative to the shaft section 633 by means of a pin 653 mounted in an arm 655 projecting from the shaft section and engaging in an opening in the cam disk. The cam disk 352 is connected to rotate with the upper shaft section 631, and to this end is formed with a wedge-shaped boss or projection 657 engaging in the wedge-shaped recess between the projections 659 formed on the lower end of the shaft section 631. The cam disk 246 is removably mounted on the cylindrical lower end of the shaft section 633, and is held between a shoulder 661 on the shaft section and the sleeve 645. The cam disk 246 is held from turning movement relative to the shaft section 633 by means of a pin 663 mounted in an arm 665 projecting from the shaft section and engaging in an opening in the cam disk. The cam disks 484 and 548 are connected with the cam disk 246 to rotate therewith by means of a pin 667 mounted in the cam disk 246 and engaging in an opening in the cam disk 484.

With this construction, after withdrawing the rod 647 from the shaft sections 635 and 633, the shaft section 633, with the cam disks 352 and 246 may be removed from between the shaft sections 631 and 635 by moving the same rearwardly, Fig. 38. The cam disks 352 and 246 are provided with passageways 669 leading from the cam grooves to the peripheries of the disks through which the dam rolls engaging in the grooves can pass as the central shaft section is removed. After the shaft section 633 is thus removed from between the shaft sections 631 and 635, the cam disks 352 and 246 may be removed from the shaft section 633 and other cam disks substituted therefor, or another shaft section having a cam disk corresponding to the cam disk 624, but of different shape, may be substituted for the central shaft section. The sleeve 645 may also be removed from the shaft section 635 and another sleeve having cam disks corresponding to the cam disks 484 and 548, but of different shape, may be placed on the shaft section 635 in place of the sleeve 645. After the central shaft section and the cam disks adapted to be mounted thereon are assembled, the shaft section and disks are replaced between the shaft sections 631 and 635 by moving the same forwardly between the shaft sections until the wedge shaped projections 657 on the cam disk 352 engages tightly between the projections 659 on the shaft section 631. The central shaft section is thus centered with relation to the shaft section 631. The rod 647 is then passed through the central shaft section 633 into the shaft section 635 to hold the central shaft section in position.

Certain features of the machine herein disclosed but not claimed, relating principally to the devices particularly adapted for use

in sewing machines, form the subject matter of a divisional application filed December 11, 1923, Serial No. 679,899.

While the invention has been illustrated and described in the present application as embodied in a machine for sewing outsoles to the welts of welted shoes, it is to be understood that except as defined in the claims the invention is not limited to any particular type or class of machines for operating upon shoes, but that the features thereof may be embodied in machines for performing various operations. It is also to be understood that the invention is not limited to the particular construction and arrangement of parts illustrated in the present application, but that it may be embodied in other forms within the scope of the claims.

Having explained the nature and object of the invention, and having specifically described a machine embodying the invention, in its preferred form, what is claimed is:

1. A machine for operating on shoes, having, in combination, means for operating on a shoe, a shoe supporting jack, means for feeding the shoe, mechanism for imparting relative movements to the operating means and jack in addition to those required to transfer the point of operation about the shoe to present the shoe properly to the operating means as the point of operation is transferred about the shoe timed for a predetermined relative rate of feed of the shoe, and mechanism for restoring said mechanism and the shoe to their proper time relations upon the occurrence of a variation from said predetermined relative rate of feed.

2. A machine for operating on shoes, having, in combination, means for operating on a shoe, a shoe supporting jack, means for feeding the shoe acting directly on the shoe, mechanism for imparting relative movements to the operating means and jack in addition to those required to transfer the point of operation about the shoe to present the shoe properly to the operating means as the point of operation is transferred about the shoe, and means for restoring said mechanism and the shoe to their proper time relations when said mechanism and the shoe are out of time.

3. A machine for operating on shoes, having, in combination, means for operating on a shoe, a shoe supporting jack, mechanism for imparting relative movements to the operating means and jack in addition to those required to transfer the point of operation about the shoe to present the shoe properly to the operating means as the point of operation is transferred about the shoe, and means for restoring said mechanism and the shoe to their proper time relations when said mechanism and the shoe are out of time.

4. A machine for operating on shoes, having, in combination, means for operating on a shoe, a shoe supporting jack, means for relatively feeding the shoe and the operating means to transfer the point of operation about the shoe, mechanism for imparting relative movements to the operating means and jack in addition to those required to transfer the point of operation about the shoe to present the shoe properly to the operating means as the point of operation is transferred about the shoe, and means for restoring said mechanism and the shoe to their proper time relations when said mechanism and the shoe are out of time.

5. A machine for operating on shoes, having, in combination, means for operating on a shoe, a shoe supporting jack, mechanism for changing the relative positions of the operating means and the jack to present the shoe properly to the operating means as the point of operation is transferred about the shoe, and means controlled from the shoe and acting automatically to restore said mechanism and the shoe to their proper time relations when said mechanism and the shoe are out of time.

6. A machine for operating on shoes, having, in combination, means for operating on a shoe, a shoe supporting jack, means for feeding the shoe, mechanism for changing the relative positions of the operating means and the jack to present the shoe properly to the operating means as the point of operation is transferred about the shoe, means adjustable for different sizes of shoes for relatively timing the shoe feeding means and said mechanism for the size of the shoe to be operated upon, and a connection between said timing means and the jack for effecting the proper adjustment of said timing means by the placing of the shoe in position in the machine for starting the operation.

7. A machine for operating on shoes, having, in combination, means for operating on a shoe, a shoe supporting jack, means for relatively feeding the shoe and the operating means to transfer the point of operation about the shoe, mechanism for imparting relative movements to the operating means and jack in addition to those required to transfer the point of operation about the shoe to present the shoe properly to the operating means as the point of operation is transferred about the shoe, means adjustable for different sizes of shoes for relatively timing said mechanism and the shoe feeding means for the size of the shoe to be operated upon, and means for restoring said mechanism and the shoe to their proper time relations when said mechanism and the shoe are out of time.

8. A machine for operating on shoes, having, in combination, means for operating on

a shoe, a shoe supporting jack, means for feeding the shoe acting directly on the shoe, mechanism for moving the jack to change the position of the shoe relative to the operating means to present the shoe properly to the operating means as the point of operation is transferred about the shoe, and means controlled from the jack and acting automatically to vary the relative speeds of the feeding means and said mechanism to restore said mechanism and the shoe to their proper time relations when said mechanism and the shoe are out of time.

means to present the shoe properly to the operating means as the point of operation is transferred about the shoe, means adjustable for different sizes of shoes for timing said mechanism for a predetermined relative rate of feed of the shoe, and means controlled from the jack and acting automatically to vary the relative speeds of the feeding means and said mechanism to restore said mechanism and the shoe to their proper time relations upon a variation from said predetermined rate of feed.

13. A machine for operating on shoes

15 9. A machine for operating on shoes, having, in combination, means for operating on a shoe, a shoe supporting jack, means for feeding the shoe, mechanism for imparting relative movements to the operating means and jack in addition to those required to transfer the point of operation about the shoe to present the shoe properly to the operating means as the point of operation is transferred about the shoe, and means for varying the relative speeds of the feeding means and said mechanism to restore said mechanism and the shoe to their proper time relations when said mechanism and the shoe are out of time.

10. A machine for operating on shoes, having, in combination, means for operating on a shoe, a shoe supporting jack, means for feeding the shoe, mechanism for changing the relative positions of the operating means and the jack to present the shoe properly to the operating means as the point of operation is transferred about the shoe, and means controlled from the jack and acting automatically to vary the relative speeds of the feeding means and said mechanism to restore said mechanism and the shoe to their proper time relation when said mechanism and the shoe are out of time.

for moving another point in the lever in timed relation to said mechanism, and devices controlled by the position of the lever for controlling the time relations of the feeding means and said mechanism.

14. A machine for operating on shoes, having in combination, means for operating on a shoe, a shoe supporting jack, means for feeding the shoe, mechanism for changing the relative positions of the operating means and the jack to present the shoe properly to the operating means as the point of operation is transferred about the shoe, means for controlling the time relations of the feeding

11. A machine for operating on shoes, having, in combination, means for operating on a shoe, a shoe supporting jack, means for feeding the shoe acting directly on the shoe, mechanism for moving the jack to change the position of the shoe relative to the operating means to present the shoe properly to the operating means as the point of operation is transferred about the shoe adapted to be timed for a predetermined relative rate of feed of the shoe, and means controlled from the jack and acting automatically to vary the relative speeds of the feeding means and said mechanism to restore said mechanism and the shoe to their proper time relations upon a variation from said predetermined rate of feed.

means and said mechanism acting to vary the time relation of said means and mechanism to restore said mechanism to its proper time relation to the shoe when said mechanism and the shoe are out of time, comprising a lever, a connection for moving one point in the lever in timed relation to the shoe, means for moving another point in the lever in timed relation to said mechanism constructed and arranged to cause a third point in the lever to remain in fixed position when said mechanism is in proper time relation with the shoe and to shift from such position when said mechanism and the shoe are out of time, and devices controlled from the third point in the lever for effecting a variation in the time relations of the feeding means

60 12. A machine for operating on shoes, having, in combination, means for operating on a shoe, a shoe supporting jack, means for feeding the shoe acting directly on the shoe, mechanism for moving the jack to change the position of the shoe relative to the operating and said mechanism upon a shift in the position of the third point in the lever. 125

65 13. A machine for operating on shoes, having in combination, means for operating on a shoe, a shoe supporting jack, means for feeding the shoe, mechanism for changing 130

the relative positions of the operating means and the jack to present the shoe properly to the operating means as the point of operation is transferred about the shoe, means for controlling the time relations of the feeding means and said mechanism acting to vary the time relations of said means and mechanism to restore said mechanism to its proper time relation to the shoe when said mechanism and the shoe are out of time, comprising, a lever, a connection for moving one point in the lever in timed relation to the shoe, a second lever connected with the first lever at another point therein, a pattern cam 10 for moving the second lever in timed relation to said mechanism, devices controlled by the position of the first lever for controlling the time relations of the feeding means and mechanism, and a variable fulcrum for the 15 second lever arranged to be adjusted for the size of the shoe to be sewn.

16. A machine for operating on shoes, having in combination, means for operating on a shoe, a shoe supporting jack, means for 25 feeding the shoe, mechanism for changing the relative positions of the operating means and the jack to present the shoe properly to the operating means as the point of operation is transferred about the shoe, a pivoted lever, 30 connections for regulating from the lever the time relations of the feeding means and said mechanism, and connections between the lever and the jack for adjusting the lever for the size of shoe to be operated upon by the 35 placing of the shoe in the machine in position to start the operation.

17. A machine for operating on shoes, having, in combination, means for operating on a shoe, a shoe supporting jack, means for 40 feeding the shoe, mechanism for imparting relative movements to the operating means and jack in addition to those required to transfer the point of operation about the shoe to present the shoe properly to the operating means as the point of operation is transferred about the shoe, means for regulating the time relations of the feeding means and said mechanism for the size 45 of shoe to be operated upon, and means for restoring said mechanism and the shoe to their proper time relations when said mechanism and the shoe are out of time.

18. A machine for operating on shoes, having, in combination, means for operating 55 on a shoe, a shoe supporting jack, means for feeding the shoe, mechanism for changing the relative positions of the operating means and the jack to present the shoe properly to the operating means as the point of operation is transferred about the shoe, means controlled from the shoe for regulating the time relations of the feeding means and said mechanism for the size of shoe to be operated upon, and means controlled from 60

the shoe for restoring said mechanism and the shoe to their proper time relations when said mechanism and the shoe are out of time. 65

19. A machine for operating on shoes, having, in combination, means for operating on a shoe, a shoe supporting jack, means for 70 feeding the shoe, mechanism for changing the relative positions of the operating means and the jack to present the shoe properly to the operating means as the point of operation is transferred about the shoe, means for controlling the time relations of the feeding means and said mechanism acting to vary the time relations of said means and mechanism to restore said mechanism to its proper time relation to the shoe when the shoe and said mechanism are out of time, comprising, a lever, a connection for moving one point in 75 said lever in timed relation to the jack, a second lever connected with the first lever at another point therein, means for moving the second lever in timed relation to said mechanism, devices controlled by the position of the first lever for controlling the time relations of the feeding means and said mechanism, a variable fulcrum for the second lever, 80 a third lever upon which said fulcrum is carried, and connections for controlling the time relations of the feeding means and said mechanism from the third lever, said third lever being adjustable for the size of shoe 85 operated upon by the placing of the shoe in operating position.

20. A machine for operating on shoes, having, in combination, means for operating on a shoe, a shoe supporting jack, positioning 100 mechanism for changing the relative positions of the operating means and the jack to present the shoe properly to the operating means as the point of operation is transferred about the shoe, detector mechanism 105 for detecting the time relations of the positioning mechanism and the shoe, and means controlled by the detector mechanism for restoring the positioning mechanism and the shoe to their proper time relations when said mechanism and the shoe are out of time. 110

21. A machine for operating on shoes, having, in combination, means for operating on a shoe, a shoe supporting jack, positioning mechanism for changing the relative positions of the operating means and the jack to present the shoe properly to the operating means as the point of operation is transferred about the shoe, detector mechanism 115 for detecting the time relations of the positioning mechanism and the shoe comprising a movable member, means for moving said member in timed relation to the positioning mechanism, a second movable member, means for moving the second member in timed relation to the shoe, and mechanism controlled by the relative positions of said members for restoring the positioning mech- 120 125

anism and the shoe to their proper time relations when said mechanism and the shoe are out of time.

22. A machine for operating upon shoes, having, in combination, means for operating on a shoe and a shoe supporting jack, mechanism for imparting movements to the jack in addition to those required to transfer the point of operation about the shoe 10 to present the shoe properly to the operating means as the point of operation is transferred about the shoe, yieldingly acting means tending to move the jack to maintain the shoe in operating position, and controlling means acting to cause variations in the tension exerted by said yieldingly acting means on the jack as the point of operation is transferred about the shoe.

23. A machine for operating upon shoes, 20 having, in combination, means for operating on a shoe, a shoe supporting jack, mechanism for moving the jack to change the relative positions of the shoe and the operating means to present the shoe properly to the 25 operating means as the point of operation is transferred about the shoe, yieldingly acting means tending to turn the jack in one direction, yieldingly acting means tending to turn the jack in the opposite direction, and 30 controlling mechanism acting to cause each of said yieldingly acting means to exert varying tensions predetermined for each point in the operation of the machine on the shoe.

24. A machine for operating upon shoes, 35 having, in combination, means for operating on a shoe and a shoe supporting jack, mechanism for imparting movements to the jack in addition to those required to transfer the point of operation about the shoe to present 40 the shoe properly to the operating means as the point of operation is transferred about the shoe, yieldingly acting means tending to move the jack to maintain the shoe in operating position, and controlling mechanism 45 for said yieldingly acting means acting to cause said means to exert a varying tension predetermined for each point in the operation of the machine on the shoe.

25. A machine for operating upon shoes, 50 having, in combination, means for operating on a shoe, shoe feeding means, a shoe supporting jack, mechanism for moving the jack to change the relative positions of the shoe and the operating means to present 55 the shoe properly to the operating means as the point of operation is transferred about the shoe, yieldingly acting means tending to move the jack to maintain the shoe in operating position, controlling mechanism for 60 said means acting to cause said means to exert a varying tension predetermined for each point in the operation of the machine on the shoe, said controlling means being timed for a predetermined feed of the shoe,

and means for restoring said means and the 65 shoe to their proper timed relation upon a variation from said predetermined feed.

26. A machine of the class described, having, in combination, mechanism for operating upon the work, work feeding means, 70 a work gage, means for moving the gage to vary the position of the work relative to the operating mechanism at predetermined points in the operation of the machine on the work timed for a predetermined feed 75 of the work, and mechanism for restoring said last means and the work to their proper timed relations upon a variation from said predetermined feed.

27. A machine of the class described, having, in combination, means for operating upon the work, means for feeding the work, means for adjusting the work feeding means to change the length of feed at predetermined points in the operation of the machine 80 on the work timed for a predetermined feed 85 of the work, and mechanism for restoring said last means and the work to their proper timed relations upon a variation from said predetermined feed.

28. A machine for operating upon shoes, having, in combination, means for operating on a shoe, a shoe supporting jack, positioning mechanism for changing the relative positions of the operating means and the 95 jack to present the shoe properly to the operating means as the point of operation is transferred about the shoe, mechanism for driving the operating means and the positioning mechanism during the operation on 100 the shoe, mechanism for driving the positioning mechanism independently of the operating means to bring the jack to starting position, means for automatically stopping the operating means and the positioning mechanism 105 at the completion of the operation on the shoe, and means for automatically stopping the positioning mechanism when the jack has been brought to starting position.

29. A machine for operating upon shoes, having, in combination, means for operating on a shoe, a shoe supporting jack, positioning mechanism for changing the relative positions of the operating means and the jack to present the shoe properly to the operating means as the point of operation is transferred about the shoe, mechanism for driving the operating means and the positioning mechanism during the operation on the shoe, 115 mechanism for driving the positioning mechanism independently of the operating means to bring the jack to starting position, devices under control of the operator for throwing in said driving mechanisms, means for automatically stopping the operating means and the positioning mechanism at the completion of the operation on the shoe, and 120 125

means for automatically stopping the positioning mechanism when the jack has been brought to starting position.

30. A machine of the class described, having, in combination, means for operating on the work, means for feeding the work, stopping mechanism for stopping the machine at a predetermined point in the operation of the machine on the work timed for a predetermined feed of the work, and means for restoring the stopping mechanism and the work to their proper timed relations upon a variation from said predetermined feed.

31. A machine for operating on shoes, having, in combination, means for operating on a shoe, means for feeding the shoe, a shoe supporting jack, mechanism for changing the relative positions of the operating means and the jack to present the shoe properly to the operating means as the point of operation is transferred about the shoe, stopping mechanism for stopping the machine at a predetermined point in the operation of the machine on the shoe timed for a predetermined feed of the shoe, and means for restoring the stopping mechanism and the shoe to their proper timed relations upon a variation from said predetermined feed.

32. A machine for operating on shoes, having, in combination, means for operating on a shoe, a shoe supporting jack, mechanism for relatively moving and guiding the shoe and operating means to transfer the point of operation along the shoe and maintain the edge of the shoe bottom in the proper position with relation to the operating means transversely of the direction of feed, mechanism for changing the relative positions of the operating means and the jack to present the shoe properly to the operating means as the point of operation is transferred about the shoe arranged to be driven in one direction when a right shoe is operated upon and in the opposite direction when a left shoe is operated upon, and means for driving said last mechanism in reverse directions.

33. A machine for operating upon shoes, having, in combination, means for operating on a shoe, a shoe supporting jack, mechanism for relatively moving and guiding the shoe and operating means to transfer the point of operation along the shoe and maintain the edge of the shoe bottom in the proper position with relation to the operating means transversely of the direction of feed, mechanism for changing the relative positions of the operating means and the jack to present the shoe properly to the operating means as the point of operation is transferred about the shoe comprising, a cam shaft, a series of cams mounted thereon, connections for moving relatively the operating means and the jack from the cams, and means for driving the cam shaft in one direction when operating upon a right shoe and in the opposite direction when operating upon a left shoe.

34. A machine for operating upon shoes, having, in combination, means for operating on a shoe, a shoe supporting jack, mechanism for relatively moving and guiding the shoe and, operating means to transfer the point of operation along the shoe and maintain the edge of the shoe bottom in the proper position with relation to the operating means transversely of the direction of feed, mechanism for changing the relative positions of the operating means and the jack to present the shoe properly to the operating means as the point of operation is transferred about the shoe comprising a cam shaft, a series of cams mounted thereon, and interchangeable connections for moving relatively the operating means and the jack from the cams arranged to be employed alternatively in operating upon right and left shoes.

35. A machine for operating upon shoes, having, in combination, means for operating on a shoe, a shoe supporting jack, mechanism for relatively moving and guiding the shoe and operating means to transfer the point of operation along the shoe and maintain the edge of the shoe bottom in the proper position with relation to the operating means transversely of the direction of feed, and mechanism for changing the relative positions of the operating means and the jack to present the shoe properly to the operating means as the point of operation is transferred about the shoe comprising a cam shaft, a series of cams mounted thereon, and interchangeable connections for moving relatively the operating means and the jack from the cams arranged to be employed alternatively in operating upon right and left shoes.

36. A machine for operating upon shoes, having, in combination, means for operating on a shoe, a shoe supporting jack, mechanism for relatively moving and guiding the shoe and operating means to transfer the point of operation along the shoe and maintain the edge of the shoe bottom in the proper position with relation to the operating means transversely of the direction of feed, mechanism for changing the relative positions of the operating means and the jack to present the shoe properly to the operating means as the point of operation is transferred about the shoe comprising interchangeable actuating devices arranged to be employed alternatively in operating upon different classes of shoes.

37. A machine for operating upon shoes, having, in combination, means for operating on a shoe, a shoe supporting jack, mechanism for relatively moving and guiding the shoe and operating means to transfer the point of operation along the shoe and maintain the edge of the shoe bottom in the proper position with relation to the operating means transversely of the direction of feed, mechanism for changing the relative positions of the operating means and the jack to present the shoe properly to the operating means as the point of operation is transferred about the shoe comprising a cam shaft, a series of cams mounted thereon, interchangeable connections for moving relatively the operating means and the jack from the cams arranged to be employed alternatively in operating upon right and left shoes, and means for driving the cam shaft in one direction when operating upon a right shoe and in the opposite direction when operating upon a left shoe.

38. A machine for operating on shoes, having, in combination, means for operating on a shoe, mechanism for relatively

- moving and guiding the shoe and operating means to transfer the point of operation along the shoe and maintain the edge of the shoe bottom in the proper position with 5 relation to the operating means transversely of the direction of feed, a jack for the shoe, and two sets of symmetrically arranged and operating devices for moving relatively the operating means and the jack to change the 10 position of the shoe relative to the operating means as the point of operation is transferred about the shoe arranged to be employed alternatively in operating upon right and left shoes.
- 15 38. A machine for operating on shoes, having, in combination, means for operating on a shoe, a jack for the shoe, a cam shaft, a series of cams mounted thereon, and two sets of symmetrically arranged and operating connections for moving relatively the operating means and the jack from the cams to change the position of the shoe relative to the operating means as the point of operation is transferred about the shoe arranged to be employed alternatively in operating upon right and left shoes.
39. A machine for operating on shoes, having, in combination, means for operating on a shoe, a shoe supporting jack comprising a spindle and devices for holding a shoe mounted upon the upper end of the spindle, and two sets of devices for moving the lower end of the spindle in horizontal directions to tip the jack to change the position of the shoe relative to the operating mechanism as the point of operation is transferred about the shoe, arranged to be employed alternatively in operating upon right and left shoes, and operating to move 40 the lower end of the spindle in paths having a symmetrical relation to each other with respect to a plane perpendicular to the line of feed and passing through the point of operation.
40. A machine for operating upon shoes, having, in combination, means for operating upon a shoe, a shoe supporting jack, mechanism for relatively moving and guiding the shoe and operating means to transfer the point of operation along the shoe and maintain the edge of the shoe bottom in the proper position with relation to the operating means transversely of the direction of feed, mechanism for changing the 55 relative positions of the operating means and the jack to present the shoe properly to the operating means as the point of operation is transferred about the shoe comprising a cam shaft, a series of cams removably mounted on the shaft and connections for moving relatively the operating means and the jack from the cams.
41. A machine for operating on shoes, having, in combination, means for operating on a shoe, a shoe supporting jack comprising a spindle and devices for holding a shoe mounted upon the upper end of the spindle, devices for supporting the spindle, a pivotal connection between said devices and the spindle permitting the spindle to tilt about a point relatively remote from the point of operation, means for moving the lower end of the spindle in horizontal directions to tip the jack to change the position of the shoe relative to the operating mechanism as the point of operation is transferred about the shoe, and devices located at the point of operation for controlling the position of the shoe to cause the tipping movements of the jack to take place about said point.
42. A machine for operating on shoes, having, in combination, means for operating on a shoe, a shoe supporting jack comprising a spindle and devices for holding a shoe mounted upon the upper end of the spindle, devices for supporting the spindle, a universal connection between said devices and the spindle permitting the spindle to tilt in any direction about a point relatively remote from the point of operation, means for moving the lower end of the spindle in horizontal directions to tip the jack to change the position of the shoe relative to the operating mechanism as the point of operation is transferred about the shoe, and devices located at the point of operation for controlling the position of the shoe to cause the tipping movements of the jack to take place about said point.
43. A machine for operating on shoes, having, in combination, means for operating on a shoe, a shoe supporting jack comprising a spindle and devices for holding a shoe mounted upon the upper end of the spindle, devices for supporting the spindle, a pivotal connection between said devices and the spindle permitting the spindle to tilt about a point relatively remote from the point of operation, means for moving the lower end of the spindle in horizontal directions to tip the jack and for rotating the spindle to turn the jack to change the position of the shoe relative to the operating mechanism as the point of operation is transferred about the shoe, and devices located at the point of operation for controlling the position of the shoe to cause the movements of the jack to take place about said point.
44. A machine for operating on shoes, having, in combination, means for operating on a shoe, a shoe supporting jack comprising a spindle and devices for holding a shoe mounted upon the upper end of the spindle, devices for supporting the spindle, a universal connection between said devices and the spindle permitting the spindle to tilt in any direction about a point relatively remote from the point of operation, means for moving the lower end of the spindle in horizontal directions to tip the jack and for rotating the spindle to turn the jack to change the position of the shoe relative to the operating mechanism as the point of operation is transferred about the shoe, and devices located at the point of operation for controlling the position of the shoe to cause the movements of the jack to take place about said point.

horizontal directions to tip the jack and for rotating the spindle to turn the jack to change the position of the shoe relative to the operating mechanism as the point of operation is transferred about the shoe, and devices located at the point of operation for controlling the position of the shoe to cause the movements of the jack to take place about said point.

10. 45. A machine for operating on shoes, having, in combination, means for operating on the shoe, mechanism including a cam shaft and intermediate connections for changing the relative positions of said means and the shoe to present the shoe properly to the operating means as the point of operation is transferred along the shoe, and an intermittently acting variable speed drive for said cam shaft comprising a ratchet wheel, a driving pawl for the ratchet wheel, an oscillatory pawl carrier and actuating means arranged to impart strokes of varying amplitude to the pawl carrier and acting to actuate the pawl carrier throughout substantially the same period in each cycle of operations.

30. 46. A machine for operating on shoes, having, in combination, means for operating on the shoe, mechanism including a cam shaft and intermediate connections for changing the relative positions of said means and the shoe to present the shoe properly to the operating means as the point of operation is transferred along the shoe, and an intermittently acting variable speed drive for said cam shaft comprising a ratchet wheel, a driving pawl for the ratchet wheel, an oscillatory pawl carrier and actuating means arranged to impart strokes of varying amplitude to the pawl carrier.

40. 47. A machine for operating on shoes, having, in combination, means for operating upon the shoe, mechanism for changing the relative positions of said means and the shoe to present the shoe properly to the operating means as the point of operation is transferred along the shoe, and means for restoring said mechanism and the shoe to their proper time relations when said mechanism and the shoe are out of time.

45. 48. A machine for operating on shoes, having, in combination, means for operating upon the shoe, shoe feeding means, mechanism for changing the relative positions of said means and the shoe to present the shoe properly to the operating means as the point of operation is transferred along the shoe, timed for a predetermined feed of the shoe, and means for restoring said mechanism and the shoe to their proper time relations upon a variation from said predetermined feed.

50. 49. A machine for operating on shoes, having, in combination, means for operating on the shoe, shoe feeding means, mechanism for changing the relative positions of

the operating means and the shoe to present the shoe properly to the operating means as the point of operation is transferred along the shoe, and means for adjusting the time relations of the feeding means and said mechanism.

50. A machine for operating on shoes, having, in combination, means for operating on the shoe, mechanism for imparting relative movements to the operating means and shoe in addition to those required to transfer the point of operation along the shoe to present the shoe properly to the operating means as the point of operation is transferred along the shoe, and means controlled from the shoe for adjusting said mechanism.

51. A machine of the class described having, in combination, means for operating on the work, work feeding means, mechanism for changing the relative positions of the operating means and the work to present the work properly to the operating means as the point of operation is transferred along the work, and means controlled from the work support for adjusting the time relations of the feeding means and said mechanism.

52. A machine for operating on shoes having, in combination, means for operating on the shoe, mechanism for changing the relative position of the operating means and the shoe to present the shoe properly to the operating means as the point of operation is transferred along the shoe, and means controlled by the relative positions of the point of operation and a predetermined point in the shoe, for adjusting the operation of said mechanism.

53. A machine of the class described having, in combination, means for operating on the work, work feeding means, mechanism for changing the relative positions of the operating means and the work to present the work properly to the operating means as the point of operation is transferred along the work, and means controlled by the relative positions of the point of operation and a predetermined point in the work, for adjusting the time relations of the feeding means and said mechanism.

54. A machine for operating on shoes having, in combination, means for operating on a shoe, a shoe supporting jack, mechanism for relatively moving and guiding the shoe and operating means to transfer the point of operation along the shoe and maintain the edge of the shoe bottom in the proper position with relation to the operating means transversely of the direction of feed, mechanism for changing the relative positions of the operating means and the jack to present the shoe properly to the operating means as the point of operation is transferred about the shoe, and mechanism controlled from the shoe for adjusting the operation of said mechanism.

55. A machine for operating on shoes having, in combination, means for operating on a shoe, means for feeding the shoe, a shoe supporting jack, mechanism for changing the relative positions of the operating means and the jack to present the shoe properly to the operating means as the point of operations is transferred about the shoe, and mechanism controlled from the shoe for adjusting the time relations of the feeding means and said mechanism.

56. A machine for operating on shoes, having, in combination, means for operating on the shoe, mechanism for changing the relative positions of the operating means and the shoe to present the shoe properly to the operating means as the point of operation is transferred along the shoe, and an intermittently acting variable speed drive for said mechanism arranged to impart an accelerated movement to said mechanism during each actuation thereof.

57. A machine for operating on shoes, having in combination means for operating on a shoe, a shoe supporting jack, mechanism for changing the relative positions of the operating means and the jack to present the shoe properly to the operating means as the point of operation is transferred about the shoe, a movable member, connections for moving a point in said member in predetermined and definite relation to the shoe distances corresponding with the feed movement of the shoe, a second movable member, means for moving a point in the second member in predetermined and definite relation to said mechanism, devices controlled by the relative positions of the respective points in the two members for restoring said mechanism and the shoe to their proper time relations when said mechanism and the shoe are out of time, and means for adjusting the movement of the point in the second member in accordance with the size of the shoe to be operated upon to cause said point to move during the operation between corresponding points on different sizes of shoes distances proportional to the relative sizes of the shoes.

58. A machine for operating on shoes, having in combination means for operating on a shoe, a shoe supporting jack, means for feeding the shoe, mechanism for changing the relative positions of the operating means and the jack to present the shoe properly to the operating means as the point of operation is transferred about the shoe, and means controlled by the relative positions of the operating point of the machine and a predetermined point in the shoe for regulating the time relations of the feeding means and said mechanism.

59. A machine for operating on shoes, having in combination means for operating on a shoe, a shoe supporting jack, means for

feeding the shoe, mechanism for changing the relative positions of the operating means and the jack to present the shoe properly to the operating means as the point of operation is transferred about the shoe, and mechanism for adjusting from the shoe the time relations of the feeding means and said first mentioned mechanism in accordance with the size of the shoe placed in the machine.

60. A machine for operating on shoes, having in combination means for operating on a shoe, a shoe supporting jack, means for feeding the shoe, mechanism for changing the relative positions of the operating means and the jack to present the shoe properly to the operating means as the point of operation is transferred about the shoe, and means for restoring said mechanism to its proper time relation to the shoe when said mechanism and the shoe are out of time, comprising a movable member, connections for moving said member in timed relations to the shoe, a lever, a pattern cam for moving one end of said lever in timed relation to said mechanism, devices controlled by the relative positions of said member and the lever for controlling the time relations of the feeding means and said mechanism, and a variable fulcrum for the lever arranged to be adjusted in accordance with the size of the shoe to be operated upon.

61. A machine for operating on shoes, having in combination means for operating on a shoe, a shoe supporting jack, means for feeding the shoe, mechanism for changing the relative position of the operating means and the jack to present the shoe properly to the operating means as the point of operation is transferred about the shoe, and means for restoring the said mechanism and the shoe to their proper time relations when said mechanism and the shoe are out of time, comprising a movable member, connections for moving said member in timed relation to the shoe, a second movable member, a pattern cam for moving the second member in timed relation to said mechanism, and devices controlled by the relative positions of said members for regulating the time relations of the feeding means and said mechanism.

62. A machine for operating on shoes, having in combination means for operating on a shoe, a shoe supporting jack, means for feeding the shoe, mechanism for changing the relative positions of the operating means and the jack to present the shoe properly to the operating means as the point of operation is transferred about the shoe, and means for adjusting the time relations of the feeding means and said mechanism to restore said mechanism and the shoe to their proper time relations when said mechanism and the shoe are out of time.

63. A machine for operating on shoes, having in combination means for operating on a shoe, a shoe supporting jack, means for feeding the shoe, mechanism for changing the relative positions of the operating means and the jack to present the shoe properly to the operating means as the point of operation is transferred about the shoe, a lever, a connection for moving one end of said lever in timed relation to said mechanism, a connection between the lever and the jack, and a variable fulcrum for the lever arranged to be adjusted through said connection from the jack for the size of the shoe to be operated upon.
64. A machine for operating on shoes, having in combination means for operating on a shoe, a shoe supporting jack, mechanism for changing the relative positions of the operating means and the jack to present the shoe properly to the operating means as the point of operation is transferred about the shoe, means for controlling the time relations of the feeding means and said mechanism, comprising a movable member, a connection for moving said member in timed relation to the shoe, a lever, means for moving the lever in timed relation to said mechanism, devices controlled by the relative positions of said member and the lever for regulating the time relations of the feeding means and said mechanism during the operation of the machine, a movable fulcrum for the lever, a second lever arranged to control the position of the fulcrum of the first lever, and devices controlled by the second lever for regulating the time relations of the feeding means and said mechanism for the size of the shoe to be operated upon, the second lever being adjusted through said connection from the shoe for the size of the shoe.
65. A machine for operating on shoes, having in combination means for operating on a shoe, a shoe supporting jack, means for feeding the shoe, mechanism for changing the relative positions of the operating means and the jack to present the shoe properly to the operating means as the point of operation is transferred about the shoe, means for controlling the time relations of the feeding means and said mechanism, comprising a movable member, a connection for moving said member in timed relation to the shoe, a lever, means for moving the lever in timed relation to said mechanism, devices controlled by the relative positions of said member and the lever for regulating the time relations of the feeding means and said mechanism during the operation of the machine, and a movable fulcrum for the lever arranged to be adjusted through said connection from the shoe for the size of the shoe to be operated upon.
66. A machine for operating on shoes, having in combination means for operating on a shoe, a shoe supporting jack, mechanism for changing the relative positions of

the operating means and the jack to present the shoe properly to the operating means as the point of operation is transferred about the shoe, a lever, a connection for moving one end of said lever in timed relation to said mechanism, a connection between the lever and the jack, and a variable fulcrum for the lever arranged to be adjusted through said connection from the jack for the size of the shoe to be operated upon.

67. A machine for operating on shoes, having in combination means for operating on a shoe, a shoe supporting jack, mechanism for changing the relative positions of the operating means and the jack to present the shoe properly to the operating means as the point of operation is transferred about the shoe, a lever, a connection for moving one end of said lever in timed relation to said mechanism, a connection between the lever and the jack, a variable fulcrum for the lever, a second lever arranged to control the position of the fulcrum of the first lever, and devices controlled by the second lever for regulating the time relations of the feeding means and said mechanism, the second lever being adjusted through said connection from the jack for the size of the shoe to be operated upon.

68. A machine for operating on shoes, having in combination means for operating on a shoe, a shoe supporting jack, devices for supporting the jack so that the end of the jack adjacent the point of operation and the end of the jack remote from the point of operation are each freely movable independently of the other in any direction laterally of the jack, and mechanism for moving the jack to change the position of the shoe with relation to the operating means to present the shoe properly to the operating means as the point of operation is transferred about the shoe.

69. A machine for operating on shoes, having in combination means for operating on a shoe, a shoe supporting jack, devices for supporting the jack so that the end of the jack adjacent the point of operation and the end of the jack remote from the point of operation are each freely movable independently of the other in any direction laterally of the jack, mechanism for moving the jack to change the position of the shoe with relation to the operating means to present the shoe properly to the operating means as the point of operation is transferred about the shoe, and devices engaging the shoe and acting to cause the movements of the jack to take place about the point of operation.

70. A machine for operating on shoes, having in combination means for operating on a shoe, a shoe supporting jack, devices for supporting the jack so that the end of the

5 jack adjacent the point of operation and the end of the jack remote from the point of operation are each freely movable independently of the other in any direction laterally of the jack, devices engaging the shoe and acting to control the lateral position thereof, and mechanism for moving the jack to change the position of the shoe with relation to the operating means to present the 10 shoe properly to the operating means as the point of operation is transferred about the shoe, comprising devices acting on the jack at a point relatively remote from the point of operation to move this point in the jack 15 in directions laterally of the jack and to control the lateral position of this point.

71. A machine for operating on shoes, having in combination means for operating on a shoe, a shoe supporting jack, devices for 20 supporting the jack so that the end of the jack adjacent the point of operation and the end of the jack remote from the point of operation are each freely movable independently of the other in any direction laterally 25 of the jack, devices engaging the shoe and acting to move the shoe laterally in a direction to transfer the point of operation about the shoe, and to control the lateral position of the shoe in other directions, and mechanism for moving the jack to change the 30 position of the shoe with relation to the operating means to present the shoe properly to the operating means as the point of operation is transferred about the shoe, comprising devices acting on the jack at a point relatively remote from the point of operation to move this point in the jack in directions laterally of the jack and to control the lateral 35 position of this point.

72. A machine for operating on shoes, having in combination means for operating on a shoe, a shoe supporting jack, devices for supporting the jack so that the end of the jack adjacent the point of operation and the 40 end of the jack remote from the point of operation are each freely movable independently of the other in any direction laterally of the jack, devices acting at the end of the jack adjacent the point of operation to control the lateral position of the shoe, and devices acting at the end of the jack remote from the point of operation to move this end of the jack in directions laterally of the jack and to control the lateral 45 position thereof.

73. A machine for operating on shoes, having in combination means for operating on a shoe, a shoe supporting jack, devices for supporting the jack so that the end of the jack adjacent the point of operation and the end of the jack remote from the point of operation are each freely movable independently of the other in any direction laterally of the jack, devices acting at the end of the jack adjacent the point of operation to move 50 the shoe laterally in a direction to transfer

the point of operation about the shoe and to control the lateral position of the shoe in other directions, and devices acting at the end of the jack remote from the point of operation to move this end of the jack in directions laterally of the jack and to control the lateral position thereof. 70

74. A machine for operating on shoes having, in combination, means for operating on a shoe, a shoe supporting jack, means for feeding the shoe, mechanism for changing the relative positions of the jack and the operating means to present the shoe properly to the operating means as the point of operation is transferred about the shoe, and 80 mechanism adjusted by the placing of the shoe in position in the machine to start the operation thereon for regulating the time relations of the feeding means and said mechanism in accordance with the size of the shoe. 85

75. A machine for operating on shoes having, in combination, means for operating on a shoe, a shoe supporting jack, devices for feeding the shoe arranged to engage directly the shoe, and mechanism continuously in operation throughout the operation for changing the relative positions of the jack and the operating means to present the shoe properly to the operating means as the point of operation is transferred about the shoe. 90

76. A machine for operating on shoes having, in combination, means for operating on a shoe, a shoe supporting jack, means for feeding the shoe arranged to engage directly the shoe, mechanism continuously in 100 operation throughout the operation for changing the relative positions of the jack and the operating means to present the shoe properly to the operating means as the point of operation is transferred about the shoe, and automatically acting means for causing the feeding means and said mechanism to act in proper timed relation. 105

77. A machine for operating on shoes having, in combination, means for operating on a shoe, a shoe supporting jack, devices for supporting the jack comprising a support pivoted to swing forwardly and rearwardly of the machine, a support pivoted to swing laterally of the machine, a support pivoted 115 to swing vertically, a connection between one of said supports and the jack permitting universal swinging movements of the jack about a point relatively remote from the point of operation, and mechanism for moving the jack to change the position of the jack with relation to the operating means to present the shoe properly to the operating means as the point of operation is transferred about the shoe. 120

78. A machine for operating on shoes having, in combination, means for operating on a shoe, a shoe supporting jack, devices for supporting the jack comprising a support pivoted to swing forwardly and rear- 130

wardly of the machine, a second support carried by the first support and pivoted to swing laterally of the machine, a third support pivotally mounted on the second support to swing vertically, a connection between the third support and the jack permitting universal swinging movement of the jack about a point relatively remote from the point of operation, and means for moving the jack to change the position of the jack with relation to the operating means to present the shoe properly to the operating means as the point of operation is transferred about the shoe.

15 79. A machine for sewing outsoles of welted shoes having, in combination, a shoe supporting jack, means for imparting lateral movements to the jack, and devices including a needle, an awl, a presser foot and a work support engaging the shoe at the point of operation and causing the movements imparted to the jack to tip the jack and shoe about said devices as a fulcrum to locate the shoe bottom in the proper plane.

20 80. A machine for operating on shoes having, in combination, a shoe supporting jack, means for imparting lateral movements to the jack, and devices engaging the shoe at the point of operation and causing the lateral movements imparted to the jack to tip the jack and shoe about said devices as a fulcrum to locate the shoe bottom in the proper plane.

25 81. A machine for operating on shoes having, in combination, means for operating on a shoe, a shoe supporting jack, mechanism for changing the relative positions of the jack and the operating means to present the shoe properly to the operating means as the point of operation is transferred about the shoe, means for locating the shoe in a predetermined position longitudinally on the jack, and means controlled from the jack for controlling the relative speeds of the shoe and said mechanism.

30 82. A machine for operating on shoes having, in combination, means for operating on a shoe, a shoe supporting jack, means for feeding the shoe, mechanism for changing the relative positions of the jack and the operating means to present the shoe properly to the operating means as the point of operation is transferred about the shoe, means for locating the shoe in a predetermined position longitudinally on the jack, and means controlled from the jack for controlling the relative speeds of the feeding means and said mechanism.

35 83. A machine for operating on shoes having, in combination, means for operating on a shoe, a shoe supporting jack, mechanism for imparting relative movements to the operating means and jack in addition to those required to transfer the point of operation

about the shoe to present the shoe properly to the operating means as the point of operation is transferred about the shoe, and means for adjusting said mechanism for the size of shoe to be operated upon by the placing of the shoe in position in the machine to start the operation.

40 84. A machine for operating on shoes having, in combination, means for operating on a shoe, a shoe supporting jack, mechanism for changing the relative positions of the jack and the operating means to present the shoe properly to the operating means as the point of operation is transferred about the shoe, means for locating the shoe in a predetermined position longitudinally on the jack, and means for adjusting the action of said mechanism for the size of the shoe to be operated upon by the placing of the shoe in operating position in the machine.

45 85. A machine for operating on shoes having, in combination, means for operating on a shoe, shoe supporting devices, means for feeding the shoe, mechanism for changing the relative positions of the jack and the operating means to present the shoe properly to the operating means as the point of operation is transferred about the shoe, means for adjusting the shoe in a predetermined position longitudinally on the jack, and means controlled from the jack for adjusting the time relations of the feeding means and said mechanism for the size of the shoe to be operated upon by the placing of the shoe in operating position in the machine.

50 86. A machine for operating on shoes having, in combination, a shoe supporting jack mounted so that it is free from constraint to tip or turn about the point of operation, devices engaging the shoe at the point of operation and furnishing a fulcrum for the shoe, and means for moving the jack to impart longitudinal and lateral tipping movements and lateral turning movements to the jack and shoe about said devices as a fulcrum.

55 87. A machine for operating on shoes having, in combination, means for operating on a shoe, a shoe supporting jack, mechanism for feeding the shoe, mechanism for changing the relative positions of the shoe and the operating means to present the shoe properly to the operating means as the point of operation is transferred about the shoe, and means controlled from the shoe for adjusting one of said mechanisms.

60 88. A machine for operating on shoes having, in combination, means for operating on a shoe, a shoe supporting jack, mechanism for feeding the shoe, mechanism for changing the relative positions of the shoe and the operating means to present the shoe properly to the operating means as the point of operation is transferred about the shoe comprising

ing a main actuating cam shaft, and mechanism controlled from the shoe for adjusting the speed of the cam shaft.

89. A machine for operating on shoes having, in combination, a shoe supporting jack, devices for engaging a shoe supported thereon to determine the point about which the jack and shoe may tip and turn, and mechanism acting to tip and turn the jack on said devices as said point is transferred along the shoe.

90. A machine for operating on shoes having, in combination, a shoe supporting jack, devices for engaging a shoe supported thereon to determine the point about which the jack and shoe may tip, and mechanism acting to tip the jack on said devices as said point is transferred along the shoe.

91. A machine for operating on shoes having, in combination, a shoe supporting jack, devices for engaging a shoe supported thereon to determine the point about which the jack and shoe may tip, supporting devices at the lower end of the jack mounted to permit movement of the lower end of the jack in any direction, and pivotal connections between the jack and supporting devices permitting the upper end of the jack to swing laterally in any direction, said shoe engaging and jack supporting devices determining the position of the shoe throughout the operation thereon.

92. A machine for operating on shoes having, in combination, a shoe supporting jack, devices for engaging a shoe supported thereon to determine the point about which the jack and shoe may tip, supporting devices at the lower end of the jack mounted to permit movement of the lower end of the jack in any direction, and connections between the jack and supporting devices permitting the jack to turn, and its upper end to swing laterally in any direction, said shoe engaging and jack supporting devices determining the position of the shoe throughout the operation thereon.

93. An outsole shoe sewing machine having, in combination, sewing mechanism, a shoe supporting jack, and mechanism acting automatically wholly to control the position of the jack relatively to the sewing mechanism to cause the outseam to be formed in a predetermined position on the shoe.

94. An outsole shoe sewing machine having, in combination, a work support and a presser foot arranged to receive the projecting edge of a shoe sole between them, stitch forming devices, a shoe supporting jack, and mechanism acting automatically to relatively actuate the jack and stitch forming devices to cause the outseam to be formed in a predetermined position on a shoe supported on the jack.

95. A machine for operating on shoes hav-

ing, in combination, means for operating on a shoe, a shoe supporting jack longitudinally movable and rotatable to transfer the point of operation about the shoe, a cam shaft mounted independently of the jack, and connections between the jack and the cam shaft for imparting rotary and tipping movements to the jack.

96. A machine for operating on shoes having, in combination, means for operating on a shoe, a shoe supporting jack movable to transfer the point of operation along the shoe, a cam shaft mounted independently of the jack, shoe feeding means acting directly on the shoe, and connections between the jack and cam shaft for imparting tipping movements to the jack.

97. A machine for operating on shoes having, in combination, means for operating on a shoe, a shoe supporting jack movable to transfer the point of operation along the shoe, a guide engaging a contour of the shoe and cooperating therewith to determine the outline operated upon, a cam shaft mounted independently of the jack, and connections between the jack and the cam shaft for imparting tipping movements to the jack.

98. A machine for operating on shoes having, in combination, means for operating on a shoe, a shoe supporting jack movable to transfer the point of operation along the shoe, a cam shaft mounted independently of the jack, connections between the cam shaft and jack for moving the jack to bring the portion of the sole near the operating point into the desired plane, and means including a pattern cam on the cam shaft and connections actuated thereby between the cam and the jack for maintaining the shoe and the cam shaft in the proper time relation.

99. A machine for operating on shoes having, in combination, means for operating on a shoe, a shoe supporting jack movable to transfer the point of operation along the shoe, a cam shaft, mechanism actuated by the cam shaft for moving the jack to bring the portion of the sole near the operating point into the desired plane, means including a pattern cam on the cam shaft and connections actuated thereby between the pattern cam and the jack for maintaining the shoe and the cam shaft in the proper time relation, means for adjusting said connections for operation with shoes of different sizes, and means for adjusting the speed of said cam shaft.

100. A machine for operating on shoes having, in combination, means for operating on a shoe, driving mechanism therefor, a shoe supporting jack, mechanism including a cam shaft and intermediate connections for changing the relative positions of the operating means and the jack to present the shoe properly to the operating means as the

point of operation is transferred about the shoe, and means for adjusting the relative speeds of said mechanisms.

101. A machine for operating on shoes having, in combination, means for operating on a shoe, a shoe supporting jack, means for feeding the shoe, mechanism including a cam shaft and intermediate connections for changing the relative positions of the operating means and the jack to present the shoe properly to the operating means as the point of operation is transferred about the shoe, and means for adjusting the speed of said mechanism.

102. A machine for operating on shoes having, in combination, means for operating on a shoe, a shoe supporting jack, shoe feeding means acting directly on the shoe, mechanism for changing the relative positions of the operating means and the jack to present the shoe properly to the operating means as the point of operation is transferred about the shoe, and means for adjusting the relative speeds of said mechanism and the feed of the shoe.

103. A machine for operating on shoes having, in combination, means for operating on a shoe, a shoe supporting jack, means for feeding relatively the shoe and the operating means to transfer the point of operation about the shoe, mechanism including a cam shaft and intermediate connections for changing the relative positions of the operating means and the jack to present the shoe properly to the operating means as the point of operation is transferred about the shoe, and means for adjusting the speed of said mechanism.

104. A machine for operating on shoes having, in combination, means for operating on a shoe, a shoe supporting jack, mechanism for relatively moving and guiding the shoe and operating means to transfer the point of operation along the shoe and maintain the edge of the shoe bottom in the proper position with relation to the operating means transversely of the direction of feed, mechanism for changing the relative positions of the operating means and the jack to present the shoe properly to the operating means as the point of operation is transferred about the shoe, and means for driving said mechanism in reverse directions.

105. A machine for operating upon shoes, having, in combination, means for operating on a shoe, a shoe supporting jack, mechanism for changing the relative positions of the operating means and the jack to present the shoe properly to the operating means as the point of operation is transferred about the shoe comprising, a cam shaft, a series of cams mounted thereon, connections for moving relatively the operating means and the jack from the cams, means for driving the cam shaft in one direction during the

normal operation of the machine, means for stopping the machine before the operation on the shoe is completed, means for driving the cam shaft in the reverse direction, and means for throwing out the reverse driving mechanism.

106. A machine for operating upon shoes, having, in combination, means for operating on a shoe, a shoe supporting jack, mechanism for relatively moving and guiding the shoe and operating means to transfer the point of operation along the shoe and maintain the edge of the shoe bottom in the proper position with relation to the operating means transversely of the direction of feed, mechanism for changing the relative positions of the operating means and the jack to present the shoe properly to the operating means as the point of operation is transferred about the shoe comprising, a cam shaft, a series of cams mounted thereon, connections for moving relatively the operating means and the jack from the cams, means for driving the cam shaft in one direction during the normal operation of the machine and means for reversing the direction of rotation of the cam shaft.

107. A machine for operating upon shoes, having, in combination, means for operating on a shoe, a shoe supporting jack, mechanism for changing the relative positions of the operating means and the jack to present the shoe properly to the operating means as the point of operation is transferred about the shoe, mechanism for driving the operating means and said first mentioned mechanism during the operation on the shoe, and mechanism for driving said first mentioned mechanism independently of the operating means to bring the jack to starting position.

108. A machine for operating upon shoes, having, in combination, means for operating on a shoe, a shoe supporting jack, mechanism for changing the relative positions of the operating means and the jack to present the shoe properly to the operating means as the point of operation is transferred about the shoe comprising, a cam shaft, a series of cams mounted thereon, connections for moving relatively the operating means and the jack from the cams, and means for driving the cam shaft independently of the operating means after the completion of the operation on the shoe.

109. A machine for operating upon shoes, having, in combination, means for operating on a shoe, a shoe supporting jack, mechanism for changing the relative positions of the operating means and the jack to present the shoe properly to the operating means as the point of operation is transferred about the shoe comprising, a cam shaft, a series of cams mounted thereon, connections for moving relatively the operating means and the

5 jack from the cams, mechanism for driving the cam shaft in either direction through a portion of a revolution during the operation on a shoe and for then completing the rotation, and means for starting and stopping the shaft at a certain point when rotated in one direction and at a different point when rotated in the opposite direction.

110. A machine for operating upon shoes, 10 having, in combination, means for operating on a shoe, a shoe supporting jack, mechanism for changing the relative positions of the operating means and the jack to present the shoe properly to the operating means as 15 the point of operation is transferred about the shoe comprising, a cam shaft, a series of cams mounted thereon, connections for moving relatively the operating means and the jack from the cams, mechanism for driving 20 the cam shaft in either direction through a portion of a revolution during the operation on a shoe and for then completing the rotation, two stop cams driven by the cam shaft, stopping devices for stopping the rotation 25 of the cam shaft, connections between said devices and said stop cams, and means for adjusting said connections to render one stop cam operative when the shaft is rotated in one direction and the other stop cam operative when the shaft is rotated in the 30 opposite direction.

111. A machine for operating on shoes

having, in combination, means for operating along the bottom margin of a shoe, a shoe supporting jack, mechanism adjusted for 35 operation with shoes of different sizes by a movement of the jack to bring the shoe to starting position, and locking devices for locking said mechanism in adjusted condition. 40

112. A machine for operating on shoes having, in combination, means for operating along the bottom margin of a shoe, a shoe supporting jack, mechanism adjusted for 45 operation with shoes of different sizes by a movement of the jack to bring the shoe to starting position, locking devices for locking said mechanism in adjusted condition, and means under the control of the operator for actuating said devices to unlock said 50 mechanism.

113. A machine for operating on shoes having, in combination, means for operating along the bottom margin of a shoe, a shoe supporting jack, mechanism adjusted for 55 operation with shoes of different sizes by a movement of the jack to bring the shoe to starting position, locking devices for locking said mechanism in adjusted condition, a starting member, and connections from said 60 member for actuating said devices to lock said mechanism.

LAURENCE E. TOPHAM.
